UNITED STATES PATENT OFFICE

2,359,851

PRINTING MACHINE

Carl J. Hueber, Euclid, Ohio, assignor to Addressograph-Multigraph Corporation, Wilmington, Del., a corporation of Delaware

Application May 6, 1941, Serial No. 392,151

49 Claims. (Cl. 101—58)

This invention relates to printing machines of the kind through which printing devices are sequentially passed, and more particularly to selectively controlling operation of one or more mechanisms embodied in the machine under control of identifying means included on the printing devices.

In machines of the aforesaid character the printing devices are customarily advanced in a step by step manner from a magazine, into which the printing devices are introduced, to a printing position or other place in the machine whereat operations are performed directly therefrom or under control thereof, and thereafter the printing devices are collected in the same sequence as that in which they were arranged when introduced into the magazine.

While the present invention may be used with any of a wide variety of printing devices, the illustrated form of the invention is adapted for use with printing devices of the character disclosed, in Gollwitzer Patent No. 2,132,412, patented October 11, 1938, printing devices of this character being arranged to have index tabs detachably connected thereto so as to project beyond one edge thereof at selected positions along such edge, this particular arrangement being shown and described in detail in Gollwitzer Patent No. 2,049,439 patented August 4, 1936. However, the invention may also be used with other printing devices, as for example, those of the character shown in Gollwitzer Patent No. 1,992,661 patented February 26, 1935, which is to say, printing devices of the one piece variety that have notches or other lacuna selectively located along one edge thereof to afford identifying means on the printing device. Furthermore the invention may also be used with printing devices of character comprising a frame enclosing a thin sheet of stencil paper or the like and in which frame perforations, notches or other lacuna may be selectively located to afford identifying means on such printing devices.

In those instances where the printing devices such as the foregoing, or other equivalent devices, are equipped with identifying means and the operation of various mechanisms embodied in the machine are to be controlled in accordance with the characteristics imparted to the respective printing devices by the identifying means included thereon, each such printing device is passed to a sensing station in the machine whereat detecting means cooperate with the identifying means on such printing device and such de-

tecting means are caused to assume various positions in accordance with the characteristics of the identifying means with which the detecting means cooperate in a particular operation thereof. Other means are provided in the machine that are responsive to the various positions that may be assumed by the detecting means and such other means are customarily arranged to selectively control the operation of one or more mechanisms included in the machine.

Heretofore the detecting means have usually cooperated with the identifying means on the printing device at sensing station in one cycle of operation of the machine and then such means have been effective in the succeeding cycle of operation to control operation of a particular mechanism in such succeeding cycle of operation, or such detection has been effective in one portion of a cycle of operation of the machine and this has been effective to control operation of a mechanism in the machine in another portion of the cycle of operation in which the detection is effected.

There are, however, many instances where the sensing or detecting of the identifying means on a printing device at a sensing station in a printing machine may be advantageously effected in a particular cycle of operation, but where the operation of one or more mechanisms in the machine is to be controlled in a cycle of operation other than the same or the succeeding cycle of operation of the machine in which the detection is effected, and to enable this to be accomplished is the primary object of the present invention.

The means in the machine responsive to the identifying means of the printing devices including the aforesaid detecting means is commonly known as a selector mechanism and such a mechanism may be employed to selectively govern or control many different operations or operative mechanisms of a printing machine in accordance with the identifying means carried by the individual printing devices which are passed through the machine.

For example, the selector mechanism may be employed to warn the operator by means of a suitable signal such as light or a bell when a printing device having identifying means thereon at a particular position is being advanced to an operative position in the machine. Such a warning may be desirable for a variety of reasons, as for example when the operator desires to utilize a particular or different type of form or letter in connection with all printing devices

bearing particular identifying means. In other instances the selector mechanism may be utilized to selectively control the operation of the printing means of the printing machine so as to print or skip each printing device in accordance with the sensed presence or absence of certain identifying means on the printing devices. In other instances it may be desirable to control other operative mechanisms of the machine, as for example, a numbering machine, or the selector mechanism may in some instances govern the final disposal of the printing devices after they have passed printing position in such a manner as to remove selected ones of the printing devices from the series thereof which has been passed through the machine. It is to be understood that the foregoing are merely typical examples of uses to which a selector mechanism may be put and that there are many other machine operations that may be controlled by a selector mechanism.

It has heretofore been customary in printing machines of the character to which this invention relates to locate the sensing station immediately ahead of or relatively close to printing position, but it has been found that with such a location of the sensing station, the construction and arrangement of the printing machine has been somewhat limited and restricted so that maximum utility of the machine could not always be attained. For example, it has been found that the location of the sensing station relatively close to the printing position has sometimes resulted in undesirable obstruction of the working space available about the printing position, so that the size of the sheet or form which could be used with machines of such character was sometimes limited, and in addition such location of the sensing station or sensing means served to limit in certain respects the positioning of the printing impression on the sheet or form. Accordingly, it is another object of the invention to incorporate a selector mechanism in a printing machine in such a manner as to obviate the aforesaid and like inconveniences and limitations with respect to the size and possible location of the sheet or form. Another object related to the foregoing is to enable the sensing station of a selector mechanism in a printing machine of the aforesaid character to be located in a relatively remote relation with respect to the printing station, and to attain a wide variety of adjustments or settings in the selector mechanism even though several intermediate machine cycles take place after the sensing operation and before the sensed printing device reaches an operative position in the machine.

A further object is to enable the identification or classification areas required on printing devices used in printing machines of the aforesaid character to be materially reduced in size, thereby to increase the number of possible classifications to be increased with respect to printing devices of any given or selected size; and a further object is to confine the sensing means in such a printing machine to a relatively small area while at the same time enabling a large number of sensing positions to be employed.

A further object is to enable a high degree of accuracy to be obtained in the sensing of the identification means of printing devices used in printing machines of the aforesaid character; and a further object related to the foregoing is

to relate the sensing means and the control means of a selector mechanism in a novel and advantageous manner.

5 A further object is to enable a wide range of control functions to be attained in a selector mechanism employed in a printing machine; and a further object related to the foregoing is to enable such a wide range of control functions to be attained in such a manner that a delay controlling action may be performed in each instance.

10 A selector mechanism of the aforesaid character may, of course, be used where but one printing impression is made from each selected printing device, but there are some types of work, such as two column listing as accomplished by the lister illustrated in my copending application, Ser. No. 410,097 filed September 8, 1941, wherein a plurality of printing impressions are made from each selected printing device, and another object of the present invention is to so relate the selector mechanism to the other control elements of the printing machine that the selector mechanism responds inherently to the type of work which is being performed by the machine and exercises its controlling functions in an accurate manner irrespective of the setting of the printing machine for single or multiple impression operation.

15 20 25 30 35 40 45 50 55 60 65 70 A further object of the invention is to enable a selector mechanism to be readily incorporated in a printing machine of the aforesaid character; to enable the control means of such a selector mechanism to be readily associated with the elements of such a printing machine; and to enable the various adjustments or variable settings of the selector mechanism to be readily attained from the front or control panel of such a printing machine, and another object related to the foregoing is to enable the variably settable sensing means of such a selector mechanism to be located in a readily accessible position in a printing machine of this character.

55 60 65 70 Other and further objects of the invention are to utilize a vertically reciprocable sensing in the selector mechanism of printing machines of the aforesaid character; to shield the moving parts of the sensing means while providing for convenient setting thereof; to insure accuracy of the sensing operations in such a machine through interrelated means for accurately positioning the printing devices during the sensing operation; to actuate the sensing means in a simple and expeditious manner and to conveniently control the operative condition or adjustment of the sensing means; to interrelate the alarm or signal means with the sensing means to obtain actuation of the signal means by the means which actuates the sensing means; to control the signal means in an indirect and delayed manner under the control of the sensing means in one cycle of its operation and to attain proper timing of the signal means under control of the sensing means in another cycle of its operation; to utilize storage means adapted to be set up under control of the sensing means and embodying a rotatable storage drum having slidable storage plungers having different positions on said drum indicative of the control operations to be performed; to provide a relatively large number of control positions for the storage plungers on the storage drum; to employ a set-up mechanism for the storage plungers operative to set such plungers in any one of the plurality of control positions afforded for such plungers; to utilize a cam and

follower means in operatively associating the sensing means with the set-up means provided for the storage plungers; to enable control operations to be performed by the storage plungers in accordance with their set-up control positions on the storage drum, and to enable the control operation to be performed by such storage plunger several cycles after the machine cycle in which the set-up operation is performed thereon; to enable the controlling action of the storage plungers in at least one of their control positions to be varied or changed; to enable similar control operations to be attained for different control positions of the storage plungers; to interrelate the control means actuated or governed by the storage plungers to attain, selectively, either a single control operation or a plurality of control operations; to restore the storage plungers in a simple and effective manner after the performance of the desired control functions thereby; to relate the storage means to the printing means in such a manner that the controlling action upon the printing means is exercised in an accurate and effective manner; and to render the storage means effective to produce the required controlling action in the same efficient manner whether the printing machine is set-up for single or multiple impression work.

Other and further objects of the present invention will be apparent from the following description and claims and are illustrated in the accompanying drawings which, by way of illustration, show three preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawings,

Fig. 1 is a perspective view illustrating a printing machine embodying the features of my invention;

Fig. 2 is a plan view taken partially in section and illustrating the machine with the table top removed so as to expose the internal mechanism;

Fig. 3 is a vertical sectional view taken substantially along the line 3—3 of Fig. 2;

Fig. 4 is an enlarged fragmental vertical sectional view taken substantially along the line 4—4 of Fig. 2;

Fig. 5 is an enlarged fragmental vertical sectional view taken substantially along the line 5—5 of Fig. 2;

Figs. 6, 7, 8 and 9 are similar fragmental plan views illustrating the printing device guideway and showing the printing device advancing means in different portions of its operative cycle;

Fig. 10 is a fragmental vertical sectional view taken substantially along the line 10—10 of Fig. 2;

Fig. 10A is a fragmental perspective view of the machine with the table top removed, the view being taken from the left-hand rear corner of the machine;

Fig. 11 is an enlarged fragmental plan view of the drive mechanism of the machine shown in association with a portion of the control mechanism of the machine;

Fig. 12 is a vertical sectional view taken just forwardly of the main drive shaft of the machine along the line 12—12 in Fig. 11;

Fig. 13 is a fragmental rear elevational view

of the machine with the rear cover plate or panel of the machine removed so as to show the internal construction;

Fig. 14 is a fragmental perspective view taken from the right-hand forward corner of the machine with the cover plate removed so as to show features of internal construction;

Fig. 15 is an elevational view showing the forward or operative face of one form of printing device adapted to be used in the machine disclosed herein;

Fig. 16 is an elevational view of the rear or reverse face of the printing device;

Fig. 17 is a perspective view of a pin carrier or selector bar of the 24-position type;

Fig. 18 is a vertical sectional view taken along the line 18—18 of Fig. 17;

Figs. 19, 20 and 21 are similar elevational views showing the different types of selector pins adapted for use with identifying means such as the tabs shown on the printing device in Figs. 15 and 16;

Fig. 22 is a perspective view of a 48-position pin carrier or selector bar adapted for use in the present machine;

Fig. 23 is a sectional view taken along the line 23—23 of Fig. 22;

Fig. 24 is an elevational view showing a selector pin of a different type in an operative relationship to an index tab of the embossed type;

Fig. 25 is a fragmental elevational view showing a printing device having embossed tabs in position thereon;

Fig. 26 is a fragmental elevational view of a printing device having perforated index tabs thereon;

Fig. 27 is an elevational view of a selector pin adapted for use with perforated tabs such as those shown in Fig. 26;

Fig. 28 is a view showing a printing device having index tabs of the perforated type mounted thereon, the index tabs shown in Fig. 28 having five classification or identifying areas rather than four classification areas as shown in Fig. 26;

Fig. 29 is a fragmental perspective view of a 60-position pin carrier or selector bar adapted for use in connection with perforated tabs such as those shown in Fig. 28;

Fig. 30 is a fragmental plan view showing a tab support adapted for use with the pin carrier;

Fig. 31 is a fragmental vertical sectional view taken along the line 31—31 of Fig. 2 and showing a portion of the sensing means and the related mechanism;

Fig. 32 is a fragmental plan section taken along the line 32—32 of Fig. 31;

Fig. 33 is a fragmental plan section taken along the line 33—33 of Fig. 31;

Fig. 34 is a fragmental plan view taken as viewed from the line 34—34 of Fig. 31;

Fig. 35 is a fragmental vertical sectional view taken substantially along the line 35—35 of Fig. 2 and showing portions of the sensing means, the storage means and the associated control means;

Fig. 36 is a fragmental vertical elevational view, taken substantially along the line 36—36 in Fig. 12;

Fig. 37 is a fragmental vertical sectional view taken substantially along the line 37—37 of Fig. 12;

Fig. 38 is a fragmental vertical sectional view taken substantially along the line 38—38 of Fig. 12;

Fig. 39 is a fragmental sectional view taken substantially along the line 39—39 of Fig. 12;

Fig. 40 is a fragmental plan view taken substantially along the line 40—40 of Fig. 35 and illustrating in a diagrammatic manner the connection of the various parts of the selector mechanism;

Figs. 41 and 42 are similar views taken in vertical section along the line 41—41 of Fig. 40 and illustrating the actuating connection for the storage mechanism, this actuating connection being shown in different positions in the two views;

Fig. 43 is a fragmental plan view taken partially in section along the line 43—43 of Fig. 35;

Figs. 44 and 45 are horizontal sectional views taken substantially along the line 44—44 of Fig. 35 and showing the set-up means of storage mechanism in different operative positions;

Fig. 46 is a vertical sectional view taken through the axis of the storage drum;

Fig. 47 is a fragmental perspective view showing the relationship of the control levers of the selector mechanism;

Fig. 48 is a plan section taken substantially along the line 48—48 of Fig. 35;

Fig. 49 is a vertical sectional view taken along the line 49—49 of Fig. 48;

Figs. 50, 51 52 and 53 are generally similar views constituting an enlarged portion of Fig. 46 and illustrating the storage plungers in different set-up positions;

Fig. 54 is a view similar to Fig. 46 showing one of the control levers in a different position of adjustment wherein the machine is operative to print from each printing device upon which a regular pin in the sensing mechanism has sensed a tab;

Fig. 55 is a view similar to Fig. 54 and showing one of the control levers in a different position;

Fig. 56 is a vertical sectional view taken substantially along the line 56—56 of Fig. 46;

The machine generally

For purposes of disclosure the invention is herein illustrated as embodied in a printing machine having a desk-like frame 100 providing a table top T upon which envelopes, letters, forms, or the like may be positioned for the performance of a printing operation thereon. The machine frame 100 is so constructed and arranged that an operator may be seated in front of the frame 100 and adjacent to a forward edge 101 of the table top T, and while seated in this working position the operator may place the sheet or form over a printing position V which is provided in the table top T adjacent to the forward edge 101 thereof.

The present machine is of the character through which a plurality of printing devices D are advanced along a printing device guideway in series and in a step by step manner by suitable feeding means from a supply magazine M to the printing position V, and thence to a collector means K wherein the printing devices D are refiled in their original sequence. When a printing device D comes to rest at printing position V, a suitable printing means such as a platen mechanism P is operable through a printing stroke to form the desired printing impression on the sheet.

The printing devices D employed in a printing machine of this character are so constructed and arranged that index or identifying means representing one or more classifications to which a printing device may pertain may be incorporated in or carried by each printing device, and variably settable selector means are incorporated in the present machine for controlling various operative mechanisms of the machine in accordance with the characteristics imparted to the printing devices by identifying means thereon. The selector means embodies a variably settable sensing means S which senses the identifying means of each printing device D as it comes to rest at a sensing station II, and in accordance with the sensed indication pertaining to each printing device, the operation of various operative mechanisms may be controlled. Such controlling action may be exerted in various ways, as for example afford a warning signal, or in the control of the platen mechanism P to either print or skip the particular printing device when it reaches

The printing devices

While the selector means of the present invention is, in most of its aspects, independent of the particular form or type of printing device and independent of the particular type of identifying means employed to represent the identity of classification of such printing devices, it will be understood that the specific form and relationship of the elements and mechanisms of the printing machine are influenced by the character of the printing means and identifying means to be employed therewith. Thus the printing machine disclosed herein is constructed and arranged particularly for the use of printing devices D such as those shown in Figs. 15 and 16 of the drawings, and for the selection of such printing devices D for print or skip operation of the machine in accordance with identifying means in the form of projecting index tabs 120 adapted to be carried in selected positions along the upper edge of each printing device.

One form of such a printing device D is illustrated and claimed in the patent to Gollwitzer, No. 2,132,412, patented October 11, 1938, and is shown in Figs. 15 and 16 hereof. The printing device D comprises a rectangular sheet metal frame 105 having a curled lower edge 106 and lugs 107 forming a guideway on the operative face thereof into which an embossable printing plate 108 may be inserted by an endwise movement. Spring latches 109 formed from the metal of the frame 105 engage the ends of the printing plate 108 to retain the same releasably in position on the frame. Along the upper portion of the operative face of the printing frame an index card 110 may be positioned as by a curled upper edge 111 and a plurality of lugs 112 formed on the frame; and an index impression 116 may be made on the card 110 from the type characters 116 embossed on the printing plate 108. Such embossure of the type characters on the printing plate 108 may be accomplished by means of an embossing machine such as that shown in Duncan Patent No. 1,518,904, patented December 9, 1924. At its opposite ends the frame 105 is reversely bent to provide spacing flanges 117 which project rearwardly from the frame so as to space the printing devices one from the other and thereby prevent damage to the type characters 116 of the printing plate during storage, handling or feeding of the printing devices. When the printing devices are stacked one against or on top of the other, the spacing flanges 117 of a particular frame 105 engage flat areas 119 formed on the upper or operative face of the adjacent frame 105 beyond the ends of the printing plate 108.

The printing devices D as herein shown are adapted for identification through the use of identifying means such as index tabs 120 which may be selectively disposed in a projecting relation along the upper edge of the printing frame 105 in any selected one or more of a plurality of spaced positions defined by mounting sockets 121 formed on the frame 105. The mounting sockets 121 are preferably formed by stamping from the metal of the frame 105 so that bases or stems 120' of the tabs 120 may be inserted along the reverse face of the frame so that the heads of the tabs project from or beyond the upper edge thereof. In the present instance the printing device D has twelve tab receiving sockets 121 disposed in uniformly spaced relation, thereby to afford twelve primary index or identification positions and enable any one or more of twelve pri-

mary classifications of a printing device to be indicated by selective mounting of one or more index tabs 120 in the appropriate socket or sockets 121.

As will hereinafter be described in detail, the heads of the tabs 120 in a sense may be subdivided into a plurality of subordinate control identifying areas, each of which may represent either a primary or a subordinate classification of a particular printing device, and thereby the number of available primary classifications may be rendered substantially greater than the number of tab-mounting positions provided by the sockets 121.

Thus the tabs 120 may be of the character shown in Figs. 15 and 16, which are known in the art as notched tabs, and in this instance one-half of the width of the head of certain tabs 120 may be cut away or notched as in tab 120A in Fig. 15, thereby to provide what may be termed a half-width projection or tab portion 125A. With such half-width tab portions 125A, the number of possible available identifying or classification areas provided by the twelve sockets 121 is doubled, or in other words, twenty-four primary classifications are rendered available.

In certain other instances a larger number of possible identifying areas or primary classifications may be provided by means of tabs, and one such method of providing a larger number of classifications is by means of tabs 120B shown in Figs. 24 and 25 of the drawings. The tabs 120B are known in the art as embossed tabs and the projecting area of each tab is divided into four areas in any one or more of which an embossure 126 may be formed. Thus the fact that a particular printing device D relates to a particular classification may be indicated by either the presence or the absence of an embossure 126 on the related area of a particular tab 120B. With this construction the twelve sockets 121 along the upper edge of each printing device D provide for the mounting of twelve tabs 120B, thereby to enable forty-eight primary classifications to be indicated by selective positioning of the suitably formed tabs in such sockets.

A forty-eight unit classification may also be attained by the use of tabs 120C shown in Figs. 26 and 27 of the drawings. The tabs 120C are known in the art as perforated tabs and the projecting area of the tab may be in effect divided into four classification areas. With this arrangement the fact that a printing device pertains to a particular classification may be indicated by the presence or absence of a perforation 127 in a particular area of a properly positioned tab 120C.

Through the use of selector mechanism such as that which will hereinafter be described, the number of possible classifications obtainable with tabs of a particular size may be materially increased, and in Fig. 28 of the drawings there is illustrated a series of tabs 120D of the perforated type wherein the area assigned to each identifying means or classification is materially smaller than with the tabs 120C. Thus the tabs 120D are each divided in effect into five identifying areas, thereby enabling sixty primary classifications to be obtained through the use of but twelve mounting sockets 121.

The printing means

While the printing or impression means, which is operative in each printing cycle, may take many different forms, and is influenced as to

form and construction by character and form of the printing devices D, I have herein shown a printing means in the form of a platen mechanism P which constitutes one form of impression means adapted for cooperation with embossed type such as the type characters 116. The platen mechanism P chosen for disclosure herein is of the geared roller type, and is fully described in my copending application, Ser. No. 361,530, filed October 17, 1940, and reference may be had to said copending application for details of structure and operation thereof. The platen mechanism P, as herein shown, is supported over a printing position V by means of a printing frame 134 having an upstanding connecting portion 135 which projects upwardly from table top T. The upwardly projecting portion 135 of the printing frame has an arm 134' formed integrally thereon so as to project toward the printing position V in upwardly spaced relation with respect to the table top T, and at its forward end the arm 134' has a supporting head 136 beneath which the platen mechanism P is mounted. The form and construction of the printing frame 134 is fully disclosed in my copending application, Ser. No. 350,678, filed August 3, 1940, now issued as Patent No. 2,275,439, patented March 10, 1942. In the present instance the platen mechanism P embodies a carriage C which is mounted for reciprocation in a direction from front to rear of the machine upon a track which is formed on a vertically adjustable mounting plate 137.

Beneath the carriage C a platen roller PR is supported for vertical movement through the medium of a toggle mechanism 138 so that the platen roller PR may be moved from its elevated inactive position of Fig. 3 to a lower or active position. When the platen roller PR is in its lower or active position, it may be moved with a rolling action across the upper face of a sheet or form so as to press the sheet into printing cooperation with a printing device D located at printing position, as described in my aforesaid copending application Ser. No. 361,530.

In a printing cycle, the platen mechanism P is actuated so that the carriage C moves forwardly through a conditioning stroke in the course of which the toggle mechanism 138 is actuated so as to move the platen roller PR to its lower or active position. Such actuation of the carriage C is accomplished by means which includes a rock shaft 139 mounted in the upper arm 134' parallel to the forward edge 101 of the frame. The rock shaft 139 has an arm 140 fixed thereto, rearwardly of the carriage C and this arm is connected by means of links 141 so as to actuate the carriage C. The required actuation of the toggles 138 is effected in timed relation to the reciprocation of the carriage C by means including a link 142'. After the carriage C has reached the forward limit of its movement, it is started through its return or operative stroke, and during this operative stroke the toggle mechanism 138 is maintained in its extended position, thereby to maintain the platen roller PR in its lower or active position. As the platen roller is moved rearwardly, a resilient platen face PF formed thereon is rolled across the top of the sheet so as to press the sheet into printing cooperation with an inking ribbon IR which overlies the printing device D then located at the printing position.

Such printing cooperation of the sheet with the inking ribbon with the printing device D is permitted by reason of a printing opening 142

which is provided in a sectional shield 143 mounted in the table top T. In the performance of such printing operations the sheet is preferably positioned through the medium of a rear guide or sheet stop 144 and one or more side guides 145, the side guides being adjustably mounted on a forward rail 146 which is disposed along the forward edge 101 of the table top T.

As described in my copending application Ser. No. 388,998, filed April 17, 1941, the machine which is herein illustrated is so constructed and arranged that an unusually deep throat is provided beneath the printing frame 134, and the construction is such that the throat possesses substantial depth not only in a direction from front to rear of the machine but also in a direction laterally of the machine or in other words parallel to the forward edge 101. Thus it will be observed that the printing frame 134 is so disposed that while the supporting head 136 thereof is located over the printing position V, the upwardly extending portion 135 of the printing frame is located a substantial distance rearwardly and to the right of the printing position, as will be evident in Figs. 1 and 2 of the drawings. Hence it will be clear that a relatively wide sheet may, when the sheet stop 144 is removed, be shifted rearwardly past the left-hand side of the portion 135 of the printing frame. Similarly an even wider sheet may be extended in a rearward direction for a considerable distance from printing position V until such sheet engages the forward face of the portion 135 of the printing frame. With this construction the capacity of the machine is substantially increased and the usefulness of the machine is materially extended. With the connecting portion of the printing frame 134 thus located a substantial distance rearwardly and laterally of the printing position V, the arm 134' extends in an angular direction along or across the table top T. When the elements of the machine are disposed as hereinabove described, the magazine M may be located adjacent to the connecting portion 135 of the printing frame, and when so located the magazine M is positioned adjacent to the right-hand end of the table top T to thereby facilitate the loading of the magazine.

59 The printing device advancing and guiding means

When the machine is to be operated, the magazine M is loaded with a stack of printing devices D in the manner described in my aforesaid copending application Ser. No. 388,998, so that the printing devices D are supported in a stacked relationship in the magazine M with their operative printing faces facing upwardly and with their upper or tab-receiving edges facing rearwardly. The printing devices D are then withdrawn or advanced one by one from the bottom of the magazine M, and are advanced in a step by step manner along a printing device guideway to the printing position V whereat each printing device D, in turn, comes to rest over an anvil A in position to have a printing impression made therefrom.

In the present printing machine printing devices D are withdrawn from the magazine M along a guideway concealed beneath the table top T, and in attaining the desired throat capacity as well as other desirable features of operational and structural convenience and simplicity in the machine, as fully set forth in my aforesaid copending application Ser. No. 388,998, this

guideway is preferably constructed and arranged in the manner illustrated in said copending application.

In such an arrangement of the printing device advancing and guiding means, the printing devices D are, in one cycle of the machine, advanced forwardly from a station I in Fig. 6 the magazine M along an initial printing device path or guideway 150 to a sensing station II whereat the printing device comes to rest so that means S may sense any tabs which may be carried by the printing device; and in the next advancing cycle, the printing device is advanced forwardly along the initial path or guideway 150 and comes to rest at a transfer station II-T. The advancing movement of a printing device from the sensing station II to the transfer station II-T takes place, in the present embodiment, in the first half of the machine cycle, and in the second half of the cycle, the printing device is advanced to the left in Fig. 6 along an intermediate guideway 160 to an intermediate station III. The intermediate guideway 160 extends parallel to the forward edge 101 of the table top 100 to a point located rearwardly of the printing station V, at which point it intersects with a final guideway 170 which extends forwardly through and past printing position.

In the next cycle of machine operation the printing device D at station III is advanced to the left to an intermediate station IV located in the intermediate guideway 160, while the next cycle of advancing operation further advances this printing device to the left along the intermediate guideway 160 to a transfer station IV-T formed at the juncture of the intermediate guideway 160 and the final guideway 170. The present machine is such that in the next cycle of operation of the advancing means the printing device D at the transfer station IV-T is advanced forwardly into printing position at the printing station V, and if a printing operation is to be performed from this printing device, the platen mechanism P operates through its forward or conditioning stroke while the particular printing device is being advanced to printing position. After the printing device D has come to rest on the anvil A, the platen mechanism P operates through its return or operative stroke so as to produce a printing impression from the printing device during the last half of the machine cycle.

In the next advancing cycle, the printing device at printing station V is advanced forwardly and is allowed to drop downwardly along a curved guideway 180 (Fig. 10) and into the forward end of the collector means K: This collector means includes a drawer holder or carrier 181 which supports a filing drawer as shown in Fig. 10 so that suitable packer means 182 may pack the printing devices in the drawer in their original filing order or sequence, as described in my aforesaid copending application Ser. No. 388,998.

The associated printing device guideways 150, 160 and 170 are preferably provided by a girder system which is supported immediately beneath the table top T upon spaced front and rear mounting or support bars 185 and 186, as shown in Figs. 2 to 5 inclusive, the mounting bars 185 and 186 being disposed parallel to the forward edge 101 of the frame 100 and being supported at their opposite ends on end panels 187 and 188 of the frame. The girder system as herein shown has a pair of spaced parallel girders 151 and 152 which form the initial guideway, a pair of spaced girders 161 and 162 which form the intermediate

guideway 160, and a pair of spaced girders 171 and 172 which form the final guideway 170; and suitable guide surfaces and upper retaining flanges or strips are provided along the upper edges of the various girders to guide the printing devices D in their advancing movements.

The advancing means for imparting the desired advancing movement to the printing devices D preferably comprises a plurality of sets of carrier bars 153, 163 and 173 associated with and reciprocable along the guideways 150, 160 and 170 respectively, and having engaging means thereon for engaging and advancing the printing devices along the guideways. On the carrier bars 153 a pair of forwardly facing shoulders 154 serve to engage and advance the printing devices from the magazine to sensing station II; while a pair of spring biased pawls 155 serve to engage and advance printing devices from station II to the transfer station II-T. On the carrier bars 163, three pairs of spring biased pawls 165 are provided at properly spaced points so that in an advancing or left-hand movement of the carrier bars 163 from the position of Fig. 8 to the position of Fig. 6, the pairs of pawls 165 each engage one of the printing devices D in the guideway 160 and advance each printing device to the next station. On the carrier bars 173 two pairs of spring biased pawls 175 are provided which operate similarly to impart advancing movements to the printing devices in the final guideway 170.

The carrier bars 153 of the initial guideway 150 and the carrier bars 173 of the final guideway are actuated in unison by means of similar actuating arms 156 and 176 which are fixed on opposite ends of a rock shaft 157. The shaft 157 is mounted on a bearing sleeve 157' fixed in the lower arm 134' of the printing frame 134 so that the arm 156 is supported beneath the guideway 150 while the arm 176 is located beneath the guideway 170, and the arms 156 and 176 are operatively connected to the carrier bars 153 and 173 respectively by means such as connecting links 159 and 178. Thus when the shaft 157 is rocked, the carrier bars 153 and 173 are first moved forwardly through their advancing strokes, and are then returned rearwardly through their idle strokes, in unison. The carrier bars 163 of the intermediate guideway 160 are actuated in timed relation to the carrier bars 153 by means of a link and lever connection 167 which is provided between the arm 156 and the carrier bars 163, as described in detail in my aforesaid copending application Ser. 388,998. The link and lever connection 167 is such that the carrier bars 163 move through their idle strokes to the right from the position of Fig. 6 to the position of Fig. 8 during the active or forwardly advancing strokes of the carrier bars 153 and 173, and are moved to the left or through their active strokes while the carrier bars 153 and 173 are moving through their rearward or idle strokes.

Means is provided in association with the several guideways to prevent retrograde movement of the printing devices therein, this means in the intermediate guideway comprising a plurality of detent pawls 168 mounted on a stationary bar 169 along the central portion of the guideway 160.

At the sensing station II and at the printing station V, such undesired retrograde movement is prevented by means which also serves to accurately position the printing devices for the performance of the sensing and printing operations respectively. Thus at the sensing station II a

positioning pawl 190 is pivoted at its forward end 191 on the girder 161 and has a pointed positioning tooth 192 adapted to engage a positioning notch 193 formed in the adjacent end of the frame of the printing device. Forwardly of the tooth 192 the pawl 190 has a stop finger 194 which may also project into the guideway 150 to prevent overfeeding or overthrow of the printing device past sensing station. At printing position V a generally similar positioning pawl 190' is pivoted at its rear end at 191' on the rail 171, and has a positioning tooth 192' thereon adapted to project into the guideway 170 to engage the notch 193 of the printing device at printing position. At its forward end the pawl 190' has a stop finger 194' which is adapted to be positioned in the guideway 170 to prevent overfeeding of the printing devices past printing position.

The two positioning pawls 190 and 190' are actuated in timed relation to the reciprocatory movements of the carrier bars 153 and 173 by means of a pair of links 195 and 195' which are connected to arms 196 and 196' of a bell crank 197. The bell crank 197 is mounted beneath a rear portion of the girder 171, and the link 195 extends to the right from a pin and slot connection with the forward end of the arm 196 and is connected at its right-hand end to the forward end of the pawl 190. The link 195' extends forwardly from the arm 196' and is connected at its forward end to an arm 190' of the pawl 190'. A spring 198 acting longitudinally of the link 195 and between this link 195 and the link 195' serves to impart a yielding actuating force to the pawl 190 at certain points in its cycle; while a spring 198' acting longitudinally with respect to the link 195' and between the arm 196' and the link 195' serves to impart a similar yielding force to the pawl 190' at certain points in its cycle of movement.

As will hereinafter be described in detail, the bell crank 197 is so actuated that the positioning teeth and the stop fingers of the two pawls 190 and 190' are completely withdrawn from the associated guideways 150 and 170 before the advancing movements of the printing devices in these guideways are initiated. As soon as the printing devices at the printing and sensing stations have been advanced past the adjacent stop fingers, the pawls 190 and 190' are returned toward the positions of Fig. 6 so that the positioning teeth are still outside of the guideways, while the stop fingers thereof are projected a short distance into the guideways. Hence the advancing printing devices may strike the stop fingers so as to be positioned in a preliminary sense at the sensing and printing stations. After the forward advancing movements of the carrier bars 153 and 173 have been completed, the positioning pawls 190 and 190' are shifted further toward their active positions of Fig. 6, this action being accomplished through the yielding action of springs 198 and 198'. Hence the positioning teeth 192 and 192' are forced into the V-shaped positioning notches 193 of the printing devices D at the sensing and printing stations, thereby to impart a final positioning action to these printing devices which accurately locates each printing device. Thus the desired registry of the printing impression is invariably attained; while the accuracy of location of the printing device at the sensing station is effective to produce accurate sensing operation of the sensing means S in each instance.

The main drive mechanism

The main actuating or drive assembly of the present machine is located in the generally triangular space rearwardly of the lower arm 134" of the printing frame; and the actuating assembly includes a drive shaft 200 rotatably mounted in a horizontal position immediately forwardly of the rear supporting bar 134 by means of a plurality of bearing brackets 201, 202 and 203 each of which is bolted to and carried by the bar 186. Adjacent the left-hand end (Fig. 2) of the shaft 200 a constantly rotating source of power such as a pulley 204 is provided, the pulley in the present instance being rotatably mounted on the shaft 200. During periods of use of the printing machine the pulley 204 is constantly driven by means such as an electric motor 205, there being a suitable speed reducing drive connection between the motor 205 and the pulley 204. The motor 205 is controlled by a switch 206 mounted within the frame 100 behind the upper front panel 207 thereof as shown in Fig. 14, and this switch is actuated and controlled by means 25 of a control slide 208 (Fig. 1) which extends forwardly through the panel 207 and into the right hand 207' thereof. The control slide 207 is so arranged that when the slide is positioned inwardly the motor 205 is stopped and when the 30 slide is pulled outwardly the switch 206 is closed and the motor is started. In the present instance the motor 205 is mounted on the rear side of a skirt 209 which defines the rear extent of the kneehole of the desk like frame 100 and is connected between the end panels 187 and 188 of the frame 100.

The mounting for the motor 205, which is best illustrated in Figs. 3 and 13, comprises a pair of spaced vertical channel members 210 secured as by welding to the back of the skirt 209 and having bolt and slot connections which support a motor mounting bracket 211. The bracket 211 is preferably formed from sheet metal to provide a body or base portion 211' with projecting arms 211" at opposite ends thereof. The arms 211" are formed at their ends to cooperate with clamping bands 212 in engaging resilient rubber mounting sleeves which surround the axially projecting bearing hubs 217 of the motor 205.

40 The speed reducing belted drive connection between the motor 205 and the pulley 204 is best shown in Figs. 3 and 13 and comprises a small pulley 230 fixed on the motor shafts and connected by a belt 231 to a large pulley 232 which is rotatably mounted on a bearing stud 232' carried on a mounting plate 233. The mounting plate 233 is generally triangular in form and is located in a vertical plane. Along most of its edges the plate 233 is flanged, and at its upper 45 rear edge the rear flange of the plate 233 is secured by means of bolts 234 to the rear supporting bar 186. At its forward corner the plate 233 rests upon and is bolted to the upper flange of the skirt 209 by means of a bolt 233' so as to be supported thereby, while suitable side bracing is provided by a brace rod 235 extending from a lower portion of the rear edge of the plate 233 angularly upwardly and bolted to the bar 186 as shown in Fig. 13. A small pulley 236 mounted on the stud 232' and rigid with the pulley 232 is connected by a belt 237 to a large pulley 238 rotatably mounted on a bearing stud 238' projecting from the plate 233; and rigid 50 55 60 65 70 75 75 with the pulley 238 is a double pulley 239 of small

diameter which is connected by a pair of parallel belts 240 to the pulley 204.

Thus the pulley 204 is constantly driven at reduced speed during the operation of the motor 205, and this constantly available source of driving power is, through the medium of properly interrelated actuating and control mechanism, utilized to actuate the various operative parts and mechanisms of the machine. In the present machine it is often desirable that certain mechanisms or groups of mechanisms be capable of operation independently of certain other mechanisms or groups of mechanisms, as for example, in what is known as "multiple" or "repeat" operation of the machine where the platen mechanism P is to be operated through a plurality of printing operations while the same printing device D remains stationary at printing position; or as another instance, in what is known as "skip" operation of the machine wherein the platen mechanism P remains inoperative while one or more printing devices D are passed through printing position. In order that such selective operation may be attained a plurality of independently connectible driving connections are provided in association with drive pulley 204 and the shaft 200, such selective driving connections in the present instance being provided through the medium of a plurality of one revolution clutches 250, 251 and 252 disposed at spaced points along the shaft 200 as shown in Figs. 11 and 12.

The clutches 250, 251 and 252, are generally similar in form, and as shown in Figs. 3, 11 and 12, the clutch 250 constitutes a main or master clutch and is utilized to connect the pulley 204 to the shaft 200 so as to rotate the shaft through one revolution each time some portion of the mechanism is to be actuated, while the clutches 251 and 252 constitute secondary clutches and are operatively associated respectively with the printing device advancing means and the platen mechanism P. The secondary clutches 251 and 252 are so arranged that they may be selectively utilized to connect the printing device advancing mechanism or the platen mechanism individually or concurrently to the shaft 200 for actuation thereby. The particular form of the clutches 250, 251 and 252 is described in detail in my aforesaid copending application, Ser. No. 388,998, wherein it is pointed out that these clutches are generally similar in construction and operation. Thus each clutch has a hub-like driving member and a driven member in the form of a hollow hub partially surrounding the driving hub and adapted to be connected to the driving hub by a clutch pawl carried on the driven member.

The master clutch 250, as herein shown, comprises a constantly rotating driving member in the form of a sleeve 255 rotatably mounted on the shaft 200 and serving as a mounting for the pulley 204 to which it is keyed as indicated at 286 in Fig. 12. At the right end of the driving member 255 (Fig. 12), the clutch 250 has a driven member in the form of an enlarged hollow hub 257 which is pinned on the shaft 200. Since the form and manner of operative engagement of the several clutches are substantially the same, these features will hereinafter be described with relation to the platen clutch 252 which is shown in detail in Fig. 5. Generally considered, however, it may be said that each clutch has a clutch dog 258 pivotally mounted on its driven

member so that an inner end of the clutch dog may operatively engage the driving hub, and having its other end projecting so as to be engageable by a stop means such as a stop lever 270 to disengage the clutch and terminate the rotation of the driven member at a particular point in its rotation.

The clutch 251, which controls the operation of the printing device advancing means, is best shown in Figs. 11 and 12, and is generally similar to the clutch 250 in its form, construction and operation. Thus as shown in Fig. 12, the bearing bracket 202 has a bearing sleeve 202' which is located between the clutch 250 and the clutch 251, and adjacent to the right-hand end of the bearing sleeve 202', a driving member 255' is pinned to the shaft 200, and this member 255' constitutes the driving member of the clutch 251. At the right-hand end of the driving member 255', a hollow hub 257' is provided having a clutch dog 258' mounted thereon in the same manner as the clutch dog in the clutch 250. The clutch dog 258' is arranged to engage a recess or notch 260' formed in the driving member 255', and a projecting stop tooth 263' on the clutch dog 258' is adapted to be engaged by a stop lever 270' to terminate the rotation of the driven member 257' of the clutch 251 after the driven member has moved through but one revolution. In the present instance the driven member 257' of the clutch 251 has an eccentric 272 mounted and carried thereon as by means of a pinned connection. With this construction the rotation of the driven member 257' serves to operate the eccentric 272, and the resulting rotative movement of the eccentric 272 is utilized through the medium of a connecting rod 274 to operate the printing device advancing means. Such actuation is attained by pivoting the forward end of the connecting rod 274 to the arm 176 at 274', as shown in Fig. 10.

Somewhat to the right of the eccentric 272 in Fig. 12 the shaft 200 has a sleeve 255' pinned thereon so as to constitute the driving member of the clutch 252, and a driven member 257'' is mounted on the shaft 200 so that its clutch dog 258'', which is constructed and arranged in the same manner as the clutch dog 258 of the clutch 250, may be operatively engaged with the driving member 255'' to produce a one-revolution operation of the driven member 257'' of the clutch 252. The clutch dog 258'' of the clutch 252 is controlled by a stop lever 270'' (Fig. 5) as will be hereinafter described in detail. The driven member 257'' of the clutch 252 has an eccentric 290 mounted thereon, such mounting being accomplished by means of a pinned connection. The eccentric 290 is utilized in the present instance through the medium of means including a connecting bearing 294 and an adjustable connecting rod 295 to operate the platen mechanism P through its operative printing cycle.

As shown in Fig. 5, the clutch dog 258'' is pivoted within the driven member 257'' so that a clutch tooth 259'' formed on the inner end of the dog 258'' may be moved into operative engagement with a recess or notch 260'' formed in the driving member 255''. The clutch dog 258'' is urged toward such operative or engaged relation by means of a spring 261'' acting between the dog 258'' and an anchoring pin within the hollow hub 257'', and when the tooth 259'' is thus engaged with the notch 260'', the hub 257'' is driven with the driving member 255''.

The other end of the clutch dog 258'' projects

beyond the pivot 268a for a considerable distance and has a stop tooth 263" projecting therefrom in a generally radial direction with respect to the shaft 200 so as to project outwardly through a slot 264" formed in the hollow hub 257". When the clutch tooth 259" has been engaged with a notch 260" in the driving member 255", rotation of the driven member 251" is initiated in a clockwise direction as viewed in Fig. 5, and such rotation continues throughout substantially one revolution, at which point the projecting stop tooth 263" moves into engagement with a stop means such as a stop lug 270S formed on a stop lever 270" which restrains the stop tooth 263" against further movement and thereby causes the clutch dog 258" to be pivoted so as to withdraw the clutch tooth 259" from the notch 260" in the driving member 255". The rotation of the driving member 255" may then continue, but the driven member is stopped in a predetermined angular relationship and is restrained against further rotation in a clockwise direction until such time as the stop lever 270" is withdrawn from its restraining relationship with respect to the stop tooth 263". The particular manner in which the stop lever 270" is mounted, actuated and controlled will be described in detail herein-after in connection with the description of the operative interrelationship of the several operative mechanisms of the machine.

While the operative connection of the drive mechanism to the platen mechanism P is described in detail in my copending application Ser. No. 361,530, filed October 17, 1940, it will be observed in Fig. 5 of the drawings that the forward end of the connecting rod 295 is pivotally connected to the end of an arm 295' which is fixed to the left-hand end of a shaft 296. The shaft 296 is mounted in a bearing sleeve 296' which extends through and is rigid with the lower arm 134" of the printing frame 134 in the manner described in detail in my copending application Ser. No. 350,678, filed August 3, 1940. At its right-hand end the shaft 296 has an arm 297 fixed thereto and rocking movement of the arm 297 is imparted to a vertically extending link 297' which is connected at its lower end to the arm 297. At its upper end the link 297' is connected to an arm 298 which is fixed to the right-hand end of the shaft 139 which is mounted in a bearing sleeve (not shown) that extends through and is rigid with the upper arm 134' of the printing frame 134 as described in my aforesaid copending application Ser. No. 350,678. At its left-hand end the shaft 139 has the arms 140 fixed thereto and the arms 140 are operatively connected to the carriage C of the platen mechanism through the medium of a pair of links 141. The details of the drive connection are fully described in my aforesaid copending application Ser. No. 361,530 and, therefore, reference may be had to said application for details of form and function. The arrangement, however, is such that each time the clutch 252 drives the eccentric 290 through a complete revolution, the carriage C of the platen mechanism is reciprocated through an operative printing stroke and is returned to the retracted or rearward position shown in Fig. 5 of the drawings, and in order that smooth operation of the eccentric 290 and the associated mechanism may be assured, a contractual spring 295S is connected between the arm 295' and an anchoring pin on the mounting bracket 203. Thus the spring 295S is tensioned during the forward or idle stroke of the platen mechanism and during the return or

work-performing stroke of the platen mechanism the spring 295S serves to supply additional power for operating the platen mechanism.

Since the clutch 250 is in the present instance utilized merely to connect the shaft 200 to the source of power, the driving member 255 of the clutch 250 is provided with a plurality of circumferentially spaced notches 260 as shown in Fig. 39, so that the time required for engagement of the clutch 250 after the release of the clutch dog 258 by its stop lever 270 is correspondingly reduced. In the present instance four such notches 260 are provided so that the clutch 250 becomes operatively engaged in every instance after a maximum rotation of approximately ninety degrees.

With relation to the clutches 251 and 252, however, it will be noted that but one notch is provided in the driving members, and bearing in mind that the driving members 255' and 255" are both pinned to the shaft 200, it is to be noted that the notches in the driving members 255' and 255" of the two clutches 251 and 252 bear a predetermined angular relationship to each other so that the printing device advancing means and the platen mechanism will, in their operative movements, invariably bear a predetermined relationship.

The control of the machine

For the purpose of controlling the machine to produce print, skip or repeat operation thereof, a plurality of manually actuatable means such as foot pedals 320, 321 and 322 are provided. These pedals are similar in form and mounting and are so located as to be capable of convenient actuation by an operator seated in front of the machine. To support the foot pedals 320, 321 and 322, a channel 323 is provided for each of the pedals mounted in a depending relation from the lower edge of the skirt 209 of the frame. Each pedal is pivoted at its rear end to its supporting channel 323, as indicated at 324 in Fig. 3, and has a spring return means 325 associated therewith to urge the pedal to its normal elevated position. The arrangement of the pedals 320, 321 and 322 is such, in the present instance, that the pedal 320 constitutes the "skip" pedal and is operative to cause engagement of the printing device advancing clutch 251; the pedal 321 constitutes the "repeat" pedal and is operative to cause engagement of the platen clutch 252; while the pedal 322 constitutes the "consecutive" pedal and is operative in the normal or usual adjustment of the machine to cause concurrent engagement of the advancing and platen clutches 251 and 252.

To attain such control of the clutches a shaft 329 is mounted in the flanges of the channels 323 so as to extend along the back of the skirt 209, and in the space between the flanges of the channels, a plurality of arms 330, 331 and 332 are mounted on the shaft 329 so as to project rearwardly therefrom. The arms 330 and 331 are disposed above and rearwardly of the pedals 320 and 321, and are loosely mounted on the shaft 329, while the arm 332 is disposed above and rearwardly of the foot pedal 322. A link 334 connects the pedal 320 to the arm, as shown in Figs. 3 and 13, so that by actuation of the pedal 320 the rear end of the arm 330 may be drawn downwardly; a similar link 335 connects the pedal 321 to the arm 331; while a similar link 336 connects the pedal 322 to the arm 332.

When the arm 330 is thus actuated by the skip pedal 320, a link or rod 338 which is connected

between the rear end of the arm 330 and the rear end of the stop lever 270' serves to shift the stop lever 270' to its inactive position, thereby to cause engagement of the advancing clutch 251; while similar actuation of the arm 331 by the repeat pedal 322 causes a link or rod 339 which is connected between the arm 331 and the stop lever 270'' to shift the stop lever 270'' and cause engagement of the platen clutch 252.

When the consecutive foot pedal 322 is actuated the shaft 329 is rocked, and a pair of arms 340 and 341 fixed on the shaft 329 are rocked in unison. The arms 340 and 341 have ears 340' and 341' formed at their ends so as to overlie the arms 330 and 331 respectively, and hence the rocking movement of the shaft 329 by the foot pedal 322 causes the stop levers 270' and 270'' of the advancing and platen clutches to be concurrently shifted to their inactive positions.

As shown in Figs. 5, 10A, 11, 12, 13, 38 and 39, the stop levers 270, 270' and 270'' are all pivoted intermediate their ends on horizontal mounting shaft 350 which is journaled just above and somewhat forwardly of the mounting bar 186 in the bearing bracket 202 and a similarly mounted auxiliary bracket 351 disposed between the brackets 202 and 203. The two stop levers 270 and 270'', which are directly actuated when the associated foot pedals are actuated, are arranged to similarly actuate the stop lever 270 of the master clutch 250 whenever either one of the stop levers 270' or 270'' is actuated. To this end the stop lever 270 is fixed on the shaft 350 and is urged toward its operative or active position of Fig. 39 by means of a spring 352, and a pair of arms 353 and 354 are fixed to the shaft 350 so as to project rearwardly therefrom beneath portions of the stop levers 270' and 270'' respectively. Thus the stop lever 270' has a screw 355 thereon as shown in Figs. 11 and 38 in such a position as to strike the arm 354 when the stop lever 270'' is actuated by its rod 339. A similar screw 356 on the stop lever 270' acts similarly on the arm 353, so that the stop lever 270 is shifted to its inactive position each time either one of the stop levers 270' or 270'' is actuated to its inactive position.

Above the shaft 350 a parallel latch shaft 360 is mounted, and a pair of latches 361 and 362 are fixed thereon for operative engagement with notches 363 formed on the stop levers 270' and 270''. When one of the stop levers 270' or 270'' is actuated, the associated latch 361 or 362 engages the notch of the actuated stop lever to maintain the same in its inactive position until engagement of the master clutch 250 has initiated rotation of the driven members of the clutches 251 and 252, after which the latches 361 and 362 are rocked to released positions by means of a release arm 365 which is fixed on the latch shaft 360. As shown in Figs. 11 and 39, the release arm 365 is biased by a spring 366 to produce a latching relation of the latches 361 and 362, and releasing movement is imparted to the release arm 366 by an eccentric roller 367 mounted on driven member of the master clutch 250.

After the master clutch 250 has started the rotation of the driven members of the clutches 251 and 252, these clutches become engaged if their stop levers 270' and 270'' have been latched in their inactive positions, and soon after the rotation of the driven members of the clutches 251 and 252 has started, the stop levers 270' and 270'' are unlatched by the release arm 365 so that the stop levers 270' and 270'' are returned to

their active positions by suitable spring means. In the present instance this spring means comprises springs 370 and 371 acting respectively on the stop levers 270' and 270'', and springs 372 and 373 acting respectively on the rods 338 and 339 as shown in Fig. 13.

As an incident to the operation of the printing device advancing means, the positioning pawls 190 and 190' actuated as hereinbefore described, and such actuation is attained in timed relation to the movement of the printing devices D. To this end a cam assembly 380 is rotatably mounted on the drive shaft 200 between the eccentric 272 of the printing device feed and the driving member 255'', and the cam assembly 380 is fixed, by means such as a pinned connection, to the eccentric 272 so as to be rotated each time the feed clutch 251 operates through its one revolution cycle. The cam assembly, as shown in Figs. 12 and 38, comprises a plurality of disks 381, 382, 383, 384 and 385. The disk 382 is concentric with the shaft 200, as shown in Fig. 38, and is embraced by bifurcations 386 on one end of a link 387. The other end of the link 387 is connected by a swivel block 388 to an arm 389 formed on the bell crank 197.

The bifurcations 386 are guided laterally between the disks 381 and 383, and a roller 390 on the link 387 is urged into contact with the periphery of the disk 381 by the action of the spring 198'. The disk 381 therefore, constitutes a cam disk, and is formed with a leading surface 391 (Fig. 38) which acts on the roller 390 soon after the clutch 251 has engaged to withdraw the positioning teeth and stop fingers of the pawls 190 and 190' completely from the printing device guideways. A dwell surface 392 of the cam 381 then maintains the positioning pawls 190 and 190' in their completely withdrawn relationship until the printing devices have been advanced from stations II and V beyond the associated stop fingers, after which a receding surface 393 on the cam 381 allows the stop fingers of the positioning pawls to move into their active positions. Such movement is limited by a dwell surface 394 on the cam. After the advancing movement of the printing devices into the printing and sensing stations has been completed, a receding surface 395 on the cam 381 permits the pawls 190 and 190' to shift to their final positions, after which a dwell surface 396 on the cam 381 rides against the roller 390. The pawls 190 and 190' are therefore, free to act under the influence of their springs 198 and 198' to produce an accurate positioning of the printing devices at sensing and printing stations.

Means is also provided for actuating the packer means 182, and for actuating a feeding and reversing means 400 for the inked ribbon IR, but since these elements and their drive means may take many different forms, it is unnecessary to include specific description herein. In the present instance a cam 401 and an eccentric 402 are mounted on the shaft 200 just to the right of the master clutch 250, and are pinned to the driven member thereof. A follower link 403 operatively associated with the cam 401 serves to actuate the feeding and reversing means 400 of the inked ribbon; while a bearing 404 and a connecting rod 405 form an operative connection between the eccentric 402 and the packer means 182.

The multiprint mechanism

In certain uses of printing machines of the type to which the present invention pertains it

is desirable to operate the machine to produce two or more printing impressions from each printing device, and while such a result could be attained by selective actuation of the repeat pedal 321 and the consecutive pedal 322, it has been found in practice to be more satisfactory to incorporate in the machine an automatic means operative to produce the required number of printing impressions from each printing device even though the successive machine cycles are initiated by the consecutive pedal 322 or equivalent means. Such an automatic control means is known in the art as a multiprint mechanism, and the present machine embodies one form of such mechanism arranged to be controlled or rendered operative by means of a control plunger 420 mounted in the front panel 207 of the machine frame.

The multiprint mechanism, as shown in Figs. 10A, 11 and 39, comprises a control rocker 421 fixed on the left-hand end of a rock shaft 422 journaled in the forward end of the bearing bracket 202, and on the right-hand end of the shaft 422 a rearwardly projecting arm 423 is fixed. As shown in Fig. 10, the arm 423 has a link 424 projecting downwardly therefrom for operative connection with a supplemental stop lever 425 which is associated with the advancing clutch 251. The stop lever 425 is freely mounted on the shaft 350, and when the lever arm 423 is in its elevated position of Fig. 10, the stop lever 425 is elevated to an inactive position by engagement of nuts 426 on the link 424 with the lower face of a swivel block 428 carried on the side of the stop lever 425. The link 424 extends slidably through the swivel block 428, and above the swivel block a spring 429 surrounds the link 423. The upper end of the spring 429 acts against a stop 430 on the link 424, so that when the arm 423 is lowered, the stop lever 425 is urged yielding into an active relation to the advancing clutch 251.

The control rocker 421 has a forwardly projecting arm 431 having a cam roller 432 at its forward end which rides on the periphery of a cam disk 433 and it is maintained in contact with the disk 433 by means of a spring 435 acting on a downwardly extending arm 436 of the rocker 421. When the roller 432 is seated in a recess 438 of the cam 433, the control rocker 421 is so positioned as to maintain the supplemental stop lever 425 of the advancing clutch 251 in its inactive position. Hence the printing device advancing mechanism may operate in its normal manner under the control of the stop lever 270' of the advancing clutch. When, however, the roller 432 is seated on a cam lobe 439 of the cam 433, the control rocker 421 is actuated so as to place the supplemental stop lever 425 in its active position. Hence under such circumstances the advancing clutch 251 is dominated by the stop lever 425 and cannot become engaged even though the normal stop lever 270' thereof is actuated to its inactive or release position.

Thus by actuating the cam 433 through a predetermined angle each time the platen mechanism P is operated, the printing device advancing means may be periodically disabled, and in accordance with the form of the cam 433, a predetermined number of printing impressions may be made from each printing device. The cam 433 as herein shown is adapted to produce "duplicate operation" of the machine, or in other words, the printing device advancing means is disabled in alternate machine cycle, thereby to

cause two printing impressions to be made from each printing device. The cam 433 is preferably formed as a part of a cam assembly which incorporates a ratchet 440, and is removably mounted on the bracket 202 by means of a headed stud 441. Thus the cam assembly may be removed and replaced by a cam of different form when a greater number of printing impressions are to be made from each printing device.

The cam 433 is actuated by a pin 443 carried on a reciprocable link 444 which is connected at its forward end to an arm 445 fixed on the rock shaft 296 of the platen actuating mechanism. The link 444 is urged upwardly by a spring assembly 446 so that in the first half of the cycle of the platen drive mechanism, the link 444 is urged upwardly and the pin 443 thereon is moved into engagement with one of the teeth of the ratchet 440 in the course of the forward movement of the link 444. Thus the came 433 is advanced in each operation of the platen mechanism P, and with the cam herein illustrated the cam roller 432 is alternately engaged by the recesses and came lobes of the cam.

The multiprint means thus described tends normally to operate, and means is provided under the control of the plunger 420 to render the actuating link 444 inoperative when operation of the multiprint is not desired. To this end a shroud plate 450 is permanently mounted for rocking movement on the bracket 202 on the axis of the stud 441, so as to be next to the ratchet 440 and in the vertical plane of the link 444. The shroud plate 450 is connected by a link 451 to the control plunger 420, and when the plunger 420 is pressed to its inward or most rearward position the shroud plate 450 is rocked to the position of Fig. 39 wherein a finger 453 on the plate 450 is located in the position shown in Fig. 39, and in this position, the finger 453 acts on the upper edge of the link 444 to prevent engagement of the pin 443 with the ratchet 440. When the plunger 420 is withdrawn to a second or multiprint position, the finger 453 is slightly elevated so as to allow the pin 443 to engage the ratchet 440, and hence the multiprint mechanism is rendered operative. In order to insure that the multiprint mechanism will be adjusted to its inactive or inoperative relation only at such a point in the cycle that the feed clutch 251 will operate in the normal manner, means is provided which prevents actuation of the shroud plate from or out of its multiprint position when the cam roller 432 is in engagement with a cam lobe 439. As shown in Fig. 39 this means comprises a spring biased latch lever 455 mounted on the shroud plate 450 and having a downwardly facing notch 456 therein. When the shroud plate 450 is in its multiprint position, the notch 456 is located over a pin 457 which is coaxial with the cam roller 432. The relationship is such that when the cam roller 432 is elevated by a cam lobe 439, the pin 457 is moved into the notch 456, thereby to prevent shifting movement of the shroud plate 450 until such time as further actuation of the cam 433 has brought a cam recess 438 into registry with the cam roller.

The shroud plate 450 may also be actuated to a "repeat" position by further forward withdrawal of the plunger 420 beyond its multiprint position, and in this position a shoulder 458 on the plate 450 engages the link 444 to render the same inoperative, while a lobe 459 on the plate 450 engages the cam roller 432 and elevates the

same in the same manner as a lobe 480 of the case 488.

The selector mechanism

In accordance with the present invention the printing machine incorporates a selector mechanism which is so constructed and arranged that it not only enables the machine to be adjusted for a wide variety of different control operations, but also enables the machine to utilize and perform selections from the identifying means of printing devices having a larger number of available identifying areas or classifications than has heretofore been possible.

The selector mechanism of the present machine is such that it is capable of use with many different types of identifying or classification means, and for purposes of initially describing the structure and operation of the present selector mechanism, its functioning and arrangement will be described with particular relation to printing devices D which are identified by means of notched tabs 120A such as those shown in Figs. 15 and 16 of the drawings. The selector mechanism of the present invention is so constructed and arranged that it cooperates with the multiprint mechanism of the machine and is effective to produce accurate control of the printing means of the machine irrespective of the operative or non-operative condition of the multiprint mechanism.

Since the present printing machine embodies a relatively large number of stations along the printing device guideway, the selector means of the present invention is arranged to embody a storage mechanism so that the identifying means of each printing device D may be sensed by the sensing means S several stations in advance of the printing position, and by reason of this construction it is possible to locate the sensing means at station II of the printing device guideway, thereby to facilitate the provision of large and unobstructed working areas on the table top T and at the same time locate the variably settable elements of the sensing means S in a convenient and readily accessible position.

In attaining such a desirable construction and arrangement in the selector mechanism, the sensing means S of the present machine has a sensing head 500 which extends across to the rear portion of the sensing station II so as to overlie the positions which are occupied by the tabs 120 of a printing device D when such a printing device is in position at sensing station II. The sensing head 500 is preferably in the form of a bar, and is mounted for movement through a sensing stroke in such a manner as to cooperate with the positioning pawl 190 in enabling an unusually large number of identifying positions or classifications to be accurately and efficiently sensed. The sensing head 500 is in the present instance arranged to reciprocate beneath a guard casting 500' which also serves as a drawer guide in the loading of the magazine M. The sensing head 500 is mounted for movement through a vertical straight-line sensing stroke by means such as a pair of guide rods 501 and 502 to the upper ends of which the sensing head 500 is fixed. The guide rods 501 and 502 are slidably guided as by means of bores formed in guide blocks 503 and 504 secured on opposite or outer sides of the girders 151 and 152. When a printing device D is in sensing position, and has been accurately located through the action of the positioning pawl 190, the tabs 120 of the printing device are 75

arranged to overlie a tab support formed by a plate 510 which is, in turn, secured to the top of a transverse spacing member 511 extending between the two girders 151 and 152 beneath the sensing position. The tab support plate 510 has a plurality of spaced grooves 512 formed therein parallel to the initial path or guideway 150, and these grooves are of such a width that a plurality of spaced supporting ribs 513 are provided which will in every instance underlie and support one or more portions of each tab 120 which may be carried by a printing device.

The sensing operation is accomplished by sensing the presence or absence of identifying means such as a tab, or a particular area of a tab, at any one or more of the available identifying positions provided on or in relation to the printing device. Such sensing is in the present instance accomplished by means of selectively positioned selector pins 525 which are adapted to be mounted in a selector bar 526 which is removably positioned on the selector head 500 so that the pins 525 project downwardly from the selector head in a direction parallel to the path of movement of the sensing head. Since different types of tabs 120, as hereinbefore described, require selector pins 525 of different forms, the pins which are employed with the different types of tabs will be identified by the use of the same reference letter. Thus the notched tabs 120A of Figs. 15 and 16 require the use of selector pins 525A such as those shown in Figs. 18 to 21; the embossed tabs 120B of Fig. 25 require the use of selector pins 525B such as that shown in Fig. 24; while the perforated tabs 120C of Fig. 26 or 120D of Fig. 28 require the use of selector pins 525C such as those shown in Figs. 22, 23, 27 and 30. The construction and operation of the mechanism will first be described with relation to tabs 120A and selector pins 525A, after which the operation with other types of tabs and selector pins will be described. Thus when a selector pin 525A is mounted in any one of a plurality of positions which are provided on the selector bar 526, and the selector head 500 is moved downwardly along the straight-line path determined by the guide rods 501 and 502, the selector pin 525A will engage any solid area of a tab 120A which may be aligned with the pin 525A. In the event that a solid area of a tab 120A is not located in the path of the selector pin 525A, the lower end of the pin 525A moves downwardly into the aligned groove 512. Thus the downward movement of the selector head 500 is controlled by the presence or absence of a solid area of a tab 120A in the path of a selector pin such as the pin 525A carried on the selector bar 526. Hence when a tab 120A is not sensed by a selector pin 525A, the selector head 500 moves downwardly to the limit of its movement to a lower level which for purposes of description herein will be termed the level 1. Similarly, when a tab is encountered by a selector pin 525A—1 of a particular length which will herein be termed a regular length pin or regular pin the selector head 500 is limited in its downward movement and comes to rest at a somewhat higher level which will hereinafter be termed level 2. It will be clear, therefore, that the termination of the downward movement at level 1 indicates that the presence of a solid area of a tab 120A has not been sensed, while the termination of the downward movement of the sensing head 500 at level 2 indicates that a solid area of a tab 120A has been sensed by a regular selector pin 525A—1.

In the use of a selector mechanism in a printing machine of this character it is often desirable to automatically sense and select printing devices pertaining to one or more selected classifications and to warn the operator or to perform another or different type of control operation when a printing device bearing identifying means corresponding to such a selected classification has been sensed. In other instances it may be desirable to detect printing devices pertaining to certain classifications and to provide for still another indication or controlling operation which is different from the controlling operation which is effected when a particular identifying means on a printing device is sensed by a sensing pin such as a regular pin 525A-1. Thus as shown in Figs. 19, 20, 21 and 31 of the drawings, the selector bar 526 may have selector pins of different lengths mounted therein. The left-hand selector pin 525A-1 shown in Fig. 31 (and in Fig. 19) is of the regular length, while the right-hand pin shown in Fig. 31 (and in Fig. 20) is identified by the reference numeral 525A-2 and is somewhat longer than the regular pin 525A-1. The central pin illustrated in Fig. 31 (and in Fig. 21) is even longer than the pin 525A-2 and is identified by the reference numeral 525A-3. Thus the pin 525A-1 may be termed a regular pin, the pin 525A-2 may be termed an intermediate pin, and the pin 525A-3 may be termed a long pin. When a tab 120A is located in the path of an intermediate pin 525A-2, the downward movement of the sensing head 500 is terminated at a level which will hereinafter be termed level 3 and which is somewhat higher than level 2 hereinbefore described. When a tab is encountered by a long pin 525A-3 the downward movement of the sensing head 500 is terminated at a fourth level which is higher than level 3 and which will hereinafter be identified as level 4.

The selector pins 525A, or the pins of any of the other types, are mounted in an appropriate selector bar 526 by downward insertion of the pins into the appropriate vertical bores or passages formed in the selector bar. The selector bar 526 is, therefore, formed so as to be readily removable from its operative positions, and in such removal is withdrawn forwardly beneath the overhanging forward edge of the guard casting 500'. The selector bar 526 is adapted for use with notched tabs and has 24 possible positions provided thereon for the mounting of selector pins 525, and the bar 526 is formed from a front section 530 and a rear section 531 which are secured together by rivets 532 and 533. At its left-hand end the selector bar 526 has a mounting notch 534 opening endwise thereof so as to be engageable with a downwardly projecting mounting pin 535 carried on the sensing head adjacent to the left-hand end thereof. The mounting pin 535 has a lower flange 536 which engages the lower face of the selector bar 526 to support the same, while an upper flange 537 is provided on the mounting pin 535 to properly space the upper face 538 of the sensing bar 526 downwardly from the downwardly facing abutment surface 539 of the sensing head 500. After moving the notch 534 into engagement with the mounting pin 535, the right-hand end of the sensing bar 526 is moved rearwardly and onto a supporting shelf 540 which is provided at the righthand end of the sensing head 500. A stud 541 on the lower surface 539 of the sensing head 500 engages the top of the sensing bar 526 adjacent to the right-hand end thereof so as to

properly space the sensing bar 526 downwardly from the surface 539. The sensing bar 526 is accurately positioned on the sensing head 500 by means of a locking lever 545 which is pivoted adjacent its left-hand end at 546 on the forward face of the sensing head 500. The right-hand end of the locking lever 545 may be elevated by means of a finger piece 547 against the force of a spring 548, such upward movement being necessary to permit mounting or dismounting of the sensing bar 526. In the upward movement of the right-hand end of the locking lever 545, this end of the locking lever is guided by a stud 549 which is threaded into the sensing head 500 through an arcuate slot 550 formed in the locking lever 545. After the sensing bar 526 has been mounted in position on the mounting pin 535 and the shelf 540, the locking lever 545 is returned to its lower position of Fig. 31 so that a downwardly facing notch 551 formed in the locking lever 545 engages a reduced or shouldered portion 552 formed on the forward end of the rivet 533. Beyond the shoulder 552 the rivet 533 is provided with a handle portion 553 which may be utilized by the operator in mounting and dismounting the sensing bar 526.

For the purpose of mounting the selector pins 525 in the selector bar 526 a plurality of similar vertical bores or openings 560 are provided in the selector bar, these openings being disposed in positions which correspond with the several available classification areas which are or may be provided on the printing device D. Thus the selector bar 526 as shown in Fig. 32 of the drawings has a single row of openings 560 and there are 24 of such openings in this row. The selector bar 526 of Fig. 32 may, therefore, be said to constitute a 24-position selector bar.

The selector pins 525 are mounted in the selector bar 526 by downward insertion through the openings 560, and such downward movement of each pin is limited by a head 562 which is provided on each of the pins 525. The selector pins are yieldingly retained in position on the selector bar 526 by spring latch devices 563 which are mounted within the selector bar and are adapted to cooperate with annular latching grooves 564 formed in each of the selector pins 525. The heads 562 of the selector pins 525 are of such a height that when the selector bar 526 is in position on the selector head 500, the upper faces of the heads 562 are firmly seated against the downwardly facing abutment surface 539 of the sensing head.

The sensing head 500 is reciprocated through a straight-line vertical sensing stroke each time a sensing operation is to be performed, and this reciprocation is imparted to the sensing head 500 in such a manner that the upward or idle movement of the sensing head 500 is positive while the downward or active stroke of the sensing head is imparted thereto by yielding means. Thus when one of the sensing pins 525 encounters a solid area of a tab 120 in the course of the downward stroke of the sensing head 500 such downward movement of the sensing head 500 is terminated at a level which is dependent upon the type or length of the sensing pin which is encountered by a tab 120.

For the purpose of imparting such controlled movement to the sensing head 500, means is associated with the feed clutch 251 so that the sensing head may be moved through its operative sensing stroke each time the printing device advancing clutch operates through its one revolu-

tion cycle. For this purpose the disk 385 of the cam assembly which is pinned to the driven member of the advancing clutch 251 is formed as an actuating cam, as shown in Figs. 12 and 36 and is engaged by a roller 601 mounted on a bifurcated link 602. The bifurcations 603 of the link 602 ride on the upper and lower faces of the concentric surface of the adjacent disk 384 which is located on the right-hand side of the cam 385, as shown in Fig. 12. Thus the link 602 is guided between the cam 385 and the disk 384, and the roller 601 is thereby maintained in a proper plane for engagement with the cam 385. The other or rear end of the link 602 is connected by a pivot pin 605 to an upwardly projecting arm 606 of a bell crank 607, and the bell crank 607 is fast on a rock shaft 608 which extends along the rear portion of the machine beneath the mounting bar 186. The shaft 608 is supported in bearings 609 formed on downwardly projecting portions of the mounting brackets 202 and 203, and at its right-hand end the shaft 608 is additionally supported in a depending bearing bracket 609' carried on the mounting bar 186. The bell crank 607 has an arm 610 projecting rearwardly from the axis of the shaft 608 in a generally horizontal direction and a spring 611 connected between the arms 610 and an anchoring pin 612 projecting rearwardly from the mounting bar 186 urges the shaft 608 in a clockwise direction, as viewed in Fig. 36, thereby to maintain the roller 601 in contact with the cam 385. Adjacent to its other or right-hand end the shaft 608 has an upwardly projecting lever arm 615 fixed thereto, as shown in Fig. 35, and this arm 615 is operatively connected to the sensing head 500 so that when the shaft 608 rocks under the joint influence of the cam 385 and the spring 611, such rocking movement is transmitted to the sensing head 500 to reciprocate the same through an operative sensing stroke. The operative connection is provided by a link 616 which extends forwardly from the arm 615 and is connected to the downwardly projecting arm 617 of a rocking frame 618. The rocking frame 618 is mounted on a shaft 619 which is, in turn, mounted in and projects to the left through a vertical bearing plate 620. The plate 620 is bolted to the right-hand side of the girder 151 so as to project downwardly therefrom as shown in Figs. 35 and 46. The left-hand end of the shaft 619 (as shown in Fig. 40) is supported by a bearing member 621 which is carried by and extends downwardly from the other or left-hand girder 152. The rocking frame 618 has an arm 625 which projects rearwardly therefrom, as shown in Fig. 35, and the arm 625 is connected by a pivot pin 626 to the lower end of a link 627 as shown in Fig. 31. The upper end of the link 627 is connected to a pivot pin 628 which projects from the right-hand end of the sensing head 500. The other or left-hand end of the shaft 619 has an arm 630 fixed to and projecting rearwardly therefrom, as shown in Figs. 31 to 34, and the end of the lever 630 is connected by a link 631 to the left-hand end of the sensing head 500. The link 631 is connected and mounted in the same general manner as the link 627. Thus when the cam 385 permits the spring 611 to rock the shaft 608, the arm 615 is moved to the left in Fig. 35, or forwardly. Since the link 616 is connected to the downwardly projecting arm 617, this action imparts a clockwise rocking movement to the shaft 619 and through the connection afforded by the two links 627 and 631, the sensing head 500 is shifted downwardly with a

yielding force. In the event that one of the selector pins 535 carried in the sensing head 500 encounters a tab 120 at the corresponding index position on a printing device D located at sensing station, the yieldingly induced downward movement of the sensing head 500 is terminated, and the point or level of such termination is determined by the length of the selector pin.

When the cam 385 is in its rest position as shown in Fig. 36 of the drawings, the cam roller 601 rides against a relatively long dwell portion or surface 635 and after the rotation of the cam is started in a clockwise direction as shown in Fig. 36 the dwell surface 635 remains in engagement with the cam roller throughout substantially 180°, thereby to maintain the shaft 608 stationary during substantially the entire first half of the cycle of movement of the printing device advancing means. A receding surface 636 of the cam 385 then moves into engagement with the cam roller 601 so as to permit movement of the cam roller 601 to the right in Fig. 36. This right-hand movement of the cam roller 601 causes clockwise rocking movement of the shaft 608, and such movement continues throughout slightly more than 90° of the rotative cycle of the cam 385. A leading surface 637 then engages the cam roller 601 so as to shift the roller 601 to the left and thereby actuate the shaft 608 through a return or counterclockwise rocking movement to its normal or rest position of Fig. 36. Thus it will be clear that the selector head 500 is maintained in its elevated position of Figs. 31 and 35 while the printing device is being advanced from the magazine to the sensing station and the downward movement of the sensing head 500 starts at substantially the time that the printing device reaches sensing station. The actual sensing of the identifying means or tabs of the printing device at sensing station takes place during the return movement of the carrier bars 153 of the initial guideway, and it will be observed that during this period the positioning tooth 192 of the positioning pawl 190 is engaged with the notch 193 formed in the printing device so that the printing device is accurately positioned and accurate sensing of the identifying means is thereby assured.

It will be evident that in many instances the operator will not desire to use the selector mechanism of the present invention, and control means in the form of a control plunger 640 is therefore provided for rendering the selector mechanism inactive. The control plunger 640 is mounted so as to extend through the upper right-hand portion of the recess 207 of the front panel 201 and when the plunger 640 is withdrawn in a forward direction the sensing head 500 is rendered operative. When the plunger 640 is shifted to its inward or rearward position, the actuating means, which normally tends to reciprocate the sensing head 500 through its operative stroke, is disabled. In the present instance the downward stroke of the sensing head 500 is attained through the yielding action of the springs 611 and 611' acting on the shaft 608, and the disabling means as herein shown is therefore in the nature of a detent means which resists the yielding action of the springs 611 and 611'. Thus as shown in Figs. 35 and 46, a detent bell crank 641 is mounted on a horizontal pivot pin 642 located upwardly and somewhat forwardly of the shaft 619. The bell crank 641 has an arm 643 which projects rear-

wardly and has a hook-like end 644 which is adapted to be engaged with an upwardly projecting and rearwardly facing tooth 645 formed on the rocking plate 618. The bell crank 641 also has an upwardly projecting arm 647, and a link 648 which is pivoted at its forward end to the control plunger 640, has its rear end adjustably connected to the upper end of the arm 647. This connection includes a swivel block 649 carried on the arm 647 and having a nut and bolt connection 650 with the rear end of the link 648. When the control plunger 640 is withdrawn in a forward direction, the end 644 of the bell crank 641 is withdrawn to its inactive position of Fig. 35 and the sensing head 500 is free to operate in each operative cycle of the printing device feeding means. When, however, the plunger 640 is pushed to its rearward position the bell crank 641 is rocked to the dotted line position of Fig. 60 so as to prevent clockwise rotation of the rocking plate 618. Thus the sensing head 500 is disabled and remains inactive in its upper position of Fig. 35. The mounting of the pivot pin 642 is in the present instance provided by a mounting casting 660 which as shown in Figs. 35, 46 and 56, is secured by means of bolts 661 to a central portion of the mounting plate 620. The pivot pin 642 is fixed in a projecting boss 662 formed on the mounting casting 660 adjacent to its upper end.

When the selector mechanism is rendered operative by withdrawing the control plunger 640 to its position of Fig. 35, and the sensing head 500 is operated through its sensing stroke, a storage means indicated generally by the reference numeral 670 is set up in accordance with the sensed identifying means or indication pertaining to the printing device D which is then at sensing position. This sensed indication which is thus stored in the storage mechanism 670 is retained in the storage mechanism for a plurality of machine cycles; or until such time as this stored information is to be rendered effective to perform a control operation. One such control operation which may be effected by the storage mechanism 670 in accordance with the information stored therein is the control of the printing means or platen mechanism P of the machine, and by such control of the platen mechanism the machine is caused to operate through print or skip cycles. In such an instance the sensed information which is set up in the storage mechanism with relation to a particular printing device is preferably retained in the storage mechanism until such time as the particular printing device is being moved into the transfer station IV-T, and at this time the stored information is rendered effective to control the conditioning of the printing machine for the next cycle of its operation.

The storage mechanism 670 as herein shown comprises a rotatable storage drum 671 having a plurality of storage plungers 672, disposed about the periphery of the storage drum at equally spaced points, and adapted for longitudinal sliding movement with respect to the drum to different set positions, so that the longitudinal setting of each plunger may represent the stored indication pertaining to a different printing device D. The storage drum 671 is mounted on a horizontal axis provided by a shaft 673 which is mounted in a stationary bearing sleeve 674. The bearing sleeve 674 is formed as a part of the mounting casting 660 and is disposed at the lower end of the casting 660 so that the right-hand por-

tion of the bearing sleeve 674 extends to the right from the plane of the mounting plate 620, as shown in Fig. 46, while the left-hand portion 674' extends to the left through a slot 675 formed in the lower edge of the mounting plate 620.

In each operation of the printing device feeding means the storage drum 671 is actuated or indexed through an angular distance corresponding to the angular spacing of the plungers 672, and in the present instance such indexing movement is derived from the arm 156 of the printing device feeding means. For this purpose a ratchet 676 is fixed on the left-hand end of the shaft 673 as viewed in Fig. 46, and the ratchet 676 is actuated by a roller type pawl mechanism provided by a roller 677 mounted on one end of a link 678. The other end of the link 678 is pivoted at 679 on a pivot pin which is mounted on the arm 156 eccentrically with respect to the axis of the shaft 157. The spring 680 acts on the link 678 as shown in Fig. 41 so as to maintain the roller 677 against a lower portion of the ratchet 676. Thus when an arm 156 is in its rest position of Fig. 41, the roller 677 is in a position slightly to the right of one of the teeth of the ratchet wheel 676. When the printing device advancing means starts through its operative cycle, the arm 156 rocks in a counterclockwise direction and the ratchet 676 is advanced to the relationship shown in Fig. 42 of the drawings, it being noted that the spacing of the teeth of the ratchet 676 corresponds to the angular spacing of the storage plungers 672. When the shaft 673 is thus actuated or indexed, the storage drum 671 is correspondingly indexed, the storage drum being fixed on the shaft 673 so as to rotate therewith. Means is provided to hold the storage drum in any one of its angular positions to which it may be advanced by the ratchet mechanism, and this means as herein shown comprises a spring pressed detent plunger 682 mounted in the right-hand end of the bearing sleeve 675 and adapted to engage properly positioned latching recesses 683 formed in a latching plate 684. The latching plate 684 is located on the inner face of an end wall 685 of the storage drum and is fixed thereto as by means of a pin 686.

The storage drum as herein shown is formed so that a cylindrical wall portion 687 extends to the left in Fig. 46 from the end wall 685 and the cylindrical wall portion 687 surrounds a part of the bearing sleeve 674 in spaced relation thereto. For the purpose of mounting the storage plungers 672 upon the storage drum 671, the cylindrical side wall 687 thereof has a plurality of longitudinal slots 690 formed therein, these slots 690 conforming in shape to the cross section of the storage plungers 672 so that the plungers may be reciprocated longitudinally in the slots 690. The slots 690 are, of course, disposed in the proper angularly spaced relation to each other, and after the plungers 672 have been mounted in the slots 690, a retaining ring 691 is secured about the left-hand end of the drum so as to engage the outer surfaces of all of the plungers 672. Thus the plungers 672 may be reciprocated, and are held in position by the retaining ring 691.

The longitudinal shifting or positioning of the storage plungers 672 is utilized as a stored indication of the various control operations which are to be effected, and means is therefore provided for yieldingly retaining the storage plungers 672 in any one of a plurality of different

longitudinal positions. For this purpose a plurality of spaced notches 693 are formed in the outer edge of each of the plungers 672, and a yielding latch means is provided for each of the plungers so as to be engageable with the notches 693 to retain the plungers in any one of the plurality of indicating positions defined by the notches 693. The retaining means is provided in the present instance by means of apertures 694 formed in the retaining ring 691 opposite each of the plungers 672. In each of the apertures 694 a ball 695 is positioned, and means is provided for yieldingly urging each of the balls into operative engagement with the notches 693 of the plungers. In the present instance there are six plungers 672 and a common spring means is provided for each pair of the plungers 672. Thus, an arcuate leaf-type spring 696 is secured between each pair of plungers by a screw 697 so that the opposite ends of the spring 696 bear on the retaining balls 695 of the two adjacent plungers.

In attaining the desired indication of a control operation which is to be performed, the plungers 672 are normally positioned at the left-hand end of their travel as shown by the lower plunger shown in Fig. 46, and the control operation which is normally to be performed is indicated by the degree of movement or displacement of the plunger 672 to the right from the normal position. It is to be noted, however, that a particular longitudinal setting of a storage plunger 672 may be effective to perform different control operations when the adjustment or setting of the machine is varied, as will hereinafter be described. For the purpose of setting the storage plungers 672, means is provided for initially shifting the plungers 672 to the left toward their normal positions while such plungers are moving through an inactive portion of the rotative cycle of the storage drum 671 and for thereafter imparting the requisite shifting movement to the plungers 672 to the right to set the same in the desired control position. In other words, each plunger 672 is normalized at the time when it reaches a set-up station which is in the present instance the lowermost position of stations on the drum 671. The plunger at the set-up station may then be shifted longitudinally to the right in Fig. 46 to give the required indication of the control operation which is to be performed under the governing action of this particular plunger 672, and the plunger which has thus been set up is advanced in a clockwise direction about the axis of the shaft 673 to a control position. While the controlling action of the set-up storage plungers 672 might be exerted selectively at different index positions, with one type of control operation being initiated at one control station or index position of the drum, and another type of control operation being performed at another position of the drum, the present embodiment of the invention provides for the performance of all of the control operations by the plungers 672 at a single control station which in the present instance is located directly above the axis of the shaft 673, or in other words, at the top of the storage drum 671. After exerting the desired controlling action at the control station, the remainder of the travel of each storage plunger 672 about the axis of the shaft 673 constitutes the idle portion of its cycle of movement during which the restoring or normalizing operation is performed thereon.

The normalizing action is in the present instance exerted on the plungers 672 by means of an arcuately shaped cam 700 which as shown in Fig. 56 of the drawings is secured by means of a screw 701 to a radial boss 702 formed on the bearing sleeve 674. Thus the cam 700 is located in part in the space between the sleeve 674 and the cylindrical portion 687 of the storage drum 671, and a cam surface 704 is provided on the left-hand end edge of the cam 700 as viewed in Fig. 46. As a storage plunger 672 moves with the drum 671 from the upper or control position and to the right in Fig. 56, a follower pin 705 which projects radially inwardly from the plunger 672 adjacent its left-hand end, as viewed in Fig. 46, engages the cam surface 704 and as the indexing movement of the storage drum 671 progresses, the cam surface 704 is operable to shift the storage plunger 672 to the normal position illustrated by the lower storage plunger in Fig. 46 of the drawings.

The storage plunger 672 which has thus been normalized and moved into the lower or set-up position is then in condition to have a new set-up operation performed thereon, and a set-up mechanism 720 is provided which is operative to accomplish such a set-up operation. The set-up mechanism 720 is in the present instance operable under the control of the sensing head 500, and operates to shift the storage plunger 672 to different longitudinal positions in accordance with the sensing operation of the sensing head 500.

As herein shown the set-up mechanism 720 comprises an L-shaped set-up arm 721 mounted on a vertical pivot 722 between vertically spaced bearings 723 provided on a mounting casting 724. The mounting casting 724 is secured to the lower rear corner of the mounting plate 620 by means of bolts 725 so that the mounting casting 724 extends downwardly and somewhat rearwardly from the lower rear corner of the mounting plate 620. Thus the axis 722 of the set-up lever 721 is located somewhat rearwardly of the vertical guide rod 501 as will be evident from Fig. 35 of the drawings, and the set-up arm 721 extends forwardly so that an adjustable push plate 730 carried on the end thereof may be moved into operative engagement with the left-hand end of the storage plunger 672 which is located at the lower or set-up position. The longitudinal position to which the plunger 672 is moved is determined by the degree of movement of the set-up lever 721, and means is provided in an operative association with the sensing head 500 whereby the angular movement of the set-up lever 721 is controlled by the vertical movement of the sensing head 500. In the present embodiment this end is attained by cam means, the set-up lever 721 being urged in a counterclockwise direction in Figs. 43 to 45 by means of a spring 731, and such movement being controlled by a vertical reciprocable cam 735 which is moved by the sensing head 500. The cam 735 is mounted for vertical reciprocation in a channel-like guideway 736 which is formed as a part of the mounting casting 724, the guideway 736 being arranged to open to the left as viewed in Fig. 31 so that the cam 735 may ride vertically therein with its operative cam surface facing to the left. The cam 735 has a straight right-hand edge 737 which rides against vertically spaced guide rollers 738 mounted in the guideway 736, and the operative cam surface of the cam 735 is engaged by a cam

roller 740 mounted on the set-up lever 721. Thus the spring 731 acts through the lever 721 and the cam roller 740 to maintain the cam in engagement with the guide rollers 738.

The operative connection between the sensing head 500 and the cam 735 is provided by upper and lower connecting blocks 741 and 742 which are pivoted respectively to the lower end of the guide rod 501 and the upper end of the cam 735, these connecting blocks 740 and 742 being adjustably related by a turnbuckle 743. Thus when the sensing head 500 is moved through a sensing stroke, the degree of its downward movement is transmitted directly to the cam 735, and the operative cam surface of the cam 735 is so formed that the set-up lever is permitted to shift through a related movement under the influence of its spring 731. Thus when the sensing head 500 is in its elevated position shown in Fig. 31, the cam roller 740 is in engagement with a dwell surface 750 of the cam 735, and the set-up lever 721 is thereby held in the retracted or inactive position of Fig. 44. Soon after the downward movement of the sensing head is initiated, a receding surface 751 of the cam is moved into alignment with the cam roller 740 so that the set-up lever 721 may be moved in a counterclockwise direction by its spring 731 toward the position shown in Fig. 45 which is preferably determined by a second dwell surface 752 of the cam 735 which moves into alignment with the cam roller 740. Thus by stopping the downward travel of the sensing head 500 at different levels, the degree or amount of actuating movement imparted to a storage plunger 672 may be varied. It will also be evident that since the set-up lever 721 is actuated through its set-up movement by a yielding force such as that applied by the spring 731, the set-up mechanism is adapted for control by any means which is capable of selectively limiting the amount of travel of the set-up lever 731.

In the present embodiment the degree of downward movement of the sensing head 500 is determined by two factors, the first of which is the presence or absence of identifying means such as a tab in alignment with the sensing pin, and the second of which is the length of the pin which encounters a tab carried by a printing device at sensing position. In accordance with the level at which the sensing head is stopped in its downward movement, the storage plunger 672 which is located at the set-up position is shifted to a corresponding one of the several possible positions determined by the notches 693. Thus when the sensing head 500 travels downwardly throughout its full stroke and comes to rest at level 1 as hereinbefore described, the set-up lever 721 moves throughout its entire range of movement to the position shown in Fig. 45, and the aligned storage plunger 672 is moved to the position shown in Fig. 50 of the drawings, this position being hereinafter termed position 1. Such setting of a plunger 672 in position 1 may be determined by the cam surface 752 as aforesaid, or by a stop lug 752' formed on the cam 700 so as to lie in the path of the pin 705 of the plunger when the plunger is at the set-up position. When the storage plunger is in position 1, the detent ball 695 thereof is engaged with the most left-hand one of the detent notches 693 of the plunger, and for the purposes of this description these detent notches have been numbered from left to right as notches 1 to 7 inclusive. Thus when the plunger is in position 1 the detent ball 695 thereof will be in engagement with the notch which is

numbered 1, and the numbering of the notch which is engaged by the detent ball will in each instance be indicative of the plunger position.

When the sensing head comes to rest at level 2, due to the engagement of a tab by a regular pin such as the regular pin 525A-1, the cam surface 751 of the cam 735 so limits the movement of the set-up lever 721 that the aligned storage plunger 672 is shifted to position 2 as shown in Fig. 51 of the drawings. When the sensing head 500 comes to rest at level 3, due to the engagement of a tab by an intermediate pin such as the pin 525A-2, the cam surface 751 so limits the actuating movement of the set-up lever 721 that the storage plunger 672 is shifted to position 3 as shown in Fig. 52 of the drawings. When a tab is sensed by a long pin such as the pin 525A-3, the sensing head 500 comes to rest at level 4 so that the aligned storage plunger 672 comes to rest in position 4, as shown in Fig. 53 of the drawings. It will be evident that through the use of different types of tabs and different lengths of sensing pins, the set-up movement of the set-up lever 721 might also be limited in different degrees so as to terminate the set-up movement of the plunger 672 in any one of the other three possible positions which are herein shown for the plungers 672. It will also be evident that such variation in the set-up movement might be accomplished through means other than the sensing head and its related cam 735, since it would only be necessary to exert a dominating limiting action upon the yieldingly actuated set-up lever 721.

As hereinbefore pointed out the storage plungers 672 are set-up while they are located at the lowermost or set-up position of the storage drum 671 and the desired controlling action is effected in accordance with the set-up position of each plunger as the plunger moves into the upper or control position. Each plunger 672 might of course exert but a single controlling action in accordance with its set-up position, but in accordance with the present invention means is provided whereby each plunger may selectively exert any one of a plurality of controlling functions, or may under the control of the operator exert more than one controlling function in each machine cycle.

To this end a plurality of individually actuatable control devices or members are operatively associated with the storage drum 671 for selective or group actuation by the storage plungers 672 in accordance with their set-up positions. As herein shown these control devices comprise a plurality of control levers mounted side by side and on a common axis above the control position of the storage drum 671. Thus the mounting casting 660 has a projecting bearing hub 760 as shown in Fig. 46 of the drawings, and a bearing sleeve 761 is mounted in the central bore 762 of the mounting hub 760 so as to project to the right therefrom. The external surface of the bearing sleeve 761 acts as a bearing for a pair of control levers 765 and 766, which are mounted on bearing hubs 765' and 766' respectively which surround the bearing sleeve 761 to the left of an end flange 761. The internal surface of the bearing sleeve 761 acts to support a third control lever 770 through the medium of a bearing plunger or pin 771 journaled in the bearing sleeve 761 and a bearing hub 772 upon which the lever 770 is rotatable. The lever 770 and its hub 772 are rotatably mounted on a reduced end 773 of the bear-

ing pin 771 and are held in a predetermined longitudinal position on the bearing pin 771.

The lower ends of all of the levers 765, 766 and 770 are of the general form shown in the lever 770 in Fig. 35 of the drawings, such lower ends extending somewhat to the right so that a cam surface 775 is provided on the lower portion of each of the control levers for operative engagement by cam lobes 776 formed on each of the storage plungers 672. Such operative engagement of a cam lobe 776 with the cam surface 775 of a control lever may take place as the storage plunger 672 moves into the upper or control position, and even then, such operative engagement with a particular one of the control levers may take place only if the storage plunger 672 is in such a longitudinal position as to align its cam lobe 776 with the particular control lever.

The several control members such as the control levers 765, 766 and 770 may be allocated to the performance of a wide variety of different control functions which the user may desire to perform in the printing machine in accordance with the sensed identifying or classification means of the printing devices, and for illustrative purposes the control levers herein shown have been allocated to exercise controlling functions with respect to a signalling means and with respect to the control of the printing means of the printing machine. Thus the control lever 770 is in the present instance arranged to exert a controlling action upon the printing means, and this end is attained by an operative controlling connection with the platen clutch 252 whereby in accordance with the position of the control lever 770 the operation of the platen clutch 252 may be controlled. In the present embodiment this controlling action is exerted in such a manner as to prevent engagement of the platen clutch 252 when the result of a sensing operation indicates that a particular printing device D is to be skipped.

To attain such automatic control of the platen clutch 252, a supplemental stop means such as a stop lever 780 is provided in association with the platen clutch, the stop lever 780 being loosely mounted on the shaft 350, as shown in Figs. 11, 12, 36, 38 and 39, just to the left of the normal stop lever 270' of the clutch 252 so that the stop lever 780 may be shifted from its inactive position of Fig. 38 to an active position wherein it is operative to maintain the clutch 252 disengaged. The supplemental stop lever 780 has an arm 780' projecting rearwardly beyond the shaft 350, and an actuating link 781 has its upper end pivoted to the rear end of the arm 780'. The link 781 extends downwardly just in front of the mounting bar 186, and has its lower end pivotally connected to the forward end of a lever arm 782 which is fixed on a rock shaft 783. The rock shaft 783 is mounted beneath and parallel to the shaft 608 in the bearing members 609 and 609'. Thus when the control shaft 783 is rocked in a counterclockwise direction as viewed in Fig. 36 of the drawings, the supplemental stop lever 780 of the platen clutch 252 is rocked in a clockwise direction toward its active position. Hence it will be clear that when the supplemental stop lever 780 is moved to its active position in the course of a particular machine operation, the succeeding machine operation will be modified to the extent that release of the normal stop lever 270' of the platen clutch 252 will not result in engagement of the platen clutch. This result follows by reason of the dominating action of the supplemental stop lever 780.

The control shaft 783 is actuated by means of the control lever 770 through the medium of a connecting link 785 which has its rear end connected by means of a swivel block 786 to the end of an arm 787 which is fixed to the right-hand end of the control shaft 783 just to the right of the bearing bracket 609'. At its other or forward end the link 785 projects slidably through a swivel block 788 carried on the upper end of the control lever 770. Rearwardly of the swivel block 788 the link 785 carries an adjustable abutment in the form of a pair of nuts 789 and 790, while forwardly of the swivel block 788 a coil spring 791 surrounds the link 785 so as to act between the swivel block 788 and a pair of adjustable lock nuts 792 threaded on the end of the link 785.

Thus when one of the storage plungers 672 has its cam lobe 776 aligned with the control lever 770, the movement of this control plunger, 20 by indexing of the storage drum 671 in the clockwise direction indicated in Fig. 35, and into the uppermost or control position at the top of the storage drum 671, will result in a counterclockwise rocking movement of the control lever 770. The spring 791 will thereby be compressed so as to draw the link 785 forwardly with a yielding force. Hence the control shaft 783 will be rocked with a yielding force so as to shift the supplemental stop lever 780 to its active relation with 30 respect to the platen clutch 252.

Such actuation of the control shaft 783 by the control lever 770 tends yieldingly to impart a counterclockwise rotation to the control shaft 783 as viewed in Fig. 39. It will be apparent 35 however, that in many instances, as where the printing machine is being operated in the performance of duplicate or other multiprint work it may be desirable to delay the effectiveness of the controlling action which would otherwise 40 normally be applied by the control lever 770. To this end the control shaft 783 is dominated by the multiprint mechanism of the machine so that the controlling action exerted by the control shaft 783 is rendered dependent upon the 45 setting or functioning of the multiprint mechanism. In accomplishing this purpose the rocking frame 421 of the multiprint mechanism has a rearwardly projecting arm 795, and a control link 796 is connected at its upper end to the rear 50 end of the arm 795 by means of a pivot pin 797. At its lower end the control link 796 has a longitudinal slot 798 formed therein, and this slot 798 is engaged by a pin 799 which projects from an arm 800 fixed on the control shaft 55 783.

When the multiprint mechanism is inactive and the cam roller 432 thereof is seated in a recess 438 of the cam 433, the multiprint rocker 421 is located in its most clockwise position so that the control link 796 is located in the position shown in Fig. 39 of the drawings. When this relationship exists it will be evident that the control shaft 783 may be freely rocked for a short distance in a counterclockwise direction 60 for the purpose of shifting the supplemental stop lever 780 into its active position, and in such movement the pin 799 will move idly upwardly in the slot 798. When, however, the multiprint mechanism of the printing machine 65 is set in an operative relationship, the first operation of the machine will serve to shift a printing device D from the transfer station IV-T into printing position, and at the same time the platen mechanism will ordinarily start through 70 its normal printing cycle. Assuming for pur- 75

poses of illustration that the sensing operation which has been performed upon the printing device which is then shifted into the transfer station IV-T has indicated that this particular printing device is to be skipped, and has, in response to such a sensing operation, set the corresponding storage plunger 672 with its cam lobe 716 in alignment with the control lever 770, it will be evident that the control lever 770 will be actuated. It will also be evident that as this particular printing device is advanced into the transfer station IV-T, the actuation of the control lever 770 by the corresponding storage plunger will tend to actuate the control shaft 783. Since the actuating force is applied to the shaft 783 in a yielding manner by the spring 791, the controlling action thereof may be delayed by preventing the control shaft 783 from moving the supplemental stop lever 780 into its active position. This end is attained by the control link 796, it being noted that the cam 433 is advanced through one increment of movement early in the conditioning movement or first-half of the cycle of the platen mechanism. Hence the rocking frame 421 is rocked in a counterclockwise direction, thereby to shift the control link 796 downwardly to such a position that the upper end of the slot 798 engages and acts as a stop in the path of the pin 799. Hence when the yielding force is thus applied to the control shaft 783 by the spring 791, the control shaft 783 will remain stationary, and this condition will prevail until the next cam recess 438 is brought into alignment with the cam roller 432. The control rocker 421 also acts in its normal manner of operation to disable the feed clutch 251 when the cam roller 432 is engaged by a cam lobe 439, and therefore, in the next cycle of machine operation the same printing device D will remain at printing position and the platen mechanism will operate to perform a second printing operation therefrom; and in addition it will be observed that due to the fact that the printing device advancing means is inactive in this machine cycle, the storage drum 671 will remain stationary and the control lever 770 will remain in its actuated position.

As this second printing impression is made from the printing device at printing position, the cam 433 is again indexed or advanced so that a cam recess 438 is brought into alignment with the cam roller 432. The control rocker 421 therefore moves to its most clockwise position shown in Fig. 39 so that the control link 796 is withdrawn in an upward direction, thereby to permit the yielding force which has been applied to the control shaft 783 by the spring 791 to rock the control shaft 783. This rocking movement shifts the supplemental stop lever 780 of the platen clutch 252 into its active relationship wherein it will prevent engagement of the platen clutch 252 in the next machine cycle. The clockwise rocking movement of the control rocker 421 also serves to withdraw the supplemental stop lever 425 of the printing device advancing clutch to its inactive position. The printing machine will therefore, be conditioned so that in the next machine cycle the printing device D at the transfer station IV-T will be advanced to printing position, but no printing operation will be performed therefrom.

When the supplemental stop lever 780 of the platen clutch 252 is thus actuated to prevent or suppress a printing operation with respect to a particular printing device, it will be evident that

the supplemental stop lever 780 need not remain in its active relationship with respect to the clutch dog for more than a slight period of time, since the normal stop lever 270' returns to its active position soon after the rotation of the drive shaft 200 has been initiated. In order to facilitate the withdrawing movement of the supplemental stop lever 780, means is provided to impart a partial releasing movement to the stop lever 780 soon after a machine cycle has been initiated. To this end a pin 805 projects to the left from the stop lever 780, as shown in Figs. 11 and 12, and this pin 805 is so positioned that when the cam 381 forces the cam roller 390 of the positioning pawl mechanism in a forward direction, the forward face of the roller 390 engages the pin 805 and rocks the supplemental stop lever 780 partially toward its released or inactive position. After such actuation by the roller 390, the supplemental stop lever 780 still remains in engagement with the end of the clutch dog, but the engagement is such that but a slight force is required to complete the disengaging movement. Hence when the storage drum 671 is actuated or advanced so as to release the control lever 770 for return in a clockwise direction as viewed in Fig. 35 to its normal position under the influence of its actuating spring 806, the supplemental stop lever 780 will complete its movement to its inactive position of Fig. 39, and will remain in this inactive position until it is again actuated through the medium of the control lever 770.

As hereinbefore pointed out the several control levers 765, 766 and 770 may be allocated for the performance of different types of controlling functions or operations, and in the present instance the control lever 766 is utilized to control a signalling means such as a bell 810 which is sounded under the controlling action of the control lever 766 to warn an operator when a printing device of a particular classification is being advanced into the transfer station IV-T. In accomplishing such control of the signalling means the control lever 766 is arranged to govern the action of a hammer 811 which is mounted on a spring arm 812. The spring arm 812 is carried on a rocking hammer bracket or hammer rocker 813 which is mounted on a pivot pin 814 projecting from the mounting bracket 660. The hammer rocker 813 has a pin 815 projecting therefrom on the right-hand side of the pivot pin 814 as shown in Figs. 56 and 57 and a spring 816 acts on the pin 815 to yieldingly urge the hammer rocker 813 in a counterclockwise direction, thereby to tend to actuate the hammer 811 toward bell 810. This action is controlled by a plurality of latch devices, one of which is governed by the control lever 766, and the other of which is governed by a control plunger 820 projecting through the front panel 201 of the machine just to the left of the control plunger 640. The control plunger 820 has a rearwardly projecting rod 821 connected thereto and at its rear end the rod 821 is connected by means of a pair of nuts 822 to a swivel block 823 which is carried on the upper end of a latch lever 824. The latch lever 824 is mounted on the pivot pin 642 somewhat to the left of the lever 641, and at its lower end the latch lever 824 has a shoulder 826 which is adapted to engage the upper surface of an ear 827 formed on the hammer rocker 813 just rearwardly of the shaft 814. Thus when the control plunger 820 is pressed rearwardly, the latch lever 824 is located in the position

shown in Fig. 56 of the drawings, with the shoulder 826 overlying the ear 827. Hence the spring 816 cannot impart a counterclockwise bell-ringing movement to the hammer rocker 813. When the operator wishes to disable a bell mechanism the plunger 820 is pressed inwardly, as just described, and the bell mechanism cannot be operated even though the other latch device operated by the control lever 766 may be released under the controlling action of the selector mechanism. When the operator wishes to render the bell mechanism effective, the control plunger 820 is withdrawn to its forward direction so that the latch lever 824 is shifted to the inactive position shown in Fig. 57 of the drawings. When the latch lever 824 is thus rendered inactive, the control lever 766 may be operated by the storage mechanism of the selector to produce operation of the bell mechanism.

To this end a second latch device or latch lever 830 is provided as shown in Figs. 58 and 59 of the drawings, this latch lever 830 being mounted on the sleeve 761 so as to project upwardly therefrom. The latch lever 830 has a spring 831 acting between its upper end and the pin 642 so as to tend to rock the latch lever 830 from its released position of Fig. 59 in a clockwise direction to its active or latched position shown in Fig. 58 of the drawings. Such clockwise rocking movement of the latch lever 830 is limited by engagement of a rearwardly facing surface 832 thereof with the mounting pin 814. When the latch lever 830 is in its active position of Fig. 58 an upwardly facing latching shoulder 833 is positioned beneath a laterally projecting ear 834 formed on the hammer rocker 813 forwardly of the shaft 814. Thus the latching shoulder 833 restrains the hammer rocker 813 against counterclockwise actuation by its spring 816. The latch lever 830 may be moved from its active position of Fig. 58 to its released position of Fig. 59 by the rocking movement of the control lever 766, it being noted that the control lever 766 is normally urged in a clockwise direction as viewed in Fig. 60 by means of a spring 835 which acts between an upper portion of the control lever 766 and the pivot pin 642. The latch lever 830 is mounted considerably to the left of the control lever 766, as viewed in Fig. 46, and a cam surface 836 formed on the forward face of the control lever 766 is adapted to be engaged with a laterally projecting pin 837 mounted on the latch lever 830, as shown in Figs. 46 and 60. When the control lever 766 is actuated in a counterclockwise direction (Figs. 60 and 61) by the action of a properly positioned storage plunger 672, the cam surface 836 engages the pin 837 and rocks the latch lever 830 to its released position of Fig. 59, thereby to permit the hammer rocker 813 to be shifted in a counterclockwise direction by its spring 816, thereby to cause ringing of the bell 810 as will hereinafter be described. Such counterclockwise rocking movement of the rocker 813 may be limited in many different ways, but in the present instance such movement is limited by engagement of the ear 834 with another abutment surface or shoulder 840 formed on the latch lever 830.

Since such release of the hammer rocker 813 by the latch member 830 takes place quite early in the machine cycle, I prefer to provide a timing means to delay actual sounding of the bell 810 until later in the cycle of operation and to this end a third latching means is normally operative upon the rocker 813 and is released at

70 the desired time in the cycle; and in addition to the timing action, this latch also enables the latch 830 to be employed in attaining other control functions as will hereinafter be described. 5 For this purpose a latch lever 841 is mounted on the shaft 642 so as to project rearwardly therefrom, and the latch lever 841 has a downwardly facing latching shoulder 842 formed thereon which is adapted to engage with the upper surface of the ear 827 as shown in Fig. 58 of the drawings. Such engagement is obtained by connecting the rear end of the spring 816 to a pin 843 which projects from the latch lever 841.

When the rocking frame 618 is actuated 15 through a clockwise movement for the purpose of lowering the sensing head 500, an upwardly facing shoulder 844 formed on a forwardly projecting arm 845 of the rocking frame 618 engages the pin 843 so as to shift the latch lever 841 to its released position of Fig. 59, and in such an instance the hammer rocker 813 is operated through a bell ringing movement in the event that the latch 830 has been released by the control lever 766. It will be observed that such actuation of the latch lever 841 to its released position also serves to apply additional tension to the spring 816.

When the rocking frame 618 is returned in a counterclockwise direction to its position of Figs. 30 35 and 58 for the purpose of returning the sensing head 500 to its elevated position, the lower surface of the arm 845 engages the pin 815 on the rocker 813, thereby to return the rocker 813 to its position of Fig. 58. When this action takes place the latch 841 returns to its active position of Fig. 58. Since the storage drum 671 has remained stationary during the restoring movement of the rocker 813, the control lever 766 has been maintained in its actuated position of Fig. 63, and as a result the latch 830 has been maintained in its released position of Figs. 59 and 63. While the rocking frame 618 remains in the position shown in Figs. 58 and 62, the engagement of the arm 845 with the pin 815 maintains the rocker 813 in its most clockwise position so that the shoulder 842 of the latch 841 is located in spaced relation to the ear 827. In the next advancing cycle of the machine the storage drum 671 is advanced during the first half of such advancing cycle so that the cam lobe 716 of the uppermost storage plunger 672 is moved from the engaged relation in which it is shown in Fig. 61 so as to release the control lever 766 for movement to the normal position shown in Fig. 60. The latch 830 is therefore moved by its spring 831 to its active or latched relationship to the ear 834 of the rocker 813 as shown in Fig. 58 of the drawings. If the next control plunger 672 which is then being moved to the upper or control position is so located or set as to be aligned with the control lever 766, the lever 766 will be actuated and the latch 830 will be again released in the last portion of the first half of the advancing cycle. The arrangement which is herein shown is such, however, that the bell 810 will not be sounded immediately upon release of the latch 830, this delay being occasioned by the latch 841 which remains effective upon the rocker 813 until early in the second half of the cycle of operation of the printing device advancing means. Thus the actuation or release of the latch 830 serves merely to condition the bell mechanism for operation at a subsequent point in the machine cycle under the control of the latch 841. Hence the latch 841 may be termed a timing latch whereby the sounding of the bell may be arranged to take

place at an appropriate point in the machine cycle.

The control lever 765 is in the present embodiment of the invention allocated to the performance of supplemental control functions related to the signalling control operation attained by the control lever 766 and also related to the control operations effected by the control lever 770. In attaining this desired interrelationship of the control lever 765 with the other control levers, the control lever 765 is positioned relatively close to the lever 766 and on the left-hand side thereof as viewed in Figs. 50 to 53, and means is provided whereby actuation of the control lever 765 by the lobe of an appropriately positioned storage plunger 612 may be rendered effective to sound the bell 810 or to impart a control movement to the control lever 770. The means which is herein provided for attaining such operative association of the several control levers is such that the interrelationship may be varied or set in different relationships, thereby to attain different types of controlling action upon the operative mechanism of the machine.

The desired interrelationship between the control lever 765 and the control lever 766 is provided in the present instance by a laterally projecting flange or arm 850 formed on the control lever 766 adjacent its upper end and arranged to project to the left as viewed in Figs. 47 and 50 to 53 inclusive. The arm 850 projects to the left for such a distance that it is positioned in front of the forward edge of the control lever 765. Thus when the control lever 765 is rocked in a counterclockwise direction by the cam lobe 776 of a suitably positioned storage plunger 612, it is moved from the position shown in Fig. 62 to the position shown in Fig. 63, and by reason of the position of the arm 850 in front of the edge of the control lever 765, the control lever 766 is rocked through a similar controlling movement as indicated in Figs. 62 and 63. Thus in such an instance the actuation of the control lever 765 results in the sounding of the bell 810 in the same manner as such operation would have been attained by direct actuation of the control lever 766 by a cam lobe 776. It will be observed, however, that when the control lever 766 is actuated directly by a cam lobe 776, the arm 850 merely moves forwardly away from the control lever 765 and the lever 765 remains in its normal position toward which it is urged by its spring 852. The spring 852 acts between an upper portion of the control lever 765 and the shaft 642, and the normal position of the control lever 765 is limited by engagement of the rear edge thereof with the shaft 614 as shown in Fig. 62 of the drawings.

In attaining the desired interrelationship of the control levers 765, 766 and 770 for the purpose of enabling the controlling action of at least certain of these control levers to be varied or changed, the present invention provides for varying the positioning of these levers relative to each other. In the present instance such variation is attained by lateral shifting of the control lever 770, and means is provided whereby such lateral shifting of the control lever 770 varies the operative interrelationship of the several levers with respect to the control lever 770. Such variation in the setting or operative interrelationship of the control levers is in the present instance utilized principally to reverse the controlling action of the selector mechanism upon the printing means of the printing machine, in

that with one setting of the control levers with relation to each other the machine is operative to print only from those printing devices upon which a tab has been sensed by a regular selector pin such as the selector pin 526A-1, while in its other setting the printing machine is operative to print from all of the printing devices except those upon which the presence of a tab at a selected identifying position has been sensed by such a regular selector pin. The first mode of operation above described, that is, where the presence of a tab must be sensed in order to cause a printing device to be used in a printing operation, is known in the art as "print tab operation"; while the second mode of operation above described, that is, where the sensed presence of a tab causes a printing device to be skipped, is known in the art as "skip tab operation," and this terminology will hereinafter be employed with reference to such setting and operation of the machine.

It will be recalled that the control lever 770 is mounted upon the right-hand end of the plunger 771 which is mounted within a sleeve 761, and as shown in Figs. 46 and 48, the plunger 771 is mounted for sliding movement longitudinally of the sleeve 761. Means is provided for imparting such shifting movement to the plunger 771, and in the present instance this means comprises a bell crank lever 855 mounted on a vertical pivot 856 in the mounting bracket 660 so that one arm 857 of the bell crank projects rearwardly through a slot 858 in the mounting sleeve 760. The rear end of the arm 857 has an operative connection with the plunger 771 so that rocking movement of the bell crank 855 imparts longitudinal shifting or setting movement to the plunger 771. To provide such a connection the left-hand end of the plunger 771 is bifurcated or slotted as shown in Fig. 46 and the rear end of the arm 857 extends into this slot. At its rear end the arm 857 has a slot 860 formed therein and the slot 860 is engaged by a pin 861 which is mounted in the plunger 771 and extends across the slot in the plunger and through the slot 860 in the arm 857.

The bell crank 855 has another arm 862 which extends to the right as shown in Fig. 48, and at its right-hand end the arm 862 has a swivel block 863 mounted thereon. For the purpose of actuating the bell crank 855 a connecting rod 864 has its rear end extending through and adjustably connected to the swivel block 863 by means of nuts 865 threaded on the connecting rod 864 in front and in back of the swivel block. At its forward end the connecting rod 864 is connected to the rear end of a control plunger 866 which is mounted in the front panel 207 of the machine just below the control plunger 640.

Thus it will be clear that the control lever 770 may be shifted laterally with respect to the control levers 765 and 766, and in such lateral shifting movement the operative interrelationship of the levers is varied, and the relationship of the control lever 770 to the storage drum and the storage plungers is materially changed; and in addition the interrelationship of the several control levers is materially varied. Thus as shown in Figs. 47, 52 and 53 inclusive, the control lever 765 has an arm 870 projecting to the right for a considerable distance, while control lever 766 has an arm 871 projecting therefrom in a right-hand direction for a distance somewhat less than the projection of the arm 870. The arms 870 and 871 are located along the rear edges of the

control levers 765 and 766 respectively and when the control lever 770 is in the position shown in Figs. 50 to 53 inclusive, it will be evident that a control actuation of either one of the control levers 765 or 766 will bring the two arms 870 and 871 into operative engagement with the rear edge of the upper portion of the control lever 770, thereby to impart a similar control actuation to the control lever 770. When, however, the control plunger 866 is withdrawn in a forward direction from its position of Figs. 48 and 49, so as to engage its spring detent plunger 872 with the second one of its detent notches 873, the plunger 771 is shifted to the right to the position shown in Fig. 54. In this position it will be observed that the control lever 770 is located in the path of the end portion of the arm 870, but is out of the path of the arm 871. Hence a control actuation of the control lever 766 in such an instance is ineffective upon the control lever 770, while a control actuation of the control lever 765 produces a corresponding actuation of the control lever 770.

When the control plunger 866 is further withdrawn so that its detent 872 engages the third or most rearward of the detent notches 873, the plunger 771 is shifted further to the right so that the control lever 770 is located in the position shown in Fig. 55. It will be observed that when the control lever 770 is in this position, it is located not only out of the path of the arm 871 but is also out of the path of the arm 870, and hence neither one of the control arms 765 or 766 can be effective upon the control lever 770.

The different lateral settings of the control lever 770, as just described, produce different controlling actions upon the machine, and with the construction herein illustrated and described the most left-hand position of the control lever 770 which is attained when the control plunger 866 is in its most rearward position, is effective to produce "skip tab operation" and this fact is indicated by the legend 875 carried on the forward end of the plunger 866 as shown in Fig. 48. When the control lever 770 is in the position shown in Fig. 54, due to actuation of the control plunger 866 in a forward direction to its second position, the present machine operates in its "print tab" manner of operation, as hereinbefore defined, and the setting of the machine for such operation is indicated by an appropriate legend 876 positioned on the top of the plunger 866 so as to be exposed when the plunger is withdrawn to its second position.

When the control lever 770 is located in the position shown in Fig. 55 of the drawings, due to actuation of the control plunger 866 to its third position, the selector mechanism is ineffective for controlling the printing means of the machine, and in the present embodiment of the invention the only control operation which may then be accomplished by the selector mechanism is the sounding of the warning signal or bell 810. Such adjustment of the machine is indicated by a suitable legend 877 formed on the top of the control plunger 866 in such a position as to be exposed when the control plunger is withdrawn to its third position.

The selector mechanism as herein shown is constructed and arranged so that when a storage plunger 672 is located in position 1 as hereinbefore defined, and as shown in Fig. 50, the cam lobe 776 of the storage plunger is aligned with the "print tab" position of the control lever

770 shown in Fig. 54 while a storage plunger 672 set in position 2, as shown in Fig. 51, has its cam lobe 776 aligned with the "skip tab" position of the control lever 770 shown in Fig. 51. When a storage plunger 672 is set in position 3, as shown in Fig. 52, the cam lobe 776 thereof is aligned with the control lever 766, while a storage plunger 672 set in position 4, as shown in Fig. 53, has its cam lobe 776 aligned with the control lever 765. Thus the controlling action which may be exerted by the cam lobe of a storage plunger 672 is dependent in the first instance upon the longitudinal position in which the storage plunger has been set, and is dependent in a secondary sense upon the adjustment or positioning of the control lever 770. It will be recognized, of course, that the setting of each storage plunger 672 is dependent upon at least two factors, the first of which is the presence or absence of a tab in the path of a sensing pin, and the second of which is the length or type of sensing pin which engages such a tab. Thus the controlling action of the selector mechanism of the present invention is dependent upon a large number of different variable and settable factors, and by appropriate variation of these factors, as by the choice of different types of tabs, the choice of different lengths of selector pins, and by appropriate setting of the control lever 770 and the various control plungers on the front panel of the machine, the present machine may be utilized to attain automatic selection in an unusually effective manner.

35 Skip tab operation with notched tabs 120A

Thus when notched tabs such as the tabs 120A shown in Figs. 15 and 16 are employed, selector pins such as those shown in Figs. 18 to 21 may be employed in a 24-position pin holder or selector bar such as that shown in Fig. 17 of the drawings. With such an arrangement of tabs 120A, the operator may use selector pins of any of the three different lengths shown in Figs. 19 to 21 inclusive, and in such an instance the machine may be set for either "print tab" or "skip tab" operation, depending in part upon the method or system employed in assigning the identifying means to the printing devices and also depending in part upon the selection problem at hand. When the machine is set for "skip tab" operation, the control lever 770 is located in the lateral position shown in Figs. 50 to 53 inclusive. As a preliminary to such operation of the machine, the operator determines what classifications are to be skipped, and regular pins, such as the regular pin 525A-1 shown in Fig. 19 are inserted in the pin holder 526A shown in Fig. 17, such pins being inserted only in those pin receiving apertures pertaining to the classifications which are to be skipped. In such a set-up of the machine the operator may also wish to use an intermediate pin such as the pin 525A-2, since such a pin is operative as will hereinafter be explained, to cause sounding of the bell 810. Such an intermediate or bell pin is in such an instance used to warn the operator that a printing device bearing identifying means at a particular position has been sensed and is being advanced into transfer position IV-T. When the machine is being used with notched tabs 120A, and with the machine set in the "skip tab" setting of Figs. 50 to 53 inclusive, it is not customary to use the long pin such as the selecting pin 525A-3, since the action of such a long pin in

this machine set-up is the same as the action of the intermediate pin or bell pin 525A-2.

After placing the proper type of selector pin in the appropriate positions or openings of the pin holder or selector bar 526, this selector bar is mounted in position on the selector head 500. The magazine M is loaded with printing devices D and the filing drawer from which the printing devices were removed is placed in position on the drawer holder 181. After returning the drawer holder to its normal or elevated position, the machine is in condition for operation. However, since the selector mechanism is to be used to control the machine in accordance with the sensed identifying means carried on the printing devices D, the various elements of the selector control or setting means must of course, be properly set. The selector control plunger 640 should, of course, be withdrawn to the position shown in Fig. 35 so that the detent 644 is withdrawn to its inactive position. The bell control plunger 820 should also be withdrawn so as to release the latch 824, it being noted that the operator in this instance desires the bell 810 to be sounded whenever a bell pin encounters a tab. The position of the control plunger 866 should also be checked to make sure that it is in its innermost position, thereby to locate the control lever 770 in its "skip tab" position of Figs. 50 to 53 inclusive.

Having thus checked the setting of the machine, the operator may turn on the motor 205 by withdrawal of the switch control plunger 208 so that operation of the machine may be instituted. The operation of the machine may, of course, be started through the actuation of an auto-stop control such as that disclosed in my co-pending application Serial No. 388,988, filed April 17, 1941, but such an auto-stop mechanism would usually be used in a machine of this character only where automatic manipulation or feeding of the sheet or sheets is employed through the provision of appropriate auxiliary mechanism. For example, the sheets or forms might be automatically fed to printing position through the use of an automatic sheet feeder such as that disclosed in the co-pending application of Morse, Serial No. 403,282, filed July 21, 1941, or a single sheet or form might be automatically shifted past printing position through the use of an automatic listing device such as that shown in my co-pending application Serial No. 410,097 filed September 8, 1941. In the event that an automatic sheet feeder were employed, the auto-stop mechanism hereinabove mentioned would be actuated to stop operation of the machine in response to a double feed or the feeding of the last sheet by the sheet feeder or in response to the withdrawal of the last printing device from the magazine M, and similar automatic termination of the operation of the machine would also be resorted to in the event that a listing device were used with the machine.

Although continuous and automatically terminated operation of the printing machine might be attained as hereinbefore mentioned, the machine is herein shown as adapted for control by means of the various foot pedals 320, 321 and 322, and when the selector of the present invention is being utilized, each cycle of operation of the machine is initiated through momentary depression of the "consecutive" foot pedal 322.

With the machine set up as aforesaid for "skip tab" operation with printing devices having notched tabs 120A as the identifying means 75 mains inactive.

thereon, the sensed absence of tabs at all of the selected identifying positions results in movement of the related storage plunger 672 which is then the lower or set-up position of the storage drum so that the plunger is set in position 1, as shown in Fig. 50 of the drawings. Hence it will be clear that when this storage plunger in position 1 moves into the upper or control position, its cam lobe 776 moves freely by the control lever 770 as shown in Fig. 50, with the result that the supplemental stop lever 780 of the platen clutch remains in its inactive position. The machine is therefore, conditioned for the performance of a printing operation from the related printing device D when it is advanced into printing position in the next cycle of operation of the printing machine.

If the next printing device D advanced to the sensing station bears a tab 120A in the position corresponding to the selected mounting of the regular sensing pin 525A-1, and there is no other tab on the printing device which might be sensed by the intermediate sensing pin 525A-2, the sensing by the regular pin 525A-1 of the tab 120A in a corresponding identifying position on a printing device acts on the related storage plunger 672 which is then in the lower or set-up position of the storage drum so as to set the storage plunger in position 2, as shown in Fig. 51.

The storage plunger 672 which is thus set in position 2 therefore operates through its cam lobe 776 to impart a control actuation to the control lever 770 when this storage plunger reaches the upper or control position on the storage drum 571. Such control actuation of the control lever 770 acts through the spring 791 and the link 785 to rock the control shaft 783, and as a result the link 781 is elevated and the supplemental stop lever 780 of the platen clutch 262 is shifted to its active position. Thus the machine is conditioned for "skip operation" in the next cycle of operation, and the related printing device will therefore, be advanced into printing position while the platen mechanism P is maintained inactive. The sensing of a tab 120A on the printing device by a regular pin 525A-1 therefore, causes the machine to "skip" this particular printing device. In this controlling action the control lever 770 moves freely away from the arms 870 and 871 of the other control levers so that the signal mechanism remains unactuated.

In the event that the next printing device D advanced to sensing station bears a tab 120A in alignment with the intermediate pin 525A-2, the resulting sensing action of the sensing head 500 causes the related storage plunger 672 to position 3, as shown in Fig. 52. As this plunger 672 moves into control position at the top of the storage drum 571, its cam lobe 776 actuates the control lever 766 through a control movement. In such control movement, the control lever 766 sounds the bell 810 so as to warn or notify the operator that a printing device bearing identifying means in a particular identifying position thereon is being moved into the transfer station IV-T; and in addition to its signalling function, the control lever 766 acts through its arm 871 to engage the control lever 770 and move it through a control operation which sets the supplemental stop lever 780 in its active position. Hence the machine is conditioned for skip operation in its next cycle, and the printing device which has induced such conditioning will be advanced to printing position while the platen mechanism remains inactive.

Where notched tabs 120A are being sensed by the machine while the machine is set for skip tab operation as aforesaid, the operator ordinarily does not employ long sensing pins such as the pins 525A-3, since such pins merely act to set the control plungers 672 to position 4, and in such a setting the plungers act upon the control lever 765 and, through the arms 850 and 870, the control lever 765 merely duplicates the controlling action which is attained as aforesaid through the use of intermediate sensing pins 525A-2.

Print tab operation with notched tabs 120A

To set the machine for print tab operation the same procedure is followed as with the skip tab operation hereinbefore described, with the exception, however, that control plunger 866 is withdrawn to its second or "print tab" position, thereby to shift the mounting plunger 771 and the control lever 770 to the position shown in Fig. 54. In this position the lower end of the control lever 770 is aligned with the location in which the cam lobes 776 are positioned when the storage plungers 672 are in position 1. Thus when the sensing head 500 moves to its lowest level in a sensing operation, or in other words to level 1, thereby to indicate the absence of tabs 120A at all of the selected identifying positions on the printing device then at sensing station, the related storage plunger 672 is shifted to position 1, and when so located, is operable to actuate the control lever 770 when the plunger reaches the upper or control position on the storage drum. In such control operation the supplemental stop lever 870 of the platen clutch 252 is shifted to its active position, so that when the particular printing device is, in the next cycle of the machine, advanced to printing position, the platen mechanism P will remain inactive. Hence the absence of a tab at a selected identifying position on a printing device causes that printing device to be skipped.

When a regular sensing pin such as a pin 525A-1 encounters a solid area on a tab 120A at a selected identifying position on a printing device at sensing station the sensing head comes to rest at level 2, so that the corresponding storage plunger 672 is set at position 2, as shown with respect to the upper storage plunger in Fig. 54. Thus when the plunger reaches the upper or control position it passes freely through the relatively wide space between the control levers 766 and 770. Hence the control lever 770 remains unactuated, and a normal printing operation is performed with respect to the related printing device.

When a sensing pin of the intermediate length, such as a sensing pin 525A-2 encounters a tab 120A as aforesaid, the sensing head 500 comes to rest at level 3, and the corresponding storage plunger 672 is set up in position 3. In such a setting the lobe of the storage plunger 672 actuates the control lever 766 when the plunger reaches the upper or control position. When the control lever 766 is thus actuated, the bell 810 is sounded, but since the control lever 770 is now located in a lateral sense so as to be out of the range of the arm 871, the control lever 770 remains unactuated, thereby to condition the machine for performance of a printing operation with respect to the related printing device.

When a tab 120A is sensed as aforesaid by a long sensing pin such as a pin 525A-3, the sensing head 500 comes to rest at level 4, and the corresponding storage plunger 672 is set in posi-

tion 4. Hence when this plunger reaches its control position it actuates the control lever 765, thereby to act through the arm 850 to sound the bell 810, and through the arm 870 to actuate the control lever 770. Thus the machine is conditioned to skip the related printing device upon which a tab 120A has been sensed, even though the primary setting of the machine is for "print tab" operation. Hence for such selector operation the long sensing pins 525A-3 may be termed "reverse" pins, since they act to reverse the primary controlling action of the selector mechanism.

Selection by signal only

When the control plunger 866 is in its outermost or third position, the control lever 770 is located as shown in Fig. 55 so that it is out of the direct path of the cam lobes 776 in all settings or positions of the storage plungers 672; and in addition, the lever 770 is located laterally beyond the ends of the arms 870 and 871 so that the control lever 770 cannot be actuated by any of the means which act thereon in other settings of the mechanism. Hence with such a set-up of the machine the operator does not employ selector pins of the regular length, but uses pins of the intermediate or long lengths to produce the selective operation of the signal means.

Skip tab operation with embossed tabs 120B

When embossed tabs such as the tabs 120B are employed as identifying means on the printing devices D, the set-up of the machine is substantially the same as hereinbefore described with relation to the notched tabs 120A, but since the embossed tabs 120B provide for forty-eight rather than twenty-four identifying positions, a forty-eight position selector bar 526B is employed to support the selector pins such as the selector pin 525B which is used with embossed tabs 120B. Thus as shown in Figs. 22 and 23, the selector bar 526B is formed from a central section 530B and similar front and rear sections 531B secured together in the same manner as in the sensing bar 526. Similar mounting openings 560B, and retaining catches 563 are also provided in the sensing bar 526B, the mounting openings 560B being disposed in two parallel rows of 24 each, so that sensing pins 525B may be selectively mounted therein at any one of the forty-eight sensing positions. Thus sensing pins such as the sensing pin 525B may be mounted in the sensing bar 526B in the same manner as the sensing pins 526C which are shown in mounted positions in Figs. 22 and 23.

When embossed tabs 120B are to be sensed, but a single length of sensing pin 525B is employed, and this sensing pin 525B is somewhat shorter than the regular pin 525A-1. This difference is such that when a flat or unembossed surface on a tab 120B is engaged by the pin 525B, the sensing head 500 comes to rest at level 1, while the presence of an embossure 126 in the path of a sensing pin 525B causes the sensing head to come to rest at level 2. Hence with the selector set for skip tab operation, the sensed absence of an embossure 126 at the selected identifying positions causes the related storage plunger 672 to be set in position 1, with the result that the control lever 770 will not be actuated by this particular storage plunger, and a printing impression will be made by the printing machine from the related printing device D.

The sensed presence of an embossure 126 at a selected identifying position causes the related

storage plunger 672 to be set in position 2, as shown in Fig. 51, so that the control lever 770 is actuated through a control operation at the appropriate point in the operation of the machine, and the operation of the platen mechanism is thereby suppressed and the related printing device D is skipped.

Print tab operation with embossed tabs 120B

When the selector is set for print tab operation, the control lever 770 is located in the position shown in Fig. 54, so that the sensed presence of an embossure 126 with the consequent setting of the related storage plunger 672 in position 2, causes the cam lobe 776 of that plunger to pass freely by the control lever 770. Hence a printing operation takes place in response to the sensing of an embossure 126.

If, however, there are no embossures in alignment with the sensing pins 525B, the sensing operation results in setting the related storage plunger 672 in position 1, so that the control lever 770 is appropriately actuated to cause the related printing device D to be skipped.

Skip tab operation with perforated tabs 120C or 120D

The form and the functioning of the perforated identifying tabs 120C and 120D are in most respects similar, with the exception that the tabs 120D are divided into five identifying areas rather than into four such areas as is the case with the tabs 120C; and by reason of the cooperative action of the straight line sensing path of the sensing head 500 and the accurate location of the printing devices D by the positioning pawl 100 at sensing station, the present machine accomplishes the desired sensing operation in an accurate and effective manner despite the reduction in the area of the various identifying areas.

When the tabs 120C are employed the sensing pins such as pins 525C-1, 525C-2 or 525C-3 are mounted as desired in the selected openings 560B of the 48-position selector bar 526B, since by the use of the selector bar 526B a selector pin may be aligned with any one of the four identifying areas provided on each of the tabs 120C. When the tabs 120D are employed, a different form of sensing bar 526D is employed as shown in Fig. 29 of the drawings. The sensing bar 526D is made from a solid bar 530D and has two spaced rows of 24 openings or bores 560D and an intermediate row of 12 openings or bores 560D, thereby to provide 60 positions in which selector pins 525D may be selectively mounted. The location and arrangement of the bores 560D corresponds with the positioning of the apertures 127 in the tabs 120D, and to provide clearance for the sensing pin 525C which may pass through the central aperture 127 of each tab 120D, the appropriate ribs 513 of the tab support 510 are bored as indicated at 513', such a formation of the tab support being necessary only when a 60-position selector bar 526D and tabs 120D are being employed.

When perforated tabs are being employed the set-up of the machine is substantially the same as described in connection with the notched tabs 120A. Thus when a regular pin 125C-1 is so located that it passes into an aperture 127 of a tab, the sensing head 500 comes to rest at level 1, thereby setting the related storage plunger 672 at position 1; and since in "skip tab" operation

of machine the control lever 770 is located in the position shown in Fig. 50, the cam lobe 776, when it reaches the control position on the storage drum 674, will pass freely by the control lever 770, and a printing operation will be effected on the related printing device D.

When in a sensing operation a regular pin 525C-1 encounters a solid or unperforated area of a tab the sensing head 500 comes to rest at level 2 and the related storage plunger 672 is set-up in position 2. Hence the cam lobe 776 will, in the appropriate machine cycle, function to actuate the control lever 770 and thereby cause the related printing device D to be skipped.

10 In the event that an intermediate sensing pin 525C-2 or a long pin 525C-3 are aligned with an untabbed area of a printing device, the sensing head 500, in the absence of other controlling forces such as the engagement of a regular pin

20 525C-1 with an unperforated tab area, comes to rest at level 1, thereby to set the related storage plunger 672 in position 1 and cause a printing operation to be effected with respect to the related printing device.

25 When the downward sensing movement of the sensing head 500 is terminated by engagement of an intermediate pin 525C-2 with a perforation 127, the sensing head 500 stops at level 2, so that the set-up of the related storage plunger 672

30 with its cam lobe 776 in alignment with the control lever 770 causes the related printing device to be skipped. If, however, such an intermediate pin 525C-2 encounters a solid or unperforated portion of a tab, the sensing head

35 stops at level 3, so as to set the related storage plunger 672 in position 3. Thus in such an instance the cam lobe 776 of the plunger actuates the control lever 766, thereby to sound the bell 810 in addition to actuating the control lever 770

40 to cause skipping of the related printing device D. This same controlling action is attained when a long sensing pin 525C-3 encounters a perforation 127, since in such an instance the sensing head also stops at level 3 and acts to set the related storage plunger in position 3.

45 The same ultimate controlling action also results when a long sensing pin 525C-3 encounters a solid or unperforated area of a tab, since the sensing head 500 in such an instance comes to rest at level 4 and thereby sets the related storage plunger 672 in position 4. When thus set up, the cam lobe 776 of the plunger actuates the control lever 766, which in turn actuates the control levers 766 and 770 to thereby cause sounding of the bell 810 and skip operation of the machine.

Print tab operation with perforated tabs 120C or 120D

60 When the selector is adjusted for print tab operation, the termination of a sensing movement of the sensing head at level 1, as for example when a regular pin 525C-1 engages a perforation 127, or when all of the pins 525C-1, the intermediate pin 525C-2 and the long pin 525C-3 carried on the sensing bar are aligned with untabbed portions of the printing device at sensing station, causes the related storage plunger to be set in position 1; and as a result the control lever 770 is actuated at the appropriate point in the machine operation so as to cause the related printing device to be skipped.

65 70 75 In the event that the sensing movement of the sensing head 500 is terminated by engagement of an unperforated area of a tab by a regular pin-

525C—1, the sensing head comes to rest at level 2, thereby to set the related storage plunger in position 2 wherein it is out of alignment with all of the control levers. Hence a printing operation is performed upon the related printing device D.

In the event that the engagement of an intermediate sensing pin 525C—2 with a perforation 127 acts to terminate the sensing head movement at level 2, the resulting set-up of the related storage plunger 672 in position 2 causes the cam lobe 776 to pass between the levers 766 and 770, so that a printing operation is performed from the related printing device when it reaches printing position. If, however, such an intermediate sensing pin 525C—2 encounters an unperforated area of a tab and thereby stops the sensing head at level 3, the related storage plunger 672 is set up in position 3 so that a different controlling action is attained. Thus the plunger in position 3 has its cam lobe 776 aligned with the control lever 766, so that when this control lever is actuated, the bell 810 is sounded. In such an instance however, the arm 871 of the control lever 766 passes freely by the control lever 770, so that the control lever 770 remains unactuated, and hence a printing operation will be performed from the related printing device in the cycle of machine operation which follows the sounding of the bell 810.

In an instance where engagement of a long sensing pin 525C—3 with a perforation 127 acts to terminate the movement of the sensing head at level 3, the operation is the same as just described with relation to the sensing of a solid tab area by an intermediate sensing pin 525C—2; and the bell is sounded in the cycle of operation wherein the related printing device is being advanced into station IV—T, followed by the performance of a printing operation from this printing device when it is advanced to printing position.

When a long sensing pin 525C—3 encounters a solid area of a tab, the sensing head stops in position 4, and due to the resulting set-up of the related storage plunger 672 in position 4, the control lever 765 is actuated when this storage plunger reaches the control position at the top of the storage drum. The lever 765 acts through the arm 850 to actuate the control lever 766, thereby to cause sounding of the bell 810, and in addition, the arm 871 engages and actuates the control lever 770 so as to cause the related printing device to be skipped. Hence in this machine set-up the long pin 525C—3 acts, in response to the sensing of a solid tab area, to cause skipping of the related printing device, an action which is opposite to action caused by sensing of a solid tab area by a regular sensing pin 525C—1. The long pin 525C—3 is therefore in this instance termed a reversing pin.

From the foregoing description of the various modes of use and operation of the selector mechanism of this invention, it will be evident that this mechanism has a wide range of use and adaptability to problems of selection and automatic control in printing machines. The variety of adjustments afforded in this mechanism enables various types of indicating means to be advantageously employed, and in addition, enables wide latitude in the range of use to which selector mechanism may be put in controlling selected operative mechanisms of the printing machine.

Selection by coordinated visual signal

In Figs. 66 to 75, inclusive, of the drawings, I have illustrated an embodiment of the invention whereby several different types of business instruments may be conveniently produced in a single run of the machine in accordance with identifying means embodied in the printing devices. In this embodiment of the invention the selector mechanism 670 hereinbefore described functions to determine whether or not a printing operation is to be performed from each printing device, and visual signalling means is arranged to cooperate with the main selector mechanism to indicate what type of form or business instrument is to be printed from each of the printing devices which is thus selected by the main selector mechanism. Thus the printing or skipping of each printing device may be determined by the presence or absence of identifying means in one or more of a selected group of primary identifying positions on each printing device, while the type of form or document to be printed from the printing devices may be designated by identifying means at a selected one of another or secondary group of identifying positions on the printing devices. In accordance with the present invention the automatic selection of the printing devices for print or skip operation of the machine is arranged to cooperate with visual indicating means in such a manner that rapid and effective selection and printing of the required form may be accomplished.

In attaining such operation the identifying means on the printing devices D are sensed by the sensing head 500 in the usual manner to determine whether or not a printing impression is to be made therefrom, and at a subsequent station along the printing device guideway another sensing operation is performed on the identifying means of the printing device so as to provide a visual indication of the type of form which is to be printed from the printing device. The second sensing operation is in the present instance arranged to control a visual signalling means which exhibits the proper signal relating to a particular printing device at the time this printing device is advanced into the transfer station IV—T, and the signal which is thus exhibited is retained or maintained so long as this particular printing device remains at the transfer station.

In the form illustrated in Figs. 66 to 75, inclusive, of the drawings, this visual signalling means embodies a signal panel or box 900 mounted above the head 136 of the printing frame arm 134 by means of a bracket 901. The signal head 900 is arranged to incorporate a plurality of visual signal devices, each of which may pertain to a different type of business instrument or form, and in the present instance the signal head 900 has six lights 902A, 902B, 902C, 902D, 902E and 902F mounted in suitable socket, spaced along the forward edge of the head 900. Individual energizing circuits are provided for the several signal lamps, including a common wire 903 leading from one terminal of a battery 904 to one terminal of each of the several signal lights 902. The other terminal of the battery 904 has a wire 905 extending therefrom to one contact 906 of a normally open switch 907 which in the present instance constitutes a timing switch. The other contact 908 of the switch 907 is connected by a wire 909 to a bus bar 910,

and individual circuits are provided from the bus bar 910 to the several signal lamps 902 in such a manner that each of the signal lamps may be individually controlled. To this end a plurality of switches 911A to 911F, inclusive, are provided, the switch 911A being connected by a wire 912A to the other terminal of the signal lamp 902A. Similar wires 912B to 912F connect the switches 911B to 911F to the appropriate signal lamps 902.

In order that the switches 911 may be selectively closed in accordance with the presence or absence of identifying means at selected positions on the printing devices D, an additional sensing means is provided to sense the identifying means after the printing device has been advanced from the sensing station II to another station along the printing device guideway. In the present instance this secondary sensing means is arranged at station IV so as to perform the required sensing operation while the printing device is at rest at this station. To this end a sensing carrier 915 in the form of a flat plate is mounted for sensing movement just rearwardly of station IV, as shown in Figs. 68 and 69 of the drawings. The sensing carrier 915 has upturned flanges 916 at its opposite ends and a supporting shaft 917 extends through the upturned flanges 916 adjacent the rear edges thereof. The projecting ends of the shaft 917 are supported in mounting bars 918 and 919 which project rearwardly from the girder 161. As shown in Figs. 68 and 69 the girder 161 is generally Z-shaped in form so as to have a rearwardly projecting upper flange 161' to the lower face of which the forward ends of the mounting bars 918 and 919 are secured by means of screws 920. The sensing carrier 915 is adapted for rocking movement about the axis of the mounting shaft 917 and in such rocking movement is adapted to move suitable sensing means through a sensing stroke wherein such sensing means operate to sense the presence or absence of identifying means such as tabs 120 at one or more selected identifying positions on the printing device located at station IV. In the embodiment shown in Figs. 66 to 75, inclusive, I have provided six indicating lamps 902 and for cooperation with this number of lamps 902 I provide six individual sensing members 922. The sensing members 922 are in the form of levers freely pivoted on a mounting shaft 923 which is mounted at its opposite ends in upturned flanges 916 of the sensing carrier 915. The sensing means are held in the desired spaced relation by a series of spacing collars 924 which are in turn secured in position by locking collars 925. At its forward end each sensing member 922 has an upwardly extending sensing finger 925 which extends into an appropriately positioned aperture 926 formed in the flange 161'. The location of the sensing fingers 925 and of the aperture 926 are such that each sensing finger 925 normally underlies the position which will be occupied by a particular identifying tab 120 carried on a printing device located at station IV. Thus when an identifying means in the form of a tab 120 is located directly over a sensing finger 925, as shown in Fig. 72, any upward movement of the sensing finger 925 will be limited by engagement of the sensing finger 925 with the tab 120. In this connection it is to be noted that the printing device D and the tab or tabs carried thereby will be held down by a retaining strip 928 which extends

along the rear side of the intermediate printing device guideway 160, as shown in Fig. 72.

The several sensing members 922 are arranged to cooperate with the switches 911 so that when one of the sensing members 922 senses the presence of a tab 120, the related switch 911 will be closed. To accomplish this purpose the several switches 911 are mounted on the lower face of the sensing carrier 915 in an operative association with the several sensing members 922. Thus the switch 911A is mounted directly beneath the left-hand one of the sensing members 922, and this sensing member is therefore identified as 922A; and a similar arrangement is employed with reference to the other sensing members 922 and switches 911. The switches 911 are in the form of normally open spring switches held in position by a plurality of insulating blocks 930 and bolts 931, as shown in Fig. 72, and above each spring 911 an insulating leaf 932 is provided to insulate the switches from the carrier 915. Each sensing element 922 has a downwardly projecting foot 933 which is adapted to engage the insulating leaf 932 to close the associated switch 911.

The resiliency of the switches 911 is such that the several sensing members 922 are normally rocked in a clockwise direction about the mounting shaft 923 so as to occupy the position shown in Fig. 72, such position being limited by a foot 934 formed on each of the sensing members 922 rearwardly of the mounting shaft 923 in such position as to engage the upper face of the sensing carrier 915. When the sensing carrier 915 is rocked in a clockwise direction about its mounting shaft 917, the several sensing members 922 are moved upwardly, and in the event that a sensing member is restrained due to engagement of its sensing finger 925 with a tab 120, the upward rocking movement of the carrier 915 continues so that the sensing finger which has thus been restrained against movement assumes the position shown in Fig. 73. It will be observed that when a sensing member 922 is thus actuated, the associated switch 911 is moved to its closed position as shown in Fig. 73. Since it is desirable that the switch 911 which is thus closed be maintained closed for a substantial period of time, means is provided for latching any sensing element 922 which may be thus actuated in its switch closing position, thereby to permit the sensing fingers 925 to be withdrawn in a downward direction so that such sensing fingers will not interfere with the feeding movement of the printing device at station IV. To this end a plurality of individual latch devices are provided, one for each of the sensing members 922. These latching devices in the present instance are in the form of latching collars 935 mounted on the mounting shaft 917 for individual rocking movement thereon. Each latching collar 935 is biased in a counterclockwise direction, as viewed in Fig. 73, by means of a spring 936 acting between an arm 937 on the latching collar and an upturned rear flange 938 formed on the sensing carrier 915. Each latching collar 935 has a pair of latching teeth 939 and 940 formed thereon and when the associated sensing member 922 is in its normal relation to the sensing collar 915, a latching finger 941 which projects rearwardly therefrom is engaged with the forward edge of the tooth 939, as shown in Fig. 72. The action of the spring 936 is such as to maintain the tooth 939 in engagement with the end of the latching finger 941. When the sensing element

is rocked to the position of Fig. 73, the latching finger 941 is moved away from the axis of the shaft 917 and outwardly beyond the tooth 939. In such an instance the spring 936 rocks the latching collar 935 in a counterclockwise direction in Fig. 73 so as to move the tooth 939 beneath the latching finger 941. Such rocking movement of the latching collar 935 is limited by engagement of the second tooth 940 with the end of the latching finger 941. Thus when the sensing carrier 915 is rocked in a counterclockwise direction to withdraw the sensing fingers 925 in a downward direction and out of the path of the tabs 120, any sensing member 922, which has been actuated to close its associated switch 911, remains latched in its actuated or switch-closing position.

The required sensing movement of the sensing carrier 915 is imparted thereto in timed relation to the printing device advancing cycle of the printing device advancing means of the machine, and in the present instance this result is attained primarily by means of a cam device which is associated with the carrier bars 163 of the intermediate printing device guideway 160. As shown in Figs. 68 and 69, the carrier bars 163 are held in spaced relation by means of U-shaped spacer members 945 which project downwardly below the lower edges of the girders 161 and 162, and a cam means such as a cam plate 946 is supported from the spacer members 945 by means of a pair of rearwardly projecting angle brackets 947. The angle brackets 947 are secured as by welding to the bottoms of the spacer members 945 and project rearwardly and then upwardly therefrom so as to be located beneath the flanges 161' of the girder 161. The cam plate 946 is secured to the upwardly projecting portions of the angle brackets 947 and is bent outwardly along its lower edge as indicated at 946' so that the lower edge of the cam plate 946 is spaced somewhat from the angle brackets 947. The lower edge of the cam plate 946 constitutes the effective cam surface thereof, and a follower 948 which is fixed to the right-hand portion of the rear edge of the sensing carrier 915 rides against the lower or effective edge of the cam plate. The follower 948 is urged into operative engagement with the cam plate 946 by means of a spring 949 which acts between the sensing carrier 915 and a stationary portion of the machine. The spring 949 is in the present instance mounted about the rear end of a control rod 950 so as to act between an abutment 949' on the rear end of the rod 950 and a downwardly projecting arm 948' formed on the sensing carrier 915 as a part of the follower 948. The control rod 950 extends forwardly and is connected to a control plunger 951 which is mounted in the front panel of the machine. When the control plunger 950 is in its rearward or innermost position, the tension of the spring 949 upon the arm 948' is relieved so that the sensing carrier 915 assumes an inactive position wherein the follower 948 is spaced downwardly a substantial distance from the cam plate 946. When the operator desires to employ the visual selector, the plunger 951 is withdrawn in a forward direction so as to impart tension to the spring 949, it being noted that the plunger 951 has a suitable spring detent means associated therewith to maintain the spring 949 in its tensioned position wherein the follower 948 is maintained in an operative relationship to the cam plate 946.

The cam plate 946 is arranged to produce the

required sensing movement of the sensing carrier 915 as an incident to the operative reciprocation of the carrier bars 163. When the carrier bars 163 are in their rest position at the left-hand end of their reciprocating stroke, the cam plate 946 is positioned as shown in Figs. 68 and 70, and the follower 948 is engaged with the right-hand end of a dwell surface 952 formed on the lower edge of the cam plate 946. In an advancing cycle of the printing device advancing means, the carrier bars 163 move to the right during the first half of the machine cycle, and during substantially one-half of such right-hand movement of the carrier bars 163, the dwell surface 952 remains in engagement with the follower 948 so as to retain the sensing carrier 915 in its downward or retracted position of Fig. 72. At this point in the machine cycle a receding surface 953 formed on the cam plate 946 moves into alignment with the follower 948 so that the sensing carrier 915 is allowed to move upwardly toward the position shown in Fig. 73 under the influence of its spring 949. Such upward movement of the sensing carrier 915 is limited by engagement of the follower 948 with a dwell surface 954 which remains in engagement with the follower 948 until the carrier bars 163 are relatively close to the right-hand limit of their travel. At this point in the machine cycle a leading cam surface 955 formed on the cam plate 946 moves into engagement with the follower 948, thereby to rock the sensing carrier 915 in a counterclockwise direction to the position shown in Fig. 72, and when the carrier bars 163 have reached the right-hand end of their travel, a dwell surface 956 formed on the cam plate 946 engages the follower 948, as shown in Fig. 71 of the drawings. It will be recalled that while the sensing carrier 915 is being rocked through such sensing stroke by the cam plate 946, the printing device at station IV is at rest and the required sensing operation will be performed and any sensing members 922 which have been actuated so as to close their associated switches 911, as shown in Fig. 73, will be latched in their actuated or switch-closing positions.

Thus it will be seen that when the carrier bars 163 are in their right-hand positions, the various sensing fingers 925 are withdrawn so that the printing devices in the intermediate guideway, and particularly the printing device at station IV, may be advanced by the carrier bars 163 as they return toward their most left-hand position, and means is provided for maintaining the sensing carrier 915 in its retracted position of Fig. 72 during such feeding stroke of the carrier bars 163, despite the form of the cam plate 946 which would normally tend to permit a sensing stroke of the sensing carrier 915 during the left-hand or advancing stroke of the carrier bars. In the present instance this means is arranged for operation by a link 195 which actuates the positioning pawl 190. It will be recalled that the link 195 is moved to the right so as to release the positioning pawl 190 soon after the initiation of an advancing operation of the printing device advancing means, and the link 195 is permitted to return to the left under the influence of its spring 193 just prior to the completion of the first half of the cycle of the printing device advancing means. Thus the link 195 moves to the left at the time when the follower 948 is engaged with the dwell surface 956 of the cam plate 946, and the link 195 remains in its left-hand position throughout the remainder of the cycle of the printing device advancing means and until

the initiation of the subsequent advancing cycle. This cycle of movement of the link 195 is utilized to latch the sensing carrier 915 in its lower position of Figs. 69 and 72, and for this purpose the arm 948' of the follower 948 is utilized. For engagement with the arm 948' a detent arm 961 is formed on a plate 962 which is mounted on the top of the link 195, as shown in Figs. 68 and 69. The detent tooth 961 projects to the left from the plate 962 in a position somewhat forwardly of the link 195, and the form of the detent arm 961 is such that when the link 195 is in its left-hand position as shown in Fig. 68, the detent arm 961 is positioned forwardly of the arm 948'. Thus the detent arm 948' acts in such an instance to prevent clockwise rocking movement of the sensing carrier 915 from the position shown in Figs. 69 and 72. When the link 195 is shifted to the right from the position shown in Fig. 70 to the position shown in Fig. 70A, the detent arm 961 is withdrawn to the right out of the path of the arm 948'. Thus when the link 195 is in its right-hand position of Fig. 70A, the sensing carrier 915 is free to move through a sensing stroke, while the positioning of the link 195 in its left-hand position of Figs. 68 and 70 causes the detent arm 961 to maintain the sensing carrier in its retracted position, thereby to prevent movement of the sensing carrier through a sensing stroke.

Since the link 195 remains in its left-hand position during the movement of the carrier bars 163 in a left-hand direction, the receding or cut-away portion of the cam plate 946 passes freely over the follower 948 while the detent arm 961 maintains the sensing carrier 915 in its retracted position of Fig. 72, and the follower 948 is again engaged with the dwell surface 952, as shown in Fig. 70.

From the foregoing it will be clear that while the carrier bars 163 are moving through their right-hand or conditioning stroke, the sensing carrier 915 moves through its sensing stroke and any sensing member 922 which is actuated in such sensing stroke is latched in its actuated position when the sensing carrier is returned to its retracted position at the end of the conditioning stroke of the carrier bars 163. This latched relationship, of the actuated sensing member 922 is maintained while the printing device which has thus been sensed at station IV, is advanced from station IV to station IV-T, and the visual selection apparatus of the present invention is arranged so that the sensed indication determined by the actuated one of the sensing members 922 causes the proper one of the indicating lamps 902 to be lighted and to be maintained in its lighted condition so long as the printing device from which such indication was derived remains at station IV-T. In addition, the visual selector mechanism of the present invention is arranged so as to be dominated by the selector mechanism 670, thereby to cause lighting of the signal lamps 902 only when the printing device which is being advanced into station IV-T is one from which a printing operation is to be performed. To this end the selector mechanism 670 is controlled through the use of intermediate length or bell pins 525A-2, and such a pin 525A-2 is mounted in the pin holder 526 in each selected identifying position so that whenever a printing device bearing a tab 120A in a corresponding identifying position is moved into sensing position, the engagement of a sensing pin 525A-2 with such a tab 120A will cause the cor-

responding storage plunger 672 to be set in position 3. The control plunger 866 is set in its print tab position so that the control lever 770 is aligned with position 1, or in other words, the control lever 770 is in such a setting of the machine arranged to be actuated by the cam lobe 776 of any storage plunger 672 which is set in position 1. With this setting of the machine a sensing operation performed by the sensing head 500 on a printing device which does not bear a tab 120A at one of the selected identifying positions, results in setting of the storage plunger 672 in position 1, and as a result this storage plunger will actuate the control lever 770 and cause the related printing device to be skipped.

When, however, the sensing operation of the sensing head 500 detects the presence of a tab 120A in a selected identifying position, the storage plunger is set in position 3, as shown in Fig. 52 of the drawings, and when this storage plunger reaches the upper or control position, it actuates the control lever 766. When the control lever 766 is thus actuated, it engages the pin 837 on the latch member 830, thereby to rock the latch member 830 in a counterclockwise direction to its released position of Fig. 59, and this releasing movement of the latch member 830 is utilized to cause closure of the conditioning switch 907 whenever a printing device from which a printing operation is to be performed is being advanced into station IV-T. For this purpose the latch member 830 is constructed in a special form whenever a visual selector mechanism is to be employed, and such special formation of the latch member 830 is illustrated in Figs. 67, 74 and 75 of the drawings wherein the latch member is identified by the reference numeral 830'. In the present instance the latch member 830' has an upwardly projecting portion 970 upon which a laterally projecting ear 871 is formed. An adjustable plunger in the form of a screw 972 is mounted on the ear 871 so that when the latch member 830' is rocked from its latched position of Fig. 74 to its released position of Fig. 59, the end of the screw 972 moves into operative engagement with the switch 907 so as to close the switch 907, the switch 907 being mounted relatively close to the latch member 830', as shown in Fig. 74. This release movement of the latch member 830' also functions to produce closure of another switch, but since this second switch is not essential to the operation of the visual signalling means in all instances, the description of the visual signalling means and its operation will be completed before the relationship of the second switch means is described.

When one of the sensing members 922 has sensed a tab 120 at a particular identifying position on a printing device at station IV, and the switch 907 has been closed by the release movement of the latch member 830', the appropriate or related signal lamp 902 is lighted and this signal lamp is maintained lighted until the next cycle of operation of the machine has been initiated. This action is accomplished through utilization of the movement of the link 195, such movement of the link 195 being arranged to unlatch the sensing member which has been maintained in its actuated position of Fig. 73 by the associated latching collar 935. To this end the shaft 917 is mounted for rocking movement and in such rocking movement is arranged to impart a clockwise or releasing movement to any one of the latching collars 935 which may be in its

active or latching relation. Thus, as shown in Figs. 68, 72 and 73, each latching collar 935 has an arcuate slot 976 formed therein and a pin 977 is provided on the shaft 917 so as to project into the slot 976. Thus when a clockwise rocking movement is imparted to the shaft 917, the pin 977 engages one end of the slot 976 and imparts a corresponding rocking movement to the latching collar 935 so as to move the same to the released position of Fig. 72.

In some instances it may be desirable to adjust the several sensing means 922 to different positions along the mounting shaft 923, and in such an instance the use of pins 977 and slots 976 to impart releasing movement to the latching collars 935 would be difficult to adjust or change, and in such an instance an actuating ball 918 may be fixed to the shaft 917 so as to overlie the arms 937 of the latching collars 935. In such an instance the pin and slot arrangement 976 and 977 would be eliminated.

For the purpose of imparting the desired releasing movement to the shaft 917 an arm 980 is provided on the right-hand end of the shaft so as to project forwardly therefrom, and means is provided to engage the arm 980 when the link 195 moves to the right, thereby to raise the forward end of the arm 980 and impart a rocking movement to the shaft 917 in a clockwise direction, as viewed in Fig. 73. The means for actuating the arm 980 in the present instance comprises a pawl 981 pivoted at 982 on an upstanding flange 983 formed on the forward edge of the plate 962. The pawl 981 is maintained in the position shown in Figs. 70 and 70A by means of a spring 984 which acts between a forwardly projecting ear 985 on the pawl 981 and an anchoring post 986 which projects forwardly from the upturned flange 983. It will be observed that the pawl 981 is located on the rear face of the upturned flange 983 so that the ear 985 acts as a stop against the left-hand edge of the upturned flange 983, thereby to cause the pawl 981 to assume the position shown in Figs. 70 and 70A. It will be noted that the mounting shaft 917 is maintained in the position shown in Fig. 69 by means of a spring 987 which acts between a downwardly extending arm 988 formed as a part of the arm 980 and an anchoring pin 989 which extends to the right from the mounting bar 919. Such movement of the shaft 917 is limited by engagement of a tooth 980' formed on the arm 980 with a laterally projecting stop pin 990 which is mounted on the bar 919, as shown in Figs. 69, 70 and 70A.

When the sensing carrier 915 has moved through a sensing stroke and a sensing member 922 has been latched in its actuated position, the link 195 is in its right-hand position shown in Fig. 78 and prior to the return or left-hand movement of the carrier bars 163 and the cam plate 946, the link 195 is returned to the left to the position shown in Fig. 70. In such movement, however, it is to be noted that a releasing or rocking movement is not imparted to the shaft 917 because of the form of the pawl 981 and the particular manner in which it is mounted and related to the arm 980. Thus it will be observed that the pawl has a face 991 on its left-hand side which in the normal position of the pawl 981 is located in a vertical position. Thus when the link 195 moves to the left from the position shown in Fig. 70A to the position of Fig. 70, the face 991 engages the adjacent or right-hand side of the lever arm 980 so that the pawl 981 is

5 pivoted in a clockwise direction about its pivot 982 and against the yielding action of its spring 984. Thus the pawl 981 passes beneath the arm 980 without actuating the arm 980 in an upward direction. When the pawl 981 reaches the position shown in Fig. 70, a sloping cam face 992 formed on the upper right-hand portion of the pawl 981 faces the arm 980. Hence when the link 195 is moved to the right in the first portion 10 of the next cycle of operation of the machine, the cam surface 992 will impart the desired rocking movement to the shaft 917 and will cause unlatching movement of all of the latching collars 935.

15 It will thus be seen that the switches 911 will be returned to their open position early in the cycle of operation in which the related printing device is being advanced from the transfer station IV-T to the printing station V and at substantially this same time the conditioning switch 907 is allowed to assume its open position, for it is at this time that indexing movement of the storage drum 671 releases the control lever 766 so as to permit the latch 830' to return to its normal or active position. Thus the visual signal which has been rendered effective in the cycle of operation in which the related printing device has been advanced to the transfer station IV-T is maintained in its effective condition 20 until the machine is again operated, such succeeding operation being the one in which the operator positions the proper instrument or form at printing position and produces a printing impression on such form from the printing device 25 to which the visual signal relates. The visual signal is then rendered ineffective and the apparatus is conditioned for set-up in accordance with the selection pertaining to another printing device.

30 35 40 In the use of a visual selector of the character shown in Figs. 66 to 75, it has been found that a relatively small number or percentage of the printing devices contained in a series are printed, and it is, of course, possible for an operator to 45 control the machine by means of a consecutive foot pedal 322, and it will be recognized that such control may in many instances be employed, but where the visual selector is to be employed I prefer to utilize an auto-stop mechanism such 50 as that shown in my co-pending application Serial No. 388,998. In such an auto-stop mechanism a control element such as a plunger 1000 may be provided on the front panel 207 of the machine and mechanism may be provided under 55 the control of the auto-stop plunger 1000 to cause continuous operation of the machine which is terminated only upon the sensing of a condition in the machine which indicates that the machine should be stopped. Such auto-stop 60 mechanism is described in detail in my aforesaid co-pending application Serial No. 388,998, and reference may be had to said application for details of construction. I have, however, illustrated in Fig. 67 of the drawings, certain of the 65 operative elements and circuit connections of this auto-stop mechanism in so far as these details enter into the association of the auto-stop mechanism with the visual selector of the present invention. It may be observed that when 70 the plunger 1000 is withdrawn outwardly of the panel 207, a mechanical means is rendered effective to actuate the control shaft 328 in a manner which corresponds to the actuation thereof by the consecutive foot pedal 322, and the shaft 328 75 is maintained in its actuated position so long as

the auto-stop plunger is maintained in its withdrawn position. Thus the machine operates continuously under such circumstances and such continuous operation is interrupted by energization of a solenoid 1001 which, as disclosed in my aforesaid co-pending application Serial No. 388,998, operates to return the auto-stop plunger to its inward position, thereby to permit return of the control shaft 329 to its inactive or normal position.

The solenoid 1001 may be energized by any one of a variety of detecting means, and for this purpose one side of the solenoid 1001 is connected by means of wires 1002 and 1003 and a conditioning switch 1004 to one side of the line at a point between the motor 205 and the motor switch 206. The other side of the line is connected by means of a wire 1005 to one side of a suitable switch means which is governed by the detecting means which are to cause energization of the solenoid 1001, and the other side of such switch means is connected to the other terminal of the solenoid 1001 by means of a wire 1006. As hereinbefore pointed out the solenoid 1001 may be energized under the control of a variety of detecting means. Thus I have shown a detecting finger 1007 which, as disclosed in my aforesaid co-pending application Serial No. 388,998, is operable to detect the feeding of the last printing device from the magazine M, and the detecting finger 1007 is operatively associated with the switch 1008 which has its contacts connected to the wires 1005 and 1006. A plug connector 1009 is connected by wires 1010 and 1011 across the wires 1005 and 1006 in parallel relationship to the switch 1008 so that other detecting means may be associated with the auto-stop mechanism.

Through the use of the auto-stop mechanism as described, the visual selector of the present invention is arranged to cause the printing machine to be stopped whenever the operation of the selector mechanism 670 has indicated that a particular printing device which is being advanced into the transfer station IV—T is one from which a printing operation is to be performed. To this end a switch 1012 is connected by means of wires 1013 and 1014 across the wires 1005 and 1006 in parallel with the switch 1008, and the switch 1012 is arranged for closure by the adjustable screw 972 when the latch 830' moves to its release position.

In the present instance the two switches 907 and 1012 are arranged in a common assembly mounted within the housing 1015 which is supported by means of a bracket 1016 mounted on the upper edge of the mounting plate 620. As shown in Fig. 74 of the drawings, the two switches 907 and 1012 are of the normally closed spring type mounted in position within the housing 1015 by means of a plurality of insulating blocks 1017 and a mounting bolt 1018. The adjacent spring contacts of the two switches are separated by means of a relatively rigid insulating leaf 1019 while the outer spring terminals of the two switches have flexible insulating plates 1020 and 1021 arranged along their outer faces. The screw 972 in an actuating movement of the latch 830' engages the insulating plate 1020 so as to impart closing movement to the adjacent spring contact of the switch 1012, and in such movement a similar closing action is imparted to the switch 907 by an insulating block 1022 which is positioned between the projecting end of the

actuated spring contact of the switch 1012 and the projecting end of the adjacent spring contact of the switch 907.

Thus it will be apparent that when the operation of the selector mechanism 670 indicates that a particular printing device is to have a printing operation performed therefrom when it reaches printing position, the action of the storage mechanism in releasing the latch 830' as this particular printing device is being advanced from station IV to transfer station IV—T will cause closure of the switch 1012 so as to energize the solenoid 1001 of the auto-stop mechanism, thereby to stop the machine with the particular printing device in position at the transfer station IV—T. Simultaneously the visual indicator will exhibit a visual signal which will inform the operator as to what type of business instrument or form is to be placed in the machine in the next operation thereof. After selecting the indicated form and placing it at printing position, the operator again withdraws the auto-stop plunger 1001. As a result a printing operation will be performed from the selected printing device, and the machine will operate continuously so long as the succeeding printing devices are indicated by the selector mechanism 670 as being printing devices which should be skipped. The machine will, of course, be automatically stopped as aforesaid when a printing device from which a printing operation is to be performed is advanced to the transfer station IV—T.

It will be observed that the sensing members 922 of the visual selector shown in Figs. 66 to 75 are so constructed and mounted that an appreciable lateral spacing is required therebetween and with this form of detecting means it is customary to employ full-width or unnotched tabs 120A to indicate the type of form which is to be printed from each printing device. In some instances, however, it may be desirable to provide a visual selector having a greater range of adaptability as for example when half-width or notched tabs 120A are to be employed to indicate the type of form to be printed, and for such use a modified form of visual selector is disclosed in Figs. 76 to 78 of the drawings. In this modified form a generally similar sensing carrier 915 is similarly mounted on a shaft 917 carried in similar mounting bars 918 and 919, and the sensing carrier 915 is actuated and controlled by a cam plate 946 constructed and mounted in the same manner as in the other form of visual selector. The primary difference between the first described visual selector and the one shown in Figs. 76 to 78 resides in the manner of actuating the selector switches and the manner of latching and unlatching these switches. Thus the visual selector of Figs. 76 to 78 has twenty-four normally open spring-type selector switches 1025 mounted beneath the sensing carrier 915 in much the same manner as the switches 911 were mounted in the other embodiment. On the forward edge of the sensing carrier 915 a mounting block 1026 is secured, this block having spaced upper and lower mounting flanges 1027 and 1028 formed along its forward edge so as to project forwardly over the projecting forward ends of the switches 1025. In the mounting flanges 1026 and 1027 a plurality of sensing elements or sensing pins 1029 are mounted, one for each of the switches 1025. The sensing pins 1029 are slidably mounted in aligned openings 75 formed in the upper and lower mounting flanges

1027 and 1028, and between the two flanges each pin has a collar 1030 formed thereon. Below the collar 1030 an expansive coil spring 1031 surrounds each sensing pin 1029 so as to normally urge the sensing pin upwardly and force the collar 1030 into abutment with the lower surface of the upper mounting flange 1027. When the sensing pin is in its upper position as thus defined, the lower end of the sensing pin is in spaced relation to the associated switch 1025 so that the switch is in its open position. The upper ends of the sensing pins 1029 project into a suitable slot 1032 formed in the upper flange structure of the girder 161. Thus when the sensing carrier 915 is rocked through a sensing stroke the pins 1029 are moved upwardly, and any sensing pin which encounters a tab 120A will be restrained against further movement thereby to cause closing of the associated switch 1025, as shown in Fig. 78 of the drawings.

In this embodiment of the invention means is also provided for latching any one of the sensing pins 1029 in its actuated condition after it has sensed the presence of a tab 120A. In the present instance this latching means comprises a plurality of latching plungers 1035, one such latching plunger being provided for each of the sensing pins 1029. Each latching plunger is mounted in a bore 1036 formed in the mounting block 1026 at right angles to the associated sensing pin, and at its forward end each latching plunger 1035 has a head 1037. This head is located immediately below the upper mounting flange 1027 and at its forward end the head 1037 has a relatively thin latching finger 1038 which is adapted to be moved into the space between the mounting flange 1027 and the collar 1030 when the sensing pin 1029 is actuated. The latching plunger 1035 is urged forwardly toward a latching relationship with respect to the sensing pin by means of an expansive coil spring 1039 which surrounds the plunger rearwardly of the head 1037 and acts between the head and the body of the mounting block 1026. In the present instance the forward edge of the latching finger 1038 is arcuate in form and normally rests against the periphery of the collar 1030 as shown in Fig. 77. When the sensing pin 1029 is actuated in a downward direction with respect to the mounting flanges 1027 and 1028, the spring 1039 forces the latching finger 1038 into the space between the collar 1030 and the mounting flange 1027. Thus when the sensing carrier 915 is withdrawn in a downward direction, any sensing pin 1029 which has been actuated is maintained in its actuated or switch closing position by the action of its associated latching plunger 1035.

The latched relationship of the sensing pin 1029 is maintained until the initiation of the succeeding cycle of operation of the machine in the same manner or with the same timing action as in the other embodiment of the visual selector mechanism, and is released through rocking movement of the shaft 917 which is accomplished by the same mechanism as in the other embodiment. Rocking movement of the shaft 917 is rendered effective to release the latching plungers 1035 through the medium of a bail 1040 which has the rear ends of the several latching plungers 1035 projecting slidably through apertures formed in the cross member of the bail. Rearwardly of the cross member of the bail each

5 plunger has a pin 1041 mounted transversely therein so that by rearward movement of the bail, all or any one of the latching plungers 1035 may be withdrawn rearwardly to released position. The bail 1040 has the rear ends of its arms pivoted at 1041 to lever arms 1042 which are fixed on the shaft 917. The pivots 1041 are located above the axis of the shaft 917 so that when rocking movement is imparted to the shaft 917 by the pawl 981 the bail 1040 is actuated through a latch-releasing movement.

10 The several switches 1025 may, of course, be selectively connected to the indicating lamps of a relatively small signal panel such as that shown in Fig. 66, or a large signal board may be provided and the various switches 1025 may be connected permanently to the various lamps of such a large signal panel. It will also be evident that in some instances a relatively small number of switches 1025 and sensing pins 1029 may be employed.

Operation

15 In the use of the machine of the present invention as disclosed in Figs. 1 to 65, the required conditioning or set up operations are determined in part by the character of the identifying means or tabs which are employed upon the printing devices D which are to be passed through the machine, for as has been hereinbefore pointed out, these tabs have varying characteristics which determine the kind of sensing pins 525 which must be used. The conditioning or setting up operations which must be performed are also influenced by the nature of the classification system which is used on the printing devices, and by the nature of the selection problem which is to be performed by the machine.

20 Assuming for purposes of illustration that the printing devices D have been classified through the use of notched tabs 120A and 125A, the sensing bar 526, Figs. 22 and 35, will be set up with sensing pins 525A in appropriate locations which are determined by the selection problem 25 which has been presented. Assuming that this selection problem, under the classification system employed on the printing devices, may best be performed through the use of "skip tab" operation of the machine, a regular length pin 525A-1 is mounted in the sensing bar 526 opposite those tab positions which are to be skipped, and it will be recognized that one or more such regular length pins may be so mounted in the sensing bar. Assuming further that with 30 respect to printing devices bearing tabs at another selected position it is desired to call such printing devices to the attention of the operator as they pass through the machine, a pin 525A-2 of intermediate length is placed in the sensing bar 526 opposite such predetermined identifying position. The sensing bar 526 is then mounted in position on the sensing head 500 and is secured in place by the latch member 545, Fig. 31. Where such warning of the operator in respect 35 to certain printing devices is desired, the bell mechanism of the selector device is rendered active by release of the latch 624, Fig. 35, this being accomplished by forward withdrawal of the control plunger 620 which is disposed in the forward control panel 201 of the machine. The selector mechanism as a whole is also rendered operative by release of the latch 644, Fig. 35. This is accomplished by withdrawal of the selector control plunger 640 in the forward control 40 panel of the machine. Since the assumed se-

lection problem is to be performed through "skip tab" operation of the machine, the control plunger 866 in the forward control panel of the machine is positioned in its inner or "skip tab" position shown in Fig. 48 of the drawings, and this results in positioning of the control lever 770 opposite the number 2 position of the storage plungers 672, as illustrated in Fig. 51 of the drawings.

The machine is then loaded by placing a supply of printing devices D in the magazine M, and the motor of the machine is started through withdrawal of the motor switch control plunger 208. The drawer from which the printing devices D have been removed is then placed in position on the drawer carrier 181, Fig. 10, to serve as a collector K to receive the printing devices after they have been passed through the machine. It will be assumed that the machine is to be operated to make but one impression from each printing device which is selected for printing, and therefore the multiprint control plunger 420 will be positioned in its inner position which assures such operation of the machine.

The machine is then operated through a series of what may be termed "idle operations" or cycles in order that the first or lowermost of the printing devices D in the magazine M may be advanced to station IV-T, Fig. 6, it being recalled that after a printing device has been so positioned at station IV-T the machine may then be operated through a printing cycle to produce an impression from this printing device. Such idle or conditioning cycles are instituted through successive actuations of the skip pedal 320 which is operable to cause operation of the printing device advancing means while the platen mechanism P remains inactive.

In the first such idle cycle of the machine the lowermost printing device D in the magazine M is advanced from station I, shown in Fig. 6 of the drawings, to station II. Such advancing movement takes place in the first half of the machine cycle, and at the end of this forward or advancing movement, the printing device comes to rest with its forward edge in engagement with the stop finger 194, and soon thereafter, the positioning pawl 190 is moved into engagement with the positioning notch 193 in the adjacent end edge of the printing device. This serves to accurately locate the printing device at station II, which station constitutes the sensing position of the machine. In the second half of the aforesaid cycle of operation of the machine, the sensing head 500 is moved downwardly through the sensing stroke. This movement is governed by the cam 385, Fig. 36, and takes place when the receding surface 636 moves past the associated cam roller 601. The cam roller 601 is associated with the selector actuating shaft 608 which extends along the back of the machine, and the cam roller is urged toward engagement with the cam 385 by the spring 611. When the shaft 608 is thus moved yieldingly through a rocking movement in a counterclockwise direction, Fig. 35, the link 616 and the rocker 617 operate to move the sensing head 500 downwardly through its sensing stroke. This sensing stroke is thus yieldingly induced, and when one of the sensing pins 525A-1 or 525A-2 encounters a tab on the printing device which is located at the sensing station, the downward movement of the sensing head 500 is limited and stopped at a level which is determined by the length of the pin which has thus engaged a tab.

When none of the sensing pins encounters a tab, the sensing head 500 descends to its lowest level which has been identified as level 1.

Thus the cam 737, Fig. 31, is positioned at 5 different levels in accordance with the degree of downward movement of the sensing head 500, and the position of the cam 737 operates to control the extent of movement of the set up arm 721, Fig. 43. The set up arm 721 is operable to 10 actuate the storage plungers 672 of the storage drum 671, and when the set up arm 721 is actuated, it is effective upon the storage plunger 672 which is then located in the lowermost or set up position of the storage drum. This position 15 is indicated in Fig. 35 as position II. Thus the storage plunger at position II in Fig. 35 is related to the printing device D which is located at the sensing position in Fig. 6, and the setting of this storage plunger 672 is determined by the 20 identifying means carried on the printing device which is located at the station II.

In the next or second idle cycle of operation of the machine, the printing device advancing means will operate to advance the first printing 25 device to station II-T, and at the same time and during the first one half of the machine cycle, a second printing device D will be advanced from station I to station II. Thus, at the end of the first half of the second idle cycle the first printing device will be located at station II-T, as shown in Fig. 8 of the drawings, while the second printing device will be located at sensing station II. During such forward or advancing movement of the two printing devices, the pawl 190 will be shifted to its withdrawn position shown in Fig. 7 of the drawings, thereby to allow the desired advancing movement of the first printing device, and the positioning pawl 190 will be returned to its active position after the 30 first printing device has passed the stop lug 194. Such return movement of the pawl 190 takes place in such a manner that the stop pawl 194 is first moved into the guideway to serve as a preliminary stopping and locating means, and the pawl 190 is thereafter moved so as to shift the positioning tooth 192 into engagement with the notch 193 of the second printing device.

In the course of such advancing movement of 35 the first and second printing devices, the storage drum 671 is indexed through a sixty degree movement in a clockwise direction, as viewed in Fig. 35 of the drawings, such advancing or indexing movement being induced by the pawl 678 and the ratchet 676 which, as shown in Fig. 42, are operated by the printing device advancing arm 156. Thus when the second printing device has come to rest at station II, a new or different storage plunger 672 will be located at position 40 II of the storage drum, and the storage plunger which has been set up in accordance with the identifying means of the first printing device will be located in position III of the storage drum, as indicated in Fig. 35 of the drawings. It will be observed that at the end first half 45 of this second conditioning cycle of operation of the machine, the first printing device will be located at station II-T as shown in Fig. 8, but during the second half of the machine cycle, the first printing device will be advanced to the left as viewed in Fig. 6 so that at the end of the cycle, the first printing device will be located at station III. Thus at the end of the second idle cycle the location of the first printing device in the printing device guideway corre-

sponds with the location of the related storage plunger on the storage drum 671.

In the last half of the second idle cycle the sensing head 500 is lowered in the same manner as in the first idle cycle, and the set up arm 721 is operated to set up the storage plunger 672 at position II of the storage drum to a position which is determined by the identifying means of the second printing device.

In the next or third idle cycle of the machine, the second printing device is advanced to station II-T in the manner just described with relation to the first printing device, such advancing movement of the second printing device taking place in the first half of the machine cycle, and in the last half of the machine cycle, the first printing device is advanced to station IV of the printing device guideway and the second printing device is advanced to station III. In the first half of this machine cycle, and at the time when the second printing device is being advanced forwardly from station II, a third printing device is withdrawn from the bottom of the magazine M and is advanced into sensing station II, thereby to be located in the proper position for operation of the sensing means. The storage drum 671 is of course indexed through another sixty degrees during the first half of the machine cycle, thereby to locate still another storage plunger 672 at position II of the storage drum. Hence when the sensing head 500 is operated in the last half of the machine cycle, the set up lever 721 operates to set this lower storage plunger 672 in a longitudinal position which is determined by the identifying means of the third printing device. Thus at the end of the third idle cycle, the first printing device is located in station IV of the printing device guideway and the related storage plunger 672 is located at position IV on the storage drum; the second printing device is located at station III of the printing device guideway and the related storage plunger is located at position III of the storage drum; while the third printing device is located at station II of the printing device guideway and the related storage plunger is located at position II on the storage drum.

In the fourth or last idle cycle of the machine, the third printing device is advanced from station II to station II-T during the first half of the cycle, and at this same time the fourth printing device is advanced from the magazine M to station II. The storage drum 671 is also indexed during the first half of the machine cycle so as to locate still another storage plunger at position II on the storage drum, and during the last half of the cycle the printing device advancing means in the transverse portion of the guideway operate to advance the first printing device into station IV-T, the second printing device into station IV and the third printing device into station II. While such advancing movement is taking place in the transverse portion of the printing device guideway, the sensing head 500 is operated through its sensing stroke, thereby to set up the lowermost storage plunger 672 in a position which is determined by the identifying means carried on the fourth printing device. Thus at the end of the fourth idle cycle, the first printing device is located at station IV-T and the related storage plunger is located at position IV-T on the storage drum; the second printing device is located at station IV and the related storage plunger is located at position IV on the storage drum; the third printing device is located at station III

and the related storage plunger is located at position III on the storage drum; while the fourth printing device is located at station II and the related storage plunger is located at position II on the storage drum.

It will be assumed that the identifying means carried by the first printing device were such that the downward sensing stroke of the sensing head 500 was terminated by engagement of a regular length sensing pin 525A-1 with a tab, and hence the storage plunger 672 which is related to this first printing device will have been set in position 2 so that its cam lobe is aligned with the lower end of the control lever 770. Thus, as the storage plunger 672 which is related to the first of the printing devices is moved into position IV-T of the storage drum, the cam lobe of the storage plunger will engage the lower end of the control lever 770 to shift this control lever in a counterclockwise direction to the position shown in Fig. 65 of the drawings. Hence the spring 791 will be compressed, and will serve to draw the link 785 to the left as viewed in Fig. 35. This imparts a rotative or rocking movement to the control shaft 783 which extends along the back of the machine, such rocking movement being in a counterclockwise direction as viewed in Fig. 36. In such a rocking control movement, the arm 782 on the shaft 783 acts through the link 781 to rock the supplemental stop lever 780 of the platen clutch 252 to its active position. At the end of the cycle in which the supplemental stop lever 780 is thus rendered active, the cam lobe of the storage plunger which has caused such operation comes to rest in the position shown in Fig. 65, and hence the supplemental stop lever 780 will remain in its active position until the next cycle of operation of the machine has been initiated. This next cycle of machine operation may be instituted by actuation of the consecutive foot pedal 322, and in a normal machine cycle the first printing device would be advanced to printing station V in the first half of the machine cycle, and in the last half of the cycle the platen mechanism P would operate to produce an impression from this printing device. With respect to the aforesaid first printing device, however, sensing of a tab by a regular length sensing pin has caused such a setting of the related storage plunger 672 as to result in actuation of the control lever 770. Hence the supplemental stop lever 780 causes the platen clutch 252 to be held in its disengaged position, despite the fact that the normal stop lever 276 of this clutch has been released due to actuation of the consecutive foot pedal 322. Thus, with respect to the aforesaid first printing device, the machine will be operated through a skip cycle, and although the printing device is advanced to printing station V, the platen mechanism P will remain inactive and an impression will not be made from this printing device.

Assuming that the second of the aforesaid printing devices is one from which an impression is to be made, the sensing head 500 will have descended to its lowest level, this being due to the absence of tabs 120A in the path of the sensing pins, and such operation of the sensing head has therefore caused the related storage plunger 672 to be set in position 1, as shown in Fig. 50 of the drawings. Thus when the storage plunger which is related to the second of the aforesaid printing devices is moved into position IV-T on the storage drum, the cam lobe of the storage plunger will move freely past the side of the control lever 770. When this occurs, it will be recognized that

in the same cycle of machine operation, the second printing device will be moved into station IV—T of the printing device guideway so that it will be moved into printing station V in the next cycle of machine operation. When the second printing device is thus located, it will be apparent that the related storage plunger will be disposed in the relation shown in Fig. 64, and the control lever 770 will be disposed in its normal position so that the supplemental stop lever 780 will be in its inactive position as shown in Fig. 36. It will therefore be clear that when the next cycle of machine operation is instituted, the platen clutch 252 will be engaged in its normal manner, and as a result, the platen clutch will be connected so as to operate the platen mechanism P through an operative cycle to thereby produce a printed impression from the second printing device after it has moved into printing station V.

It will be assumed that the third printing device is one which bears a tab 120A in such a position that this tab has been engaged by an intermediate length pin 525A—2, and because of this, the related storage plunger will have been set to position III wherein it is aligned with the control lever 766, as shown in Fig. 52 of the drawings. Thus, in the cycle when the third printing device is moved from station IV into station IV—T, the related storage plunger 672 will cooperate with the control lever 766 to cause operation of the signal or bell. The indexing movement of the storage drum 671 occurs, of course, in the first half of the machine cycle, and in this indexing movement, the cam lobe of the related storage plunger engages and actuates the control lever 766 to the position shown in Fig. 61. Such counterclockwise rocking movement of the control lever 766 does not, however, cause immediate sounding of a bell 810 but merely acts through the pin 837 to release the first bell control latch 830. In such release of the latch 830, the latch surface 833 is withdrawn from its effective position beneath the ear 834 of the bell sounding rocker 813. Such release of the latch member 830 does not fully release the rocker 813, for the timing latch 841 still has its shoulder 842 disposed over the ear 827 of the bell sounding rocker 813. The bell sounding rocker 813 is thereby conditioned for operation upon release of the timing latch 841, and this is accomplished by the rocker 618 in the last half of the machine cycle. As will be evident from a comparison of Figs. 58 and 59, the rocker 618 becomes effective upon a pin 843 of a timing latch 841 to release this latch as shown in Fig. 59, and the rocker 813 is thus released to the action of its actuating spring 816. This causes the striker 811 to sound the bell 810. The bell sounding mechanism is restored by the rocker 618 as this rocker returns in a counterclockwise direction to the position of Fig. 58, the arm 845 of the rocker 618 being effective on the pin 815 to rock the rocker 813 in a clockwise direction from the position shown in Fig. 59 to substantially the position shown in Fig. 58. The spring 816 then causes the latch 841 to return to its normal position of Fig. 58, and in the first portion of the next machine cycle, in which the cam lobe will pass from beneath the control lever 766, the spring 831 will act to draw the shoulder 833 of the latch 830 to a position beneath the ear 834, thereby to condition the signal or bell mechanism for operation by the next storage plunger in the event such plunger is properly set.

It will be recognized that an operator may not

desire to utilize the signal afforded by the bell 810, and if this is the case, the operator may push the control plunger 820 inwardly to thereby render the disabling latch 824 effective. If this is done, the intermediate length pins 525A—2 will have the same controlling effect as the regular length pins, and if desired such regular length pins may be substituted for the intermediate length pins.

10 In the foregoing description of the operation of the machine shown in Figs. 1 to 65 of the drawings, it has been assumed that the machine has been set for producing but one impression from each printing device, but in certain instances it may be desirable to produce two or more impressions from each printing device which is selected for printing, and when this situation arises, the multiprint control plunger 420 is withdrawn to its multiprint position.

15 Such withdrawal of the multiprint plunger 420 shifts the shroud plate 450 to such a position that the pin 443 may engage the ratchet wheel of the multiprint cam 433, thereby to enable this cam to be indexed in each operation of the platen mechanism. The number of impressions made from each selected printing device is governed by the form of the cam 433 and this cam as shown in Fig. 39 is of such a form that two impressions are made from each selected printing device. 20 When the multiprint mechanism is thus rendered operative the cam roller 432 is located in a recess 438 of the cam 433, and it occupies this position when a printing device is located in station IV—T. When such a printing device is advanced 25 from station IV—T into printing position, the cam 433 is indexed so as to bring one of the cam lobes 440 into engagement with the roller 432, thereby to rock the control rocker 421 in a counterclockwise direction as viewed in Fig. 39. In 30 the cycle when this occurs the platen mechanism P will operate to produce a first impression from the printing device which has thus been advanced to printing position, and by virtue of the aforesaid counterclockwise rocking movement of the control rocker 421, the supplemental stop lever 425, Fig. 10, will be moved to its active position, thereby to render the printing device advancing clutch 251 inoperative in the 35 next cycle of machine operation. Hence in this 40 next cycle, the same printing device will remain at printing position, and a second impression will be made therefrom. It will thus be clear that the multiprint mechanism operates to dominate the normal control means of the printing device 45 advancing clutch 251 so as to maintain the printing device advancing means inoperative when it is desired to maintain a printing device at printing position for more than one cycle.

45 The multiprint means also dominates the selector mechanism, and as will be evident in Fig. 39, the control rocker 421, when actuated in a counterclockwise direction, moves the link 796 in a downward direction so that the upper end of its slot 798 engages the pin 799 on the arm 800. Hence the shaft 783 is held against actuation by the link 785, Fig. 35, and in the event that the control lever 770 is actuated, it serves merely to compress the spring 791. Hence in the cycle when the supplemental stop lever 425 of the printing device advancing clutch 251 is moved to its active position, the control shaft 783 cannot be operated by the control lever 770, even though the control lever 770 is actuated. Hence the supplemental stop lever 780 of the platen 50 clutch 252 must remain in its inactive position.

As a result of this dominating action of the multiprint mechanism, the platen mechanism is operative in the second machine cycle in which a printing device remains at printing position, and in this second cycle, the cam 433 is again advanced so as to bring another recess 438 into alignment with the cam roller 432. Thus, in this cycle of operation the control rocker returns in a clockwise direction to the relationship of Fig. 39, thereby to free the control shaft 783 for rocking movement. Such rocking movement is, of course, immediately imparted to the shaft 783 by the spring 791 which has remained compressed during the cycle in which the printing device advancing means has been inactive. This result necessarily follows because the sensing drum 671 also remains stationary during such cycle. Thus the selector mechanism conforms automatically to the operation which is desired when the multiprint mechanism is rendered active, and when the multiprint mechanism is rendered inactive, the selector mechanism automatically conforms to this different set up of the machine.

If a particular selection problem indicates that the machine may be more expeditiously operated under what has been called "print tab" operation, the control plunger 866 is withdrawn so as to expose the print tab legend 876, and this locates the control lever 770 opposite position 1 of the storage plungers as shown in Fig. 54 of the drawings. When this arrangement is used with printing devices bearing notched tabs 120A, the sensing bar 526A is set up with pins 525A. Regular length pins 525A-1 are mounted in the sensing bar opposite those tab positions which indicate printing devices which are to be printed, and long pins 525A-3 are mounted in positions opposite those tab positions which indicate printing devices which are to be skipped even though the presence of other tabs may indicate that impressions should be made from such printing devices. Sensing pins of intermediate length are mounted in those positions with respect to which it is desired to have the signal bell sounded so as to notify the operator of the presence of such printing devices.

When the sensing bar is thus set up, the operation of the regular length pins 525A-1 in limiting the downward movement of the sensing head will cause the storage plunger to be set up in such a position that the cam lobe thereof will be ineffective to actuate any of the control levers and will pass between the control levers 766 and 770 as shown in Fig. 54. Thus, in such instances the machine will operate through a normal printing cycle to produce a printed impression from the related printing device. In the event that the long pin 525A-3 engages a tab on a printing device, the related storage plunger will be set to position 4, and when it reaches the upper position on the storage drum, such a storage plunger will actuate the control lever 765. Such a control lever acts through the arm 870 to actuate the control lever 770 with the result that the platen mechanism will be disabled in respect to the related printing device; and in addition the arm 80 on the lever 766 will be engaged so as to sound the bell 810.

It will be observed that when a medium length pin 525A-2 engages a tab and serves to stop the downward movement of the sensing head 500, the setup mechanism will set the related storage plunger 672 in position 3. When this storage plunger reaches position IV-T on the storage

drum, the control lever 766 will be actuated to thereby sound the bell 810 as the related printing device is moved into station IV-T of the guideway. Such actuation of the lever 766 however does not actuate the lever 770, since this lever is out of the path of the arm 871, as shown in Fig. 54. Thus a printing operation will be performed from the particular printing device when it is advanced from station IV-T to station V.

In the operation of the machine in its print tab setting, the timing of the movements of the printing devices along the printing device guideway and the timing of the related storage plungers 672 about the storage drum 671 is the same as the timing of these elements hereinbefore described in connection with the skip tab operation of the machine. It will also be observed that the dominating action of the multiprint mechanism is the same in the print tab operation of the machine as it is in the skip tab operation.

When an operator desires to effect selection through use of the signal bell only, the machine is set up with either intermediate or long pins so that when a tab is encountered by one of these pins, the related storage plunger 672 will be set to either position 3 or position 4. In addition to the foregoing, the plunger 866 is withdrawn to its outermost position so as to locate the control lever 770 in its most right hand position as viewed in Fig. 55. Thus the control lever 770 is in effect disabled. In such operation of the machine the timing of the printing devices and the storage plungers is the same as in skip tab operation of the machine, and when a printing device is being moved into station IV-T, the related storage plunger is effective through one of the control levers 765 or 766 to operate the bell 810 as hereinbefore described.

Where the printing devices D have been classified through the use of embossed tabs 120B, the selector mechanism is set up through the use of sensing pins 525B which are mounted on a sensing bar 526B in accordance with the desired selecting action. The operator must of course decide whether skip tab or print tab operation is to be used and the sensing pins are located in accordance with the type of selection operation which is to be used. In such use of the machine the timing of the printing device and the storage plungers is the same as has been hereinbefore described.

When the selector is set for skip tab operation, the sensed absence of an embossure 126 at the selected identifying positions causes the related storage plunger 672 to be set in position 1, with the result that when the storage plunger reaches position IV-T on the drum, the lobe of the storage plunger will pass by the lever 770 in the relationship shown in Fig. 50. Thus a printing impression will be made from the particular printing device when it is advanced to printing position in the next machine cycle. In the event that an embossure 126 at a selected identifying position is sensed by the sensing means, the related storage plunger will be set to position 2 and when this storage plunger reaches position IV-T on the storage drum, it will be aligned with the control lever 770 as shown in Fig. 51. Hence the lever 770 will be actuated and the operation of the platen mechanism will be suppressed with relation to this particular printing device.

The multiprint mechanism will of course exert a dominating influence upon the selector mechanism when such selector mechanism is being used in its skip tab setting to sense embossed tabs.

When embossed tabs are being used, the machine may of course be set for print tab operation, and here again the timing of the storage plungers and the printing devices is the same as hereinbefore described. In such use of the selector, the sensing pins 525B are employed and the control lever 770 is set in the position shown in Fig. 54. Thus when the sensed presence of an embossure sets the storage plunger in position 2, the lobe of the storage plunger will pass freely by the control lever 770 when the control plunger reaches station IV-T. When the sensed absence of an embossure 126 causes the storage plunger 672 to be set to position 1 the cam lobe of this plunger will of course be in alignment with the control lever 770, and when this storage plunger reaches station IV-T on the storage drum, the control lever 770 will be actuated. Because of this the operation of the platen mechanism will be suppressed as hereinbefore described in the next cycle of operation and hence the printing device will be skipped when it reaches printing position.

The multiprint mechanism acts in such print tab operation to dominate the action of the selector, thereby to produce proper operation of the machine when the multiprint mechanism is rendered operative.

The printing devices may in some instances be classified through the use of perforated tabs 120C or 120D, and the operation of the machine is the same for both of these tabs except for the use of a different bar 526.

Assuming that the machine is to be used in its skip tab setting, the sensing pins 125C of the desired lengths may be set in place in the selector bar 526. When a regular pin 125C-1 is aligned with a perforation 127 of a tab carried on a printing device at sensing station, the sensing head will come to rest at level 1 and the storage plunger at position II of the storage drum will be set to position 1, and when this storage plunger reaches position IV-T on the storage drum the cam lobe of the storage plunger will pass the control lever 770 in the relationship shown in Fig. 50. Hence the control lever 770 will not be actuated, and a printing operation will be performed in respect to the related printing device. When a regular length sensing pin 525C-1 encounters a solid or unperforated area of a tab, the sensing head 500 will come to rest at level 2. Hence the related storage plunger will be set in position 2 and when it reaches the upper position on the drum it will engage the control lever 770 as shown in Fig. 51. This actuation of the control lever 770 will cause the related printing device to be skipped when it reaches printing position.

An intermediate sensing pin 525C-2 or a long pin 525C-3 may of course serve to modify the action of the regular length pin 525C-1, but when such long pins or intermediate pins are aligned with untabbed areas of the printing device at sensing station, the regular length pin 525C-1 may exert its control action in the manner just described.

In the event that an intermediate pin 525C-2 engages a perforation 127 and is effective to stop the downward movement of the sensing head 500, the sensing head will come to rest at level 2 and the related storage plunger will be set up in position 2 as shown in Fig. 51 of the drawings. Hence the cam lobe of this plunger will actuate the control lever 770 and will cause the related printing device to be skipped. If such an intermediate length pin 525C-2 encounters a solid or unperforated area of a tab, the sensing head

comes to rest at level 3 and the storage plunger 672 is set in position 3 as shown in Fig. 52 of the drawings. Thus this storage plunger will actuate the control lever 766, thereby to sound the bell 810 and operate the control lever 770 so as to skip the related printing device.

When a long pin 525C-3 encounters a perforation 127 the sensing head comes to rest at level 3 and the related storage plunger is set in position 3. Hence this storage plunger causes the bell to be sounded and also causes the related printing device to be skipped.

When such a long pin 525C-3 encounters an unperforated area, the related storage plunger is set up in position 4 so as to actuate the lever 765 as shown in Fig. 53 when this storage plunger reaches the upper position on the storage drum. Such actuation of the lever 765 acts to operate the control levers 766 and 770 and hence the bell is sounded and the printing device is skipped.

The multiprint mechanism may of course be used in such skip tab operation of the machine with perforated tabs, and when so used it is operable to dominate the selector mechanism in the manner hereinbefore described.

When the mechanism is set for print tab operation with perforated tabs, the sensing pins 525-C may be arranged in the sensing head in the appropriate manner, and the various lengths of the pins will operate to set the storage plungers in the different positions as hereinbefore described in relation to the skip tab operation with perforated tabs. It will be observed, however, that in print tab operation of the machine, the control plunger 866 will be withdrawn to its second position so as to set the control lever 770 in the position shown in Fig. 54. Hence when a storage plunger is set in position 1, the related printing device will be skipped when it reaches printing position. When a storage plunger is set in position 2, the cam lobe of this plunger will be ineffective and the printing device will be utilized to produce a printing impression in the normal manner. When a storage plunger 672 is set in position 3, the control lever 766 will be actuated so as to sound the bell 810, but such actuation of the lever 766 will be ineffective on the control lever 770 and hence a printing operation will be performed in respect to the related printing device. When a storage plunger is set in position 4, the plunger will be effective to actuate the control lever 765 and this will cause sounding of the bell 810 and will actuate the control lever 770 to thereby cause the related printing device to be skipped.

The multiprint mechanism may of course be utilized in such print tab operation of the machine with perforated tabs, and when so used, the multiprint mechanism will exert a dominating influence over the selector mechanism as hereinbefore described.

In the use of the embodiment of the invention shown in Figs. 66 to 75, the identifying means of the printing devices are sensed twice during the passage of such printing devices through the machine. The first sensing operation takes place at the usual sensing station II, and this sensing operation is utilized to control the print-skip operation of the machine. The second sensing operation is performed at station IV of the printing device guideway, and this sensing operation is utilized to control the signal lamps 902 which are mounted on the panel 900. The arrangement is such however that these signal lamps are lighted only when a printing operation is to be performed from the printing device which

has been sensed at station IV, and moreover, the arrangement is such that the signal light which is energized under control of the sensing means at station IV is maintained energized until the cycle of machine operation has been started in which the printing impression is to be made from the related printing device.

The two related sensing mechanisms must of course be set up in accordance with the selection problem at hand, and in respect to the selector mechanism 670, this is accomplished by placing intermediate length pins 525A-2 in the selected positions in the selector bar 526A. In respect to the second selector mechanism, at station IV, the desired adjustment is effected by locating the various sensing members 922 and their related switch members in the proper longitudinal positions along the printing device guideway.

When a printing device which is to be printed is advanced to sensing station II, the sensing of a tab by the intermediate length pin causes the related storage plunger 672 to be set in position 3, and when this storage plunger reaches the upper or control position, it will serve to release or operate the bell mechanism. It will be recognized that the timing of the storage plungers 672 in their movement about the storage drum 671 and with respect to the movements of the printing devices is the same as in the previously described embodiment of the invention, and hence such release of the bell mechanism takes place in the cycle of machine operation when the related printing device is advanced from station IV to station IV-T. When the bell mechanism is thus released, the bell latch 630' acts to close the switches 907 and 1012, and it is the closure of these switches which renders the visual signal means and the autostop mechanism effective.

In the cycle of machine operation where the switches 907 and 1012 are thus closed, the related printing device is initially located at station IV. The printing device remains in this position during the first half of the machine cycle and the sensing operation at station IV is performed during this portion of the cycle. Thus it will be observed that the bar 195 is moved to the right during the first half of the machine cycle, thereby to move the lug 961 out of engagement with respect to the follower 948'. This releases the follower 948 so as to thereby permit rocking movement of the carrier 915 under the control of the cam 946. When the recessed portion 954 of the cam 946 moves into alignment with the follower 948, the carrier 915 rocks from the position shown in Fig. 72 to the position shown in Fig. 73, and if one of the sensing fingers 925 engages a tab 120, this produces relative movement between the sensing member and the carrier 915. Such relative movement causes closure of the related switch 911, and at the same time, the tooth 941 is elevated relative to the latch 939 and the latch therefore moves under this tooth so as to maintain the switch in its closed position. At the end of the right hand stroke of the cam 946, the follower 948 is rocked downwardly by the cam surface 956, and early in the last half of the cycle, the bar 195 returns to its left hand position, thereby to move the lug 961 into position in front of the follower 948'. This maintains the carrier 915 in the position shown in Fig. 72 during the time when the recessed portion 954 of the cam is passing the follower 948. During this time the latch shoulder 939 remains effective so as to maintain the switch 911 of the actuated sensing member in its closed position.

During the time when the cam 946 is being returned in a left hand direction, Fig. 70, the printing device which has just been sensed is being advanced from station IV to station IV-T, and during such movement the closure of the switches 907 and 1012 takes place. Thus the signal lamp 902 which is associated with the closed switch 911 is energized and remains energized until the next cycle of machine operation is initiated. Moreover, the closure of the switch 1012 serves to energize the auto-stop solenoid 1001 and the machine is thereby caused to stop. The operator then selects the proper form in accordance with the signal displayed on the panel 900, and then initiates further operation of the machine by withdrawal of the auto-stop plunger 1000.

In the next cycle of machine operation, the cam 981 moves from the position shown in Fig. 70 to the position shown in Fig. 70A, and the cam surface 992 acts on the lever 980 to rock the shaft 917 in a clockwise direction, Fig. 73. Such rocking movement causes the pin 977 to rotate the collar 935 and thereby release the latch 939. Hence the sensing member 922 is released and the related switch 911 is allowed to open.

It will be observed that the sensing operation of the sensing means at station IV takes place in each machine cycle, but when a printing device is to be skipped, the related storage plunger 672 is located in position 1 so that the control lever 766 is not actuated when this control plunger reaches its control position. Thus the switches 907 and 1012 are not closed, and the operation of the machine continues and none of the signal lamps 902 is lighted.

The mechanism shown in Figs. 76 to 78 may in some instances be utilized to perform the sensing operation at station IV, and in such an instance this mechanism would replace the sensing mechanism which is associated with the switches 911. The operation would in such an instance be substantially similar to the operation just described with respect to the machine shown in Figs. 66 to 75, but where the sensing mechanism of Figs. 76 to 78 is employed, a larger number of sensing positions is provided. The sensing carrier 915 is rocked in the same manner as hereinbefore described, and when a tab 120A lies in the path of a sensing pin 1029, this pin is moved downwardly from the position shown in Fig. 77 to the position shown in Fig. 78. This closes the related switch 1025, and such a switch is latched in its closed position by the spring biased latch device 1037. The switch which is thus closed is maintained closed until the next machine cycle when the shaft 917 is rocked as hereinbefore described. Such rocking movement moves the bail 1040 in a rearward direction, thus to withdraw the latching device 1037 and permit opening of the related switch.

Summary

It will be evident from the foregoing description that the selector mechanism of this invention enables a wide range of control operations to be attained in a printing machine in accordance with identifying means carried at selected identifying positions on printing devices passed sequentially through the machine; and this selector mechanism is such as to enable such a wide variety of control operations to be attained even though the identifying means on the printing devices are sensed several stations in advance of the printing position. The construction and arrangement of the selector mechanism of the pres-

ent invention is such that the sensing station may be conveniently located, and the selector may be readily incorporated in printing machines which are produced in quantity, as a relatively simple basic model which ordinarily does not include selector mechanism.

The present selector also enables relatively large and wide forms to be used with printing machines of the character with which the selector is associated, since the selector of this invention enables large unobstructed areas to be provided on the table top of the machine with which it is used. Moreover, the selector mechanism of the present invention is so constructed and associated with the printing device advancing and positioning means that great accuracy of sensing action is attained, and by reason of this novel relationship it has been found that extremely small identifying areas may be employed on the printing devices. Through the use of such small identifying areas it has been possible to materially increase the number of identifying positions or areas available on any given size or type of printing device, thereby to increase the utility of the selector mechanism and of the printing machine as a whole.

The present selector mechanism is such that it cooperates inherently with the setting of the machine for single or multiple impression operations, and hence the selector is adapted for use with printing machines which are employed in producing a wide variety of work.

The visual selector of the present invention also functions to facilitate rapid and accurate work, since it cooperates with the automatic stop means to effect rapid disposal of the printing devices which are to be skipped, and stops the machine and exhibits a continued or sustained visual signal when a printing device which is to be printed is advanced to a predetermined relation to printing position. The relationship of the visual signal selector to the main selector mechanism is such that the visual signalling means is rendered effective only with respect to those printing devices which are to be printed, thereby to reduce the opportunities for misreading of the visual signals. The maintenance of the signals for a sustained period, that is, until the next machine cycle is initiated, also serves to reduce possible errors, and results in convenience of operation and use heretofore unattained.

While I have illustrated and described preferred embodiments of my invention it is to be understood that these are capable of variation and modification and I therefore do not wish to be limited to the precise details set forth but desire to avail myself of such changes and alterations as fall within the purview of the following claims:

I claim:

1. In a printing machine having a frame providing a table top with a printing position defined thereon adjacent to a forward edge thereof and having a magazine located on said table top a substantial distance laterally of said printing position and adjacent to the rear edge of said table top, means providing a sensing position, a printing device guideway beneath said table top extending from said magazine through said sensing position and to and past said printing position and along which a series of printing devices, each adapted to bear identifying means at one or more selected identifying positions thereon, are adapted to be advanced one

by one from said magazine through said sensing position in said guideway adjacent to said magazine and thence along said guideway to and through said printing position, advancing means operable to advance such printing devices along said guideway in a step by step manner such that said printing devices come to rest at sensing and printing positions; a printing frame having an upper arm extending over and in spaced relation to said table top in an angular relation from a point adjacent to said magazine to a point over said printing position, impression means carried on said arm over said printing position and operable to produce a printing impression from a printing device located at printing position, actuating means for said advancing means and said impression means located beneath said table top rearwardly of said printing position and including an advancing clutch engageable to drive said advancing means through an advancing cycle and an impression clutch engageable to drive said impression means through an impression forming cycle, sensing means located at said sensing position and operable through a sensing stroke to sense the identifying means of a printing device located at sensing position, actuating means for said sensing means comprising an actuating rock shaft disposed beneath said table top parallel to the rear edge thereof, a cam adjacent to and driven by said advancing clutch and operatively associated with the adjacent end of said actuating rock shaft to impart a rocking movement thereto when said advancing means is operated through an advancing cycle, a link and lever connection between the other end of said actuating rock shaft and said sensing means whereby such rocking movement actuates said sensing means through a sensing stroke, storage means located adjacent to said sensing means and embodying a plurality of storage elements adapted to be variably set-up in succession by and under the control of said sensing means in its successive sensing strokes, a control element adapted to be actuated selectively by said storage elements in accordance with the set-up positions of said storage elements, a clutch governing member operable to control the operation of said impression clutch, and a transmitting connection between said control element and said clutch controlling element comprising a control rock shaft extending adjacent and parallel to said actuating rock shaft and having link and lever connections at its opposite ends to said control element and said clutch controlling member respectively.

2. In a printing machine having a printing device guideway along which sensing and printing positions are provided at widely separated locations and along which guideway a series of printing devices, each adapted to bear identifying means at selected identifying positions thereon, are adapted to be advanced in a step by step manner so as to come to rest at said sensing and printing positions, advancing means for imparting such advancing movement to the printing devices, impression means operable to produce a printing impression from a printing device at printing position, sensing means mounted for movement through a sensing stroke and operable to sense the identifying means on printing devices located at sensing position, a storage drum mounted for indexing movement, means operating in timed relation to said advancing means for

imparting indexing movement to said storage drum, a plurality of storage plungers mounted at spaced positions on said drum for shifting movement to different set positions, set-up means for shifting said plungers and operable in turn upon each plunger as indexing movement of said drum moves the plunger into a particular index position to set-up said plungers in different set-up positions in accordance with the sensing operation of said sensing means, an advancing clutch and an impression clutch located adjacent to said printing position and operative to actuate said advancing means and said impression means respectively, a control element adapted for actuation by said plungers at a different index position of said storage drum in accordance with the set-up positions of said plungers, a control member for governing said impression clutch having an operative connection with said control element, and an actuating connection for said sensing means driven from said advancing clutch.

3. In a printing machine embodying a plurality of operative mechanisms and having a frame providing a table top with a printing position defined thereon adjacent to a forward edge thereof, said frame having a magazine located on said table top a substantial distance laterally of said printing position and adjacent to the rear edge of said table top, a printing device guideway beneath said table top extending from said magazine to and past said printing position and along which a series of printing devices, each adapted to bear identifying means at one or more selected identifying positions thereon, are adapted to be advanced one by one from said magazine through a sensing position in said guideway adjacent to said magazine and thence along said guideway to and through said printing position, advancing mechanism operable to advance such printing devices along said guideway in a step by step manner such that said printing devices come to rest at sensing and printing positions, a printing frame having an upper arm extending over and in spaced relation to said table top from a point adjacent to said magazine to a point over said printing position, impression mechanism carried on said arm over said printing position and operable to produce a printing impression from a printing device located at printing position, actuating mechanism for said advancing mechanism and said impression mechanism located beneath said table top rearwardly of said printing position and including an advancing clutch mechanism engageable to drive said advancing mechanism through an advancing cycle and an impression clutch mechanism engageable to drive said impression mechanism through an impression forming cycle, sensing means located at sensing position and operable through a sensing stroke to sense the identifying means of a printing device located at sensing position, actuating means for said sensing means comprising an actuating rock shaft disposed beneath said table top parallel to the rear edge thereof, a cam adjacent to and driven by said advancing clutch and operatively associated with the adjacent end of said actuating rock shaft to impart a rocking movement thereto when said printing device advancing mechanism is operated through an advancing cycle, a link and lever connection between the other end of said actuating rock shaft and said sensing means whereby such rocking movement moves said sensing means through a sensing stroke, and means operable under the control of said sensing means

to govern the operation of one of said operative mechanisms of the machine.

4. In a printing machine embodying a plurality of operative mechanisms and having a printing device guideway along which sensing and printing positions are provided and along which a series of printing devices, each adapted to bear identifying means at selected identifying positions thereon, are adapted to be advanced in a step by step manner so as to come to rest at said sensing and printing positions, advancing mechanism for imparting such advancing movement to the printing devices, sensing mechanism mounted for movement along a straight line sensing path and having at least one elongated sensing element mounted thereon and extending parallel to said sensing path, a storage drum mounted for indexing movement actuating mechanism operating in timed relation to said advancing mechanism for imparting indexing movement to said storage drum, a plurality of storage plungers mounted at spaced index positions on said drum for longitudinal shifting movement from an idle position to any one of a plurality of different set-up positions, yielding detent means operable to retain each plunger in any one of a plurality of set-up positions, set-up mechanism for shifting said plungers operable in turn upon each plunger as indexing movement of said drum moves the plunger into a first index position, said set-up mechanism comprising a shiftable set-up member spring-biased toward the plunger at said first position, a cam and a cooperating cam follower operatively interposed between said sensing mechanism and said set-up mechanism whereby movement of said set-up member is controlled by said sensing mechanism, a plurality of control elements located adjacent to a second index position of said drum and adapted for selective actuation by said plungers as they approach said second index position, in accordance with the set-up positions of such plungers, said control elements being operable to control certain of said mechanisms of the machine, and means operable on said plungers as they move with said drum from said second index position to said first index position to restore each of said plungers to its idle position.
5. In a printing machine having a printing device guideway along which a sensing position is provided and along which a series of printing devices, each adapted to bear identifying means at selected identifying positions thereon, are adapted to be advanced in a step by step manner so as to come to rest at said sensing position, advancing means for imparting such advancing movement to the printing devices, sensing means mounted for movement along a straight line sensing path and having at least one elongated sensing element mounted thereon and extending parallel to said sensing path, a storage drum mounted for indexing movement, means operating in timed relation to said advancing means for imparting indexing movement to said storage drum, a plurality of storage plungers mounted at spaced index positions on said drum for longitudinal shifting movement from idle positions to any selected one of a plurality of different set positions, set-up means for shifting said plungers and operable in turn upon each plunger as indexing movement of said drum moves the plunger into a particular index position, said set-up means comprising a shiftable set-up member spring-biased toward the plunger at said particu-

lar position, and a cam and a cooperating cam follower operatively interposed between said sensing means and said set-up member whereby movement of said set-up member is controlled by said sensing means.

6. In a printing machine having a printing device guideway along which a sensing position is provided and along which a series of printing devices, each adapted to bear identifying means at selected identifying positions thereon, are adapted to be advanced in a step by step manner so as to come to rest at said sensing position, advancing means for imparting such advancing movement to the printing devices, sensing means mounted for movement in a sensing path and having at least one elongated sensing element mounted thereon, a storage drum mounted for indexing movement, means operating in timed relation to said advancing means for imparting indexing movement to said storage drum, a plurality of storage plungers mounted at spaced index positions on said drum for longitudinal shifting movement from idle positions to any one of a plurality of different set positions, set-up means for shifting said plungers and operable in turn upon each plunger as indexing movement of said drum moves the plunger into a particular index position, said set-up means comprising a shifttable set-up member spring-biased toward the plunger at said particular position, a cam shifttable with said sensing means, and a co-operating cam follower carried on said set-up member and actuated by said cam whereby movement of said set-up member and the set-up movement of the aligned storage plunger are controlled by said sensing means.

7. In a printing machine including a plurality of operative mechanisms and through which a series of printing devices each bearing identifying means at one or more of a plurality of identifying positions thereon are adapted to be advanced one by one along a guideway providing sensing and printing positions, printing device advancing mechanism operable in each cycle to advance the printing devices along said guideway for a predetermined distance, impression mechanism operable in each cycle of its operation to produce a printing impression at said printing position in accordance with a printing device located at said printing position, sensing means operable to sense the identifying means of a printing device located at said sensing position, a storage drum mounted for indexing movement and having a plurality of storage plungers mounted for individual shifting movement from an idle position to any one of a plurality of different set positions on said drum, means operable to shift said plungers when they are in a predetermined index position of said drum to locate the plungers in different set-up positions in accordance with and under the control of said sensing means, a plurality of individually operable control elements each operable in a control actuation thereof to control a different one of the operative mechanisms of the machine and said control elements being selectively operable by each of said storage plungers in another index position of said drum in accordance with the set-up position of each such storage plunger on said drum, and means for variably adjusting the relationship of said control elements to vary the selective effectiveness of said plungers thereon.

8. In a printing machine including a plurality of operative mechanisms and through which a

series of printing devices each bearing identifying means at one or more of a plurality of identifying positions thereon are adapted to be advanced one by one along a guideway providing sensing and printing positions, advancing means for advancing printing devices from station to station along said guideway, impression mechanism for producing printing impressions from said printing devices at printing position, individually operable single cycle drive mechanism for said advancing means and said impression means, sensing means operating under the control of the advancing means drive mechanism and operable to sense the identifying means of a printing device at sensing station, a plurality of control elements each operable in a control actuation to effect a control operation upon a different one of said mechanisms, and intermediate means operable under the control of said sensing means to impart a control movement to different ones of said control elements in accordance with different sensing operation of said sensing means, and means operable upon at least selected of said control elements to vary the effectiveness of said intermediate means thereon.

9. In a printing machine having a plurality of operative mechanisms and through which a series of printing devices each bearing identifying means at one or more of a plurality of identifying positions thereon are adapted to be advanced one by one along a guideway providing sensing and printing positions, advancing means for advancing printing devices from station to station along said guideway, impression mechanism for producing printing impressions from said printing devices at printing position, individually operable single cycle drive mechanism for said advancing means and said impression means, sensing means operating under the control of the advancing means drive mechanism and operable to sense the identifying means of a printing device at sensing station, a plurality of control elements each operable in a control actuation to effect a control operation upon a different one of said mechanisms, an intermediate means operable under the control of said sensing means to impart a control movement to different ones of said control elements in accordance with different sensing operation of said sensing means, means forming an operative connection between two of said control elements whereby actuation of a selected one of the said two elements is operable to impart a similar actuation to the other of said two elements, and means for disabling said operative connection.

10. In a printing machine including a plurality of operative mechanisms and through which a series of printing devices each bearing identifying means at one or more of a plurality of identifying positions thereon are adapted to be advanced one by one along a guideway providing sensing and printing positions, advancing means for advancing printing devices from station to station along said guideway, impression mechanism for producing printing impressions from said printing devices at printing position, individually operable single cycle drive mechanism for said advancing means and said impression means, sensing means operating under the control of the advancing means drive mechanism and operable to sense the identifying means of a printing device at sensing station, a plurality of control elements each operable in a control actuation to effect a control operation upon a different one of said mechanisms, an intermediate

means operable under the control of said sensing means to impart a control movement to different ones of said control elements in accordance with different sensing operation of said sensing means, a first operative connection from a first one of said elements to a third one of said elements whereby actuation of said first element imparts a similar actuation to said third element, a second operative connection from a second one of said elements to said third element whereby actuation of said second element imparts a similar actuation to said third element, and means operable selectively to disable one of said operative connections, or to disable both of said operative connections.

11. In a printing machine embodying a plurality of operative mechanisms and having a printing device guideway along which a sensing position is provided and along which a series of printing devices, each adapted to bear identifying means at selected identifying positions thereon, are adapted to be advanced in a step by step manner so as to come to rest at said sensing position, advancing mechanism for imparting such advancing movement to the printing devices, sensing mechanism mounted for movement through a sensing stroke, a storage drum mounted for indexing movement, actuating mechanism operating in timed relation to said advancing mechanism for imparting indexing movement to said storage drum, a plurality of storage plungers mounted at spaced positions on said drum for longitudinal shifting movement from an idle position to any one of at least two different set-up positions, yielding detent means operable to retain each plunger in any one of its plurality of positions, set-up mechanism controlled by said sensing mechanism and operable in turn upon each plunger as indexing movement of said drum moves the plunger into a first index position to actuate said plungers from their idle positions to different set-up positions as determined by the sensing operation of said sensing mechanism, a plurality of control elements located adjacent to a second index position of said drum and adapted for selective actuation by said plungers as they approach said second index position, in accordance with their set-up positions, said control elements being operable to control certain of said mechanisms of the machine, and means operable on said plungers as they move with said drum from said second index position to said first index position to restore each of said plungers to its idle position.

12. In a printing machine embodying a plurality of operative mechanisms and having a printing device guideway along which a sensing position is provided and along which a series of printing devices, each adapted to bear identifying means at selected identifying positions thereon, are adapted to be advanced in a step by step manner so as to come to rest at said sensing position, advancing mechanism for imparting such advancing movement to the printing devices, sensing mechanism mounted for movement through a sensing stroke, a storage drum mounted for indexing movement, actuating mechanism operating in timed relation to said advancing mechanism for imparting indexing movement to said storage drum, a plurality of storage plungers mounted at spaced positions about said drum for shifting movement from an idle position to any one of at least two different set-up positions, yielding detent means operable to retain each plunger in any one of its plurality

5 of positions, set-up mechanism controlled by said sensing mechanism and operable in turn upon each plunger as indexing movement of said drum moves the plunger into a first index position to actuate said plungers from their idle positions to different set-up positions as determined by the sensing operation of said sensing mechanism, a control element operable when actuated to govern the operation of one of said mechanisms and adapted to be actuated by said control plungers as the plungers approach a second index position of said drum, and means for selectively rendering said control element subject to actuation by said plungers in different set-up positions thereof.

13. In a printing machine embodying a plurality of operative mechanisms and having a printing device guideway along which a sensing position is provided and along which a series of printing devices, each adapted to bear identifying means at selected identifying positions thereon, are adapted to be advanced in a step by step manner so as to come to rest at said sensing position, advancing mechanism for imparting such advancing movement to the printing devices, sensing mechanism mounted for movement through a sensing stroke, a storage drum mounted for indexing movement, actuating mechanism operating in timed relation to said advancing mechanism for imparting indexing movement to said storage drum, a plurality of storage plungers mounted at positions spaced angularly about said drum and arranged for shifting movement on said drum from an idle position to any one of at least two different set-up positions, set-up mechanism controlled by said sensing mechanism and operable in turn upon each plunger as indexing movement of said drum moves the plunger into a first index position to actuate said plungers from their idle positions to different set-up positions as determined by the sensing operation of said sensing mechanism, a first control element operable when actuated to govern the operation of one of said mechanisms and adapted to be actuated by said control plungers as the plungers approach a second index position of said drum, means for selectively rendering said control element subject to actuation by said plungers in different set-up positions thereof, and another control element adapted for actuation by said plungers in another of said set-up positions and operable when thus actuated to effect a control operation with respect to another of said operative mechanisms of the machine.

14. In a printing machine embodying a plurality of operative mechanisms and having a printing device guideway along which a sensing position is provided and along which a series of printing devices, each adapted to bear identifying means at selected identifying positions thereon, are adapted to be advanced in a step by step manner so as to come to rest at said sensing position, advancing mechanism for imparting such advancing movement to the printing devices, sensing mechanism mounted for movement through a sensing stroke, a storage drum mounted for indexing movement, actuating mechanism operating in timed relation to said advancing mechanism for imparting indexing movement to said storage drum, a plurality of storage plungers mounted on said drum at spaced positions about said drum and arranged for shifting movement from an idle position to any one of at least three different set-up positions, set-

up mechanism controlled by said sensing mechanism and operable in turn upon each plunger as indexing movement of said drum moves such a plunger into a first index position to actuate each such plunger from its idle position to different set-up positions as determined by the sensing operation of said sensing mechanism, a plurality of control elements located adjacent to a second index position of said drum and adapted for selective actuation by said plungers as they approach said second index position, in accordance with their set-up positions, said control elements being operable to control certain of said mechanisms of the machine, means for restoring said plungers to their idle positions, means whereby a first one of said control elements is actuated by a second one of said control elements when such second control element is actuated, and means for rendering said first one of said control elements independent of said second control element.

15. In a printing machine embodying a plurality of operative mechanisms and having a printing device guideway along which a sensing position is provided and along which a series of printing devices, each adapted to bear identifying means at selected identifying positions thereon, are adapted to be advanced in a step by step manner so as to come to rest at said sensing position, advancing mechanism for imparting such advancing movement to the printing devices, sensing mechanism mounted for movement through a sensing stroke, a storage drum mounted for indexing movement, actuating mechanism operating in timed relation to said advancing mechanism for imparting indexing movement to said storage drum, a plurality of storage plungers mounted at spaced positions on said drum for shifting movement from an idle position to any one of at least four different set-up positions, set-up mechanism controlled by said sensing mechanism and operable in turn upon each plunger as indexing movement of said drum moves the plunger into a first index position to actuate said plungers from their idle positions to different set-up positions as determined by the sensing operation of said sensing mechanism, three control elements located adjacent to a second index position of said drum and adapted for selective actuation by said plungers as they approach said second index position, in accordance with their set-up positions, said control elements being operable to control certain of said mechanisms of the machine, means for restoring said plungers to their idle positions, one of said control elements being shiftable to three different positions, in one of which it is actuatable by a plunger in a particular set-up position, or by either one of the other control elements, and in another position is actuatable by a storage plunger in another set-up position or by a particular one of the other control elements, and in another of said three different positions is independent of both of the other control elements and independent of said storage plungers in all of said set-up positions.

16. In a printing machine having sensing and printing positions and including a plurality of operative mechanisms, said printing machine having a printing device guideway along which a series of printing devices each bearing identifying means at one or more of a plurality of identifying positions thereon are adapted to be advanced one by one to said sensing and printing positions, printing device advancing mechanism

operable in its successive cycles to advance the printing devices along said guideway in a step by step manner, impression mechanism operable in each cycle of its operation to produce a printing impression at said printing position in accordance with the printing device then located at printing position, sensing means operable to sense the identifying means of a printing device located at said sensing position, a storage drum mounted for indexing movement and having a plurality of storage plungers mounted for individual shifting movement from an idle position to any one of at least two different set-up positions on said drum, means operable to shift said plungers when they are in a predetermined index position of said drum to shift the plungers to different set-up positions in accordance with and under the control of said sensing means, and a plurality of individually operable control elements each operable in a control actuation thereof to control a different one of the operative mechanisms of the machine and said control elements being selectively operable by each of said storage plungers in another index position of said drum in accordance with the set-up position of each such storage plunger on said drum.

17. In a printing machine providing a sensing position and a printing position and having a plurality of operative mechanisms, said machine having a guideway along which a series of printing devices each bearing identifying means at one or more of a plurality of identifying positions thereon are adapted to be advanced one by one to said sensing and printing positions, printing device advancing mechanism operable to advance the printing devices along said guideway in a step by step manner, impression mechanism operable in each cycle of its operation to produce a printing impression at said printing position in accordance with a printing device, sensing means operable to sense the identifying means of a printing device located at said sensing position, a storage drum mounted for indexing movement and having a plurality of storage plungers mounted for individual shifting movement from idle positions to at least two different set-up positions on said drum, means operable to shift said plungers when they are in a predetermined index position of said drum to locate the plungers in accordance with and under the control of said sensing means, each of said plungers having at least one cam lobe formed thereon and arranged to be located in different positions relative to said drum when said plungers are in different set-up positions, a plurality of individually operable control elements each operable in a control actuation thereof to control a different one of the operative mechanisms of the machine and said control elements having cam surfaces thereon adapted to be selectively engaged by the cam lobe of each plunger in another index position of said drum in accordance with the positioning of each such storage plunger on said drum to actuate said control levers selectively.

18. In a printing machine including a plurality of operative mechanisms and through which a series of printing devices each bearing identifying means at one or more of a plurality of identifying positions thereon are adapted to be advanced one by one along a guideway providing sensing and printing positions, advancing means for advancing printing devices from station to station along said guideway, impression mechanism for producing printing impressions from

said printing devices at printing position, individually operable single cycle drive mechanism for said advancing means and said impression means, sensing means operating under the control of the advancing means drive mechanism and operable to sense the identifying means of a printing device at sensing station, a plurality of control elements each operable in a control actuation to effect a control operation upon a different one of said mechanisms, and an intermediate means including at least one control member settable by and under the control of said sensing means from an idle position to any one of a plurality of active control positions and operable in accordance with the active control position to which it is thus set to impart a control movement to different ones of said control elements.

19. In a printing machine including a plurality of operative mechanisms and through which a series of printing devices each bearing identifying means at one or more of a plurality of identifying positions thereon are adapted to be advanced one by one along a guideway to sensing and printing positions in said machine, printing device advancing mechanism operable in a succession of feeding cycles to advance the printing devices along said guideway in a step by step manner, impression mechanism operable in each cycle of its operation to produce a printing impression at said printing position in accordance with a printing device, sensing means operable to sense the identifying means of a printing device located at said sensing position, a storage drum mounted for indexing movement and having a plurality of storage plungers mounted for individual shifting movement from an idle position to any one of at least two different set-up positions on said drum, means operable to shift said plungers when they are in a predetermined index position of said drum to locate the plungers in different set-up positions in accordance with and under the control of said sensing means, a plurality of individually operable control elements each operable in a control actuation thereof to control a different one of the operative mechanisms of the machine and said control elements being selectively operable by each of said storage plungers in another index position of said drum in accordance with the set-up positioning of each of such storage plungers on said drum, means operable to impart indexing movement to said storage drum each time said advancing means is operated, multiprint means settable to disable said advancing means in predetermined operative cycles of said impression mechanism, and one of said control elements being operable upon said impression means to control operation thereof and being dominated by the setting of said multiprint means.

20. In a printing machine including a plurality of operative mechanisms and through which a series of printing devices each bearing identifying means at one or more of a plurality of identifying positions thereon are adapted to be advanced one by one along a guideway providing sensing and printing positions, printing device advancing mechanism operable in each cycle to advance the printing devices along said guideway for a predetermined distance, impression mechanism operable in each cycle of its operation to produce a printing impression at said printing position in accordance with a printing device, sensing means operable to sense the identifying means of a printing device located at said

sensing station, a storage drum mounted for indexing movement and having a plurality of storage plungers mounted for individual shifting movement from an idle position to any one of at least two different set-up positions on said drum, means operable to shift said plungers when they are in a predetermined index position of said drum to locate the plungers in different set-up positions in accordance with and under the control of said sensing means, a plurality of individually operable control elements each operable in a control actuation thereof to control a different one of the operative mechanisms of the machine and said control elements being selectively operable by each of said storage plungers in another index position of said drum in accordance with the set-up positioning of each of such storage plungers on said drum, means operable to impart indexing movement to said storage drum each time said advancing means is operated, multiprint means settable to disable said advancing means in predetermined operative cycles of said impression mechanism, one of said control elements having a yielding lost-motion control-transmitting connection with said impression means to prevent operation thereof when said one of said control elements is actuated, and means operable by said multiprint means to place a stop in the path of a part of said lost-motion connection to thereby cause compression of said yielding connection when said advancing means is disabled.

21. In a printing machine having a frame providing a table top with a printing position defined thereon adjacent to a forward edge thereof and having a magazine located on said table top a substantial distance laterally of said printing position and adjacent to the rear edge of said table top, a printing device guideway beneath said table top extending from said magazine to and past said printing position and along which a series of printing devices, each adapted to bear identifying means at one or more selected identifying positions thereon, are adapted to be advanced one by one from said magazine through a sensing position in said guideway adjacent to said magazine and thence along said guideway to and through said printing position, an advancing means operable to advance such printing devices along said guideway in a step by step manner such that said printing devices come to rest at sensing and printing positions, a printing frame having an upper arm extending over and in spaced relation to said table top from a point adjacent to said magazine to a point over said printing position, impression means carried on said arm over said printing position and operable to produce a printing impression from a printing device located at printing position, actuating means for said advancing means and said impression means located beneath said table top rearwardly of said printing position and including an advancing clutch engageable to drive said advancing means through an advancing cycle and an impression clutch engageable to drive said impression means through an impression forming cycle, sensing means located at sensing position and operable through a sensing stroke to sense the identifying means of a printing device located at sensing position, actuating means for said sensing means comprising an actuating rock shaft disposed beneath said table top parallel to the rear edge thereof, a cam adjacent to and driven by said advancing clutch and operatively associated with the adjacent end

of said actuating rock shaft to impart a rocking movement thereto when said advancing means is operated through an advancing cycle, a link and lever connection between the other end of said actuating rock shaft and said sensing means whereby such rocking movement moves said sensing means through a sensing stroke, storage means located adjacent to said sensing means and embodying a plurality of storage elements adapted to be variably set-up in succession by and under the control of said sensing means in its successive sensing strokes, a control element adapted to be actuated selectively by said storage elements in accordance with the set-up positions of said storage elements, an impression clutch governing member operable to control the operation of said impression clutch, and a control transmitting connection between said control element and said clutch controlling element comprising a control rock shaft extending adjacent and parallel to said actuating rock shaft and having link and lever connections at its opposite ends to said control element and said clutch controlling member respectively, one of said link and lever connections in said control transmitting connection including a yielding lost motion, a supplemental advancing control element operable upon said advancing clutch to prevent operation thereof, a multiprint means adapted to be rendered operative or inoperative and effective when operative to render said supplemental advancing control element operable in certain cycles of operation to thereby cause the machine to print more than one impression from each printing device, and means governed by said multiprint means to cause the yielding lost motion of said link and lever connection to be compressed and thereby render said control rock shaft ineffective on said impression clutch controlling member whenever said supplemental advancing control element is in its operative relation to said advancing clutch.

22. In a printing machine including a plurality of operative mechanisms and through which a series of printing devices each bearing identifying means at one or more of a plurality of identifying positions thereon are adapted to be advanced one by one along a guideway providing sensing and printing positions, printing device advancing mechanism operable in each cycle to advance the printing devices along said guideway from one position to another, impression mechanism operable in each cycle of its operation to produce a printing impression at said printing position in accordance with a printing device located at said printing position, sensing means operable to sense the identifying means of a printing device located at said sensing station, means for actuating said sensing means in timed relation to the operation of said advancing mechanism, a storage drum mounted for indexing movement and having a plurality of storage plungers mounted for individual shifting movement to different set-up positions on said drum, means operable to shift said plungers when they are in a predetermined index position of said drum to locate the plungers in different set-up positions in accordance with and under the control of the identifying means sensed by said sensing means, a plurality of individually operable control elements each operable in a control actuation thereof to control a different one of the operative mechanisms of the machine and said control elements being selectively operable by each of said storage plungers in another index posi-

tion of said drum in accordance with the set-up position of each such storage plunger on said drum, a rocker member normally biased for movement in one direction to perform a selected operation and latched against such movement by a particular one of said control elements, a second latch operable to restrain said rocker member against such movement, said particular control element when actuated by a set-up plunger being operable to unlatch said rocker member and to thereby place said rocker member under the control of said second latch, means operable in timed relation to said sensing mechanism to release said second latch, and means operable in timed relation to said sensing means to restore said rocker member to its latched relation to said second latch.

23. In a printing machine through which a series of printing devices each bearing identifying means at one or more of a plurality of identifying positions thereon are adapted to be advanced one by one along a guideway providing sensing and printing positions, printing device advancing mechanism operable in each cycle to advance the printing devices along said guideway from one position to another, impression mechanism operable to produce a printing impression from the printing device at said printing position, sensing means operable to sense the identifying means of a printing device located at said sensing station, means for actuating said sensing means in timed relation to the operation of said advancing mechanism, a storage drum mounted for indexing movement and having a plurality of storage plungers mounted for individual shifting movement to different set-up positions on said drum, means operable to shift said plungers when they are in a predetermined index position of said drum to locate the plungers in different set-up positions in accordance with and under the control of the identifying means sensed by said sensing means, a plurality of individually operable control elements each operable in a control actuation thereof to control a different one of the operative mechanisms of the machine and said control elements being selectively operable by each of said storage plungers in another index position of said drum in accordance with the set-up position of each such storage plunger on said drum, a rocker member normally biased for movement in one direction to perform a selected operation and latched against such movement by a particular one of said control elements, a second latch operable to restrain said rocker member against such movement, said particular control element when actuated by a set-up plunger being operable to unlatch said rocker member and to thereby place said rocker member under the control of said second latch, and means operable in timed relation to the operation of said sensing mechanism to release said second latch.

24. In a printing machine through which a series of printing devices each bearing identifying means at one or more of a plurality of identifying positions thereon are adapted to be advanced one by one along a guideway providing sensing and printing positions, printing device advancing mechanism operable in each cycle to advance the printing devices along said guideway from one position to another, impression mechanism operable to produce a printing impression from the printing device at said printing position, sensing means operable to sense the identifying means of a printing device located at said sensing station, means for actuating said

sensing means in timed relation to the operation of said advancing mechanism, a storage drum mounted for indexing movement and having a plurality of storage plungers mounted for individual shifting movement to different set-up positions on said drum, means operable to shift said plungers when they are in a predetermined index position of said drum to locate the plungers in different set-up positions in accordance with and under the control of the identifying means sensed by said sensing means, a rocker member normally biased for movement in one direction to perform a selected operation, a control element operable to latch said rocker member against such movement, said control element being selectively operable by each of said storage plungers in another index position of said drum in accordance with the set-up position of each such storage plunger on said drum, a second latch operable to restrain said rocker member against such movement, said control element when actuated by a set-up plunger being operable to unlatch said rocker member and to thereby place said rocker member under the control of said second latch, and means operable at a predetermined time in the operation of the machine to release said second latch.

25. In a printing machine through which a series of printing devices each bearing identifying means at one or more of a plurality of identifying positions thereon are adapted to be advanced one by one along a guideway providing sensing and printing positions, printing device advancing mechanism operable in each cycle to advance the printing devices along said guideway from one position to another, impression mechanism operable in each cycle of its operation to produce a printing impression from the printing device at said printing position, sensing means operable to sense the identifying means of a printing device located at said sensing station, a member normally biased for movement in one direction to perform a selected operation in said machine, a first latch element acting on said member to prevent such movement, a second latch element operable to restrain said member against such movement, means operable under the governing action of the identifying means sensed on a printing device to release said first latch element to thereby place said member under the control of said second latch element, means operable in timed relation to said sensing mechanism irrespective of the identifying means sensed thereby to release said second latch element, and means operable in timed relation to said sensing means to restore said member to its latched relation to said second latch.

26. In a printing machine through which a series of printing devices, each adapted to bear identifying means at selected identifying positions thereon, are adapted to be advanced from a magazine along a guideway in a step by step manner such that each printing device comes to rest successively at each of a series of stations including a pair of sensing stations and a printing station provided along said guideway, advancing means operable to impart such step by step movement to printing devices along said guideway, printing means for producing a printing impression from a printing device at printing station, a first selector mechanism including sensing means operable to sense the identifying means of a printing device at one of said sensing stations and operable in accordance with the

5 sensed presence or absence of identifying means at a selected identifying position thereon to control said printing means to print or skip the sensed printing device when it reaches printing position, and a selector mechanism including a second sensing means operable to sense the identifying means on each printing device while it is located at the other of said sensing positions and operable in accordance with the sensed presence or absence of identifying means at other selected identifying positions thereon to exhibit, in the cycle preceding the cycle in which the related printing device reaches printing station, a visual indication of the identifying means thus sensed, and means associated with said second sensing means operable to maintain said visual indication until the printing cycle with respect to the related printing device has been initiated.

27. In a printing machine through which a series of printing devices, each adapted to bear identifying means at selected identifying positions thereon, are adapted to be advanced from a magazine along a guideway in a step by step manner such that each printing device comes to rest successively at each of a series of stations including a pair of sensing stations and a printing station provided along said guideway, advancing means operable to impart such step by step movement to printing devices along said guideway, printing means for producing a printing impression from a printing device at printing station, selector mechanism including sensing means operable to sense the identifying means of a printing device at one of said sensing stations and operable in accordance with the sensed presence or absence of identifying means at a selected identifying position thereon to control said printing means to print or skip the sensed printing device when it reaches printing position, 30 and a selector mechanism including a visual indicator and a second sensing means operable to sense the identifying means on each printing device while it is located at the other of said sensing positions and operable in accordance with the sensed presence or absence of identifying means at other selected identifying positions thereon to exhibit on said visual indicator, in the cycle preceding the cycle in which the related printing device reaches printing station, a visual 35 indication of the identifying means thus sensed, and means operatively associated with said visual indicator and operable to maintain said visual indication effective thereon until the printing cycle with respect to the related printing device has been initiated.

28. In a printing machine through which a series of printing devices, each adapted to bear identifying means at a selected one of a plurality of identifying positions thereon, are adapted to be advanced in a step by step manner from a magazine along a guideway through sensing and printing positions, a selector mechanism comprising a plurality of visual indicating devices adapted to be rendered effective selectively, 40 a sensing means adapted to sense the identifying means on a printing device at said sensing station and operable selectively to render one of said indicating devices effective in accordance with the identifying position in which identifying means has been sensed on the printing device at sensing station, and means operable when a visual indicating device has been rendered effective in one cycle of machine operation to maintain the same effective at least until the succeeding machine cycle has been initiated.

29. In a printing machine through which a series of printing devices, each adapted to bear identifying means at a selected one of a plurality of identifying positions thereon, are adapted to be advanced in a step by step manner from a magazine along a guideway through sensing and printing positions, a selector mechanism comprising a plurality of visual indicating devices each allocated to indicate the presence or absence of identifying means at a different one of said identifying positions and adapted to be rendered effective selectively, and sensing means adapted to sense the identifying means on a printing device at said sensing station and operable selectively to render one of said indicating devices effective for a sustained operating period in accordance with the identifying position in which identifying means has been sensed on the printing device at sensing station.

30. In a printing machine through which a series of printing devices, each adapted to bear identifying means at a selected one of a plurality of identifying positions thereon, are adapted to be advanced in a step by step manner from a magazine along a guideway through sensing and printing positions, a selector mechanism comprising a plurality of visual indicating devices adapted to be rendered effective selectively, electrical control means for said visual selector mechanism including an individual energizing circuit for each indicating device operable when closed to render the associated indicating device effective, plurality of selector switches, one included in each of said circuits, a sensing means adapted to sense the identifying means on a printing device at said sensing station and operable selectively to close one of said switches in accordance with the identifying position in which identifying means has been sensed on the printing device at sensing station to render the associated indicating means effective, and means operable when such a switch has been closed in one cycle of machine operation to maintain the same closed at least until the succeeding machine cycle has been initiated.

31. In a printing machine through which a series of printing devices, each adapted to bear identifying means at a selected one of a plurality of identifying positions thereon, are adapted to be advanced in a step by step manner from a magazine along a guideway through sensing and printing positions, a selector mechanism comprising a plurality of visual indicating devices adapted to be rendered effective selectively, electrical control means for said visual selector mechanism including an individual energizing circuit for each indicating device operable when closed to render the associated indicating device effective, a plurality of selector switches, one included in each of said circuits, a sensing means adapted to sense the identifying means on a printing device at said sensing station and operable selectively to close one of said switches in accordance with the identifying position in which identifying means has been sensed on the printing device at sensing station to render the associated indicating means effective, and latching means operable when a switch has been thus closed to latch the same in closed position, and latch release means operable thereafter and prior to the subsequent sensing operation of said sensing means to release said latching means and thereby permit the opening of such switch.

32. In a printing machine through which a

series of printing devices, each adapted to bear identifying means at a selected one of a plurality of identifying positions thereon, are adapted to be advanced in a step by step manner from a magazine along a guideway through sensing and printing positions, a selector mechanism comprising a plurality of electrically operated visual indicating devices, individual energizing circuits for said indicating devices each including a selector switch adapted to be closed selectively, a sensing means adapted in a sensing operation to sense the identifying means on a printing device at said sensing station and operable selectively to close one of said selector switches in accordance with the identifying position in which identifying means has been sensed on the printing device at sensing station to thereby energize the associated indicating device, and means operable when a visual indicating device has been thus energized to maintain the same energized for a sustained period after said sensing operation.

33. In a printing machine through which a series of printing devices, each adapted to bear identifying means at a selected one of a plurality of identifying positions thereon, are adapted to be advanced in a step by step manner from a magazine along a guideway through sensing and printing positions, a selector mechanism comprising a plurality of visual indicating devices adapted to be rendered effective selectively, a sensing means adapted to sense the identifying means on a printing device at said sensing station and operable selectively to render one of said indicating devices effective in accordance with the identifying position in which identifying means has been sensed on the printing device at sensing station, and means operable when a visual indicating device has been rendered effective to produce a sustained period of effectiveness of the effective indicating device.

34. In a printing machine through which a series of printing devices, each adapted to bear identifying means at selected identifying positions thereon, are adapted to be advanced from a magazine along a guideway in a step by step manner such that each printing device comes to rest successively at each of a series of stations including a pair of sensing stations and a printing station provided along said guideway, advancing means operable to impart such step by step movement to printing devices along said guideway, printing means for producing a printing impression from a printing device at printing station, a first selector mechanism including sensing means operable to sense the identifying means of a printing device at one of said sensing stations and operable in accordance with the sensed presence or absence of identifying means at a selected identifying position thereon to control said printing means to print or skip the sensed printing device when it reaches printing position, and a selector mechanism including a second sensing means operable to sense the identifying means on each printing device while it is located at the other of said sensing positions and operable in accordance with the sensed presence or absence of identifying means at other selected identifying positions thereon to exhibit, in the cycle preceding the cycle in which the related printing device reaches printing station, a visual indication of the identifying means thus sensed, means associated with said second sensing means operable to maintain said visual indication until the printing cycle with

respect to the related printing device has been initiated, and means operable under the control of said first selector mechanism to render said second sensing means ineffective to exhibit a visual indication as aforesaid except in relation to printing devices which are to be printed.

35. In a printing machine through which a series of printing devices, each adapted to bear identifying means at selected identifying positions thereon, are adapted to be advanced from a magazine along a guideway in a step by step manner such that each printing device comes to rest successively at each of a series of stations including a pair of sensing stations and a printing station provided along said guideway, advancing means operable to impart such step by step movement to printing devices along said guideway, printing means for producing a printing impression from a printing device at printing station, a first selector mechanism including sensing means operable to sense the identifying means of a printing device at one of said sensing stations and operable in accordance with the sensed presence or absence of identifying means at a selected identifying position thereon to control said printing means to print or skip the sensed printing device when it reaches printing position, and a selector mechanism including a plurality of individually operable indicating devices and a second sensing means operable to sense the identifying means on each printing device while it is located at the other of said sensing positions and having operative connections with said indicating devices whereby said indicating devices may be operated by said second sensing means in accordance with the sensed presence or absence of identifying means at other selected identifying positions on a printing device to operate the appropriate one of said indicating devices in the machine cycle preceding the cycle in which the related printing device reaches printing station, and means controlled by said first selector mechanism and dominating the action of said second sensing means to disable said operative connections of said second sensing means with said indicating devices and permit operation of said indicating devices only with relation to printing devices which are to be printed when they reach printing position.

36. In a printing machine through which a series of printing devices, each adapted to bear identifying means at selected identifying positions thereon, are adapted to be advanced from a magazine along a guideway in a step by step manner such that each printing device comes to rest successively at each of a series of stations including a pair of sensing stations and a printing station provided along said guideway, advancing means operable to impart such step by step movement to printing devices along said guideway, printing means for producing a printing impression from a printing device at printing station, a first selector mechanism including sensing means operable to sense the identifying means of a printing device at one of said sensing stations and operable in accordance with the sensed presence or absence of identifying means at a selected identifying position thereon to control said printing means to print or skip the sensed printing device when it reaches printing position, a selector mechanism including a second sensing means operable to sense the identifying means on each printing device while it is located at the other of said sensing stations and

5 operable in accordance with the sensed presence or absence of identifying means at other selected identifying positions thereon to exhibit, in the cycle preceding the cycle in which the related printing device reaches printing station, a visual indication of the identifying means thus sensed, means associated with said second sensing means operable to maintain said visual indication until the printing cycle with respect to the related printing device has been initiated, and auto-stop means having an active relationship wherein it is operable to control said printing machine to produce continuous operation thereof and having an inactive relationship wherein it is operable to stop the printing machine, an actuating means for said auto-stop means operable upon said auto-stop means under the control of said first selector mechanism to stop said machine when a printing device which is to be printed is advanced to a predetermined relation to said printing station by said advancing means.

37. In a printing machine through which a series of printing devices, each adapted to bear identifying means at one or more selected identifying positions thereon, are adapted to be advanced from a magazine along a guideway providing a pair of sensing stations and a printing station at spaced points therealong, printing device advancing means for advancing such printing device through the machine in a step by step manner such that each printing device comes to rest at said sensing and printing stations, an automatic mechanical selector, an automatic selector including a plurality of indicating devices, sensing means at each of said sensing stations movable through sensing strokes from inactive retracted positions to active sensing positions wherein they are in sensing cooperation with the identifying means of a printing device at the associated sensing station, printing means for producing a printing impression from a printing device at printing station and governed by said mechanical selector to produce print or skip operation of the machine in accordance with the sensing means operative at one of said sensing stations, and governing means for said indicating devices controlled in part by said sensing means operative at the other of said sensing stations and in part by said mechanical selector.

38. In a printing machine through which a series of printing devices, each adapted to bear identifying means at one or more selected identifying positions thereon, are adapted to be advanced from a magazine along a guideway providing a pair of sensing stations and a printing station at spaced points therealong, printing device advancing means for advancing such printing device through the machine in a step by step manner such that each printing device comes to rest at said sensing and printing stations, a first automatic selector, a second automatic selector including a plurality of indicating devices, sensing means at each of said sensing stations movable through sensing strokes to sense the identifying means of a printing device at the associated sensing station, printing means for producing a printing impression from a printing device at printing station and governed by said first selector to produce print or skip operation of the machine in accordance with the sensing means operative at one of said sensing stations, means for rendering said machine operative continuously, and means operable upon said last named means under the control of said first selector to stop the continuous operation of said machine.

39. In a printing machine through which a series of printing devices, each adapted to bear identifying means at one or more selected identifying positions thereon, are adapted to be advanced from a magazine along a guideway providing a pair of sensing stations and a printing station at spaced points therealong, printing device advancing means for advancing such printing device through the machine in a step by step manner such that each printing device comes to rest at sensing and printing stations, an automatic mechanical selector, an automatic selector including a plurality of indicating devices, sensing means at each of said sensing stations movable through sensing strokes from inactive retracted positions to active sensing positions wherein they are in sensing cooperation with the identifying means of a printing device at the associated sensing station, printing means for producing a printing impression from a printing device at printing position, storage means forming part of said mechanical selected, and set up, under the control of the sensing means operative upon a particular printing device at the first one of said sensing stations and operative in a subsequent cycle of the machine to produce print or skip operation of the machine with respect to the particular printing device in accordance with the sensed presence or absence of selected identifying means thereon, means operable under the control of the other sensing means when the particular control device reaches the other of said sensing stations to condition said indicating devices selectively for operation in accordance with the identifying means sensed on said particular printing device at said other sensing station, and means operable under the control of said storage means to render the conditioned indicating device operative in the event that said particular printing device is one from which a printing impression is to be made.

40. In a printing machine having a printing device guideway along which a printing station is provided and a pair of sensing stations are provided in advance of the printing station, and along which guideway a series of printing devices, each adapted to bear identifying means at selected identifying positions thereon, are adapted to be advanced in a step by step manner so as to come to rest at said sensing and printing stations, advancing means for imparting such advancing movement to the printing devices, printing means operable to make a printing impression from a printing device at printing station, sensing means at said pair of sensing stations whereby the identifying means of each printing device are sensed successively as they come to rest in the successive sensing stations, and means coordinating the sensing operations of the sensing means pertaining to a particular printing device bearing identifying means at a particular identifying position to stop the machine when such particular printing device has been advanced from the second one of said sensing stations and at the same time to exhibit a visual indication of other identifying means carried by the particular printing device.

41. In a printing machine having a printing device guideway along which a printing station is provided and a pair of sensing stations are provided in advance of the printing station, and along which guideway a series of printing devices, each adapted to bear identifying means at selected identifying positions thereon, are adapted to be advanced in a step by step manner so as

to come to rest at said sensing and printing stations, advancing means for imparting such advancing movement to the printing devices, printing means operable to make a printing impression from a printing device at printing station, sensing means at said pair of sensing stations whereby the identifying means of each printing device are sensed successively as they come to rest in the successive sensing stations, and means coordinating the sensing operations of the sensing means which are performed in two different machine cycles pertaining to a particular printing device to stop the machine at the end of still another machine cycle when such particular printing device bears identifying means at a particular identifying position, and at the same time to exhibit a visual indication of other identifying means carried by the particular printing device.

42. In a printing machine through which a series of printing devices, each adapted to bear identifying means at one or more selected identifying positions thereon, are adapted to be advanced from a magazine along a guideway providing a pair of sensing stations and a printing station at spaced points therealong, printing device advancing means for advancing such printing device through the machine in a step by step manner such that each printing device comes to rest at sensing and printing stations, a plurality of indicating devices, sensing means at each of said sensing stations movable through sensing strokes to sense the identifying means of a printing device at the associated sensing station, selector mechanism, printing means for producing a printing impression from a printing device at printing station and governed by said selector mechanism to produce print or skip operation of the machine in accordance with the sensing means operative at one of said sensing stations, and governing means for said indicating devices controlled in part by said sensing means operative at the other of said sensing stations, and means controlled by said selector mechanism to sound an audible signal and cooperate with said governing means to render one of said visual indicating devices operative when a printing device from which a printing impression is to be made is advanced to a particular station along said guideway.

43. In a printing machine having a plurality of operative mechanisms and including a sensing position through which a series of printing devices, each adapted to bear identifying means at one or more identifying positions thereon, may be passed one by one and in a step-by-step manner such that each printing device comes to rest at said sensing position, a plurality of shiftable control members each allocated to the control of a different operative mechanism of the machine and each adapted when actuated through a control movement to cause predetermined operation of the operative mechanism to which it is allocated, a governing element having an actuating part adapted by shifting set up movement of said element from an idle position in a first direction to be located in any one of a plurality of different set positions wherein it is aligned with different ones of said control members for imparting shifting control movement to the control member with which it is aligned when said governing element is moved in a second direction, sensing means operable to sense the identifying means of a printing device at sensing position and operatively associated with said governing

element to align said actuating part with different control members in accordance with the sensed identifying means, and means for variably connecting at least selected of said control members together to vary the controlling action of said governing element on the operative mechanisms of the machine.

44. In a printing machine having a plurality of operative mechanisms and including a sensing position through which a series of printing devices, each adapted to bear identifying means at one or more identifying positions thereon, may be passed one by one and in a step-by-step manner such that each printing device comes to rest at said sensing position, a plurality of shiftable control members through selective actuation of which different operation of the operative mechanisms of the machine may be instituted, a governing element having an actuating part adapted by shifting set up movement of said element in a first direction from an idle position to be located in any one of a plurality of different set positions wherein it is aligned with different ones of said control members for imparting shifting control movement to the control member with which it is aligned when said governing element is moved in a second direction, sensing means operable to sense the identifying means of a printing device at sensing position and operatively associated with said governing element to align said actuating part with different control members in accordance with the sensed identifying means, and means for moving said governing element in said second direction.

45. In a printing machine having a plurality of operative mechanisms and including a sensing position through which a series of printing devices, each adapted to bear identifying means at one or more identifying positions thereon, may be passed one by one and in a step-by-step manner such that each printing device comes to rest at said sensing position, sensing means operable to sense the identifying means of a printing device at sensing position, a plurality of shiftable control members for governing operation of selected of said operative mechanisms, a settable governing element operatively associated with and settable by said sensing means and shiftable along one path from an idle position to any one of at least two different active governing positions in accordance with the identifying means sensed by said sensing means, said different active governing positions of said governing element being such as to dispose said element for active cooperation with different ones of said shiftable control members to impart control movement thereto when said governing element is shifted along a second path, and means for shifting said governing element along said second path.

46. In a printing machine having a plurality of operative mechanisms and including a sensing position through which a series of printing devices, each adapted to bear identifying means at one or more identifying positions thereon, may be passed one by one and in a step-by-step manner such that each printing device comes to rest at said sensing position, a plurality of shiftable control members each allocated to the control of a different operative mechanism to which it is allocated, a governing element having an actuating part adapted by shifting set up movement of said element in a first direction from an idle position to be located in any selected one of at least two different set positions wherein it is

arranged for cooperation with different ones of said control members for imparting shifting control movement to such control member when said governing element is moved in a second direction, sensing means operable to sense the identifying means of a printing device at sensing position and operatively associated with said governing element to arrange said actuating part for cooperation with different control members in accordance with the sensed identifying means, and means for shifting at least one of said control members to different positions to arrange the same for operation by the actuating part of said governing element in different set positions thereof whereby to vary the governing effect of said governing element.

47. In a machine having a plurality of operative mechanisms, means providing a sensing position, a guideway along which a series of devices each adapted to bear identifying means at one or more of a plurality of identifying positions thereon are adapted to be advanced to and through said sensing station, means for imparting such advancing movement to a series of such devices, sensing means operable to sense the identifying means of each such device as it is located in said sensing position, a storage drum mounted for controlled movement in a rotative direction and having a plurality of storage plungers mounted for individual shifting movement from idle position to any one of at least two set-up positions on said drum, means operable under control of said sensing means to shift said storage plungers to different set up positions in accordance with the identifying means sensed by said sensing means, and a plurality of individually operable control elements each operable in a control actuation thereof to control a different one of said operative mechanisms of the machine, said control elements being selectively operable by each of said storage plungers in accordance with the set up position of such storage plunger on said drum.

48. In a machine having a plurality of operative mechanisms, means providing a sensing position, a guideway along which a series of devices each adapted to bear identifying means at one or more of a plurality of identifying positions thereon are adapted to be advanced to and through said sensing station, means for imparting such advancing movement to a series of such devices, sensing means operable to sense the identifying means of each such device as it is located in said sensing position, a plurality of shiftable control members each allocated to the control of a different operative mechanism to which it is allocated, a governing element having an actuating part adapted by shifting set up movement of said element in a first direction from an idle position to be located in any selected one of at least two different set positions wherein it is arranged for cooperation with different ones of said control members for imparting shifting control movement to such control member when said governing element is moved in a second direction, sensing means operable to sense the identifying means of a device at sensing position and operatively associated with said governing element to arrange said actuating part for cooperation with different control members in accordance with the sensed identifying means, and means for shifting at least one of said control members to different positions to arrange the same for operation by the actuating part of said governing element in different set

positions thereof whereby to vary the governing effect of said governing element.

48. In a machine having a plurality of operative mechanisms, means providing a sensing position, a guideway along which a series of devices each adapted to bear identifying means at one or more of a plurality of identifying positions thereon are adapted to be advanced to and through said sensing station, means for imparting such advancing movement to a series of such devices, sensing means operable to sense the identifying means of each such device as it is located in said sensing position, a plurality of shiftable control members for governing operation of selected of said operative mechanisms, 15

a settable governing element operatively associated with and settable by said sensing means and shiftable along one path from an idle position to any one of at least two different active governing positions in accordance with the identifying means sensed by said sensing means, said different active governing positions of said governing element being such as to dispose said element for active cooperation with different ones of said shiftable control members to impart control movement thereto when said governing element is shifted along a second path, and means for shifting said governing element along said second path.

CARL J. HUEBER.
